MACHINE FOR PACKAGING CYLINDRICAL ARTICLES

Grover Cleveland Currie, Bernard David Dans,
 Louis Frederick Wilkens, and Maurice B. Dunn,
 Charlotte, N. C., assignors to Dacam Corpora-
 tion, Charlotte, N. C., a corporation of North
 Carolina

Application December 26, 1951, Serial No. 263,206

95 Claims. (Cl. 53—34)

1

This invention relates to packaging machinery and more especially to an improved machine for placing cylindrical articles, such as beer cans and the like, in carriers and for placing a plurality of carriers in a common container, such as a paper board box.

The improved packaging machine is particularly designed to accommodate carriers of the type shown in the co-pending application of Grover C. Currie, Serial No. 185,072, filed September 15, 1950, and entitled Carrier. The machine is also particularly designed for carrying out the method disclosed in the co-pending application of Grover C. Currie, Serial No. 190,327, filed October 16, 1950, and entitled Method of Forming Carriers.

It is the primary object of this invention to provide a fully automatic machine having a magazine for receiving a stack of flat, substantially rectangular carrier blanks, preferably made from cardboard, and means for partially folding the carrier blanks as they are propelled through the machine and wherein means are provided above the path of travel of the carriers for directing cylindrical articles, such as beer cans and the like, to a point immediately above the path of travel of the partially folded carrier with means to deposit a predetermined number of the cylindrical articles into the partially folded carrier. After the articles are deposited in each carrier, the carrier is folded in the form of a rectangular tube to completely surround the said cylindrical articles, after which means are provided for stitching or otherwise securing the walls of the carrier together. As the carrier is subsequently advanced another step through the machine, means are provided for folding an outwardly extending flap, defining a handle on the carrier, against the carrier and, upon a predetermined number of carriers being advanced through the machine, means are provided for moving a predetermined number of carriers into a relatively large container, carton or box subsequent to which the operator merely has to seal the box, carton or container to prepare the same for further handling or shipment.

More specifically, it is an object of this invention to provide an improved packaging machine for packaging cylindrical articles comprising an intermittently movable conveyor and a magazine for containing carrier blanks disposed in advance of the conveyor and having means for feeding the carrier blanks, one at a time, to the conveyor. An inclined chute is disposed above

2

the magazine and a portion of the conveyor for directing cylindrical articles to an article depositing station which is spaced closely above the conveyor and subsequent to the magazine. The machine also has means for initially folding the carrier to form opposite side flaps or panels which extend in substantially perpendicular relation to a bottom portion of the carrier and wherein the carrier rests on said bottom portion as it is propelled through the machine in a step-by-step manner. Upon each carrier reaching the depositing station, beneath the articles, means are provided for directing a predetermined number of the cylindrical articles into the carrier and for preventing a greater number than said predetermined number of cylindrical articles from escaping from the lower end of the inclined chute until each subsequent carrier is properly positioned for reception of a predetermined number of articles.

After said predetermined number of articles have been properly positioned in the carrier, another step is imparted to the conveyor to cause the carrier to move therewith through a folding means folding one side of the carrier intermediate its ends to form a top flap positioned against the upper surfaces of the cylindrical articles, the carrier being so shaped to also form a pair of outwardly projecting handle portions which extend longitudinally of the carrier and in overlapping relation to each other. The carrier is then in the form of an elongated rectangular tube and, upon the next step in movement of the conveyor, the carrier is passed through a suitable stitching means, such as a stapler, and the handle portions, one of which extends outwardly from one edge of the first side wall of the carrier and the other of which extends from the top flap or uppermost wall of the carrier, are stapled or stitched together.

Another step or series of steps is then imparted to the conveyor to cause each successive carrier to move to a filled carrier boxing station in the course of which the handle portions are folded against the first side wall of the carrier. Means are provided at the boxing station which operate in timed relation to the step-by-step movement of the conveyor for moving each successive filled carrier upwardly in superposed relation to each other to position the same in alignment with an opening in the frame of the machine which has means thereon on which a carton, box or relatively large container may be positioned with its open end facing said opening in the frame of the machine.

Upon a group of a predetermined number of the filled carriers being elevated in juxtaposition, means are provided for automatically moving the group of carriers laterally through said opening in the frame of the machine and into the carton, container or box previously positioned in communication with said opening. Thus, the box is completely filled with the carriers containing the cylindrical articles, after which the carton, box or container, may be folded and sealed for further handling or shipment.

Some of the objects of the invention having been stated, other objects will appear as the description proceeds when taken in connection with the accompanying drawings, in which—

Figure 1 is a right-hand side elevation of our packaging machine showing many of the parts schematically and many of the parts being omitted for purposes of clarity;

Figure 2 is an enlarged fragmentary elevation showing the ingress or feed end of the machine and being an enlarged elevation of the left-hand portion of Figure 1;

Figure 2-A is an extension to the right hand end of Figure 2 illustrating the station at which the cylindrical articles are introduced into the partially folded carrier;

Figure 2-B is an extension to the right-hand end of Figure 2-A illustrating the stitching device on the machine and showing the manner in which it is driven in timed relation to movement of the conveyor;

Figure 2-C is an extension to the right-hand end of Figure 2-B showing the boxing station at the discharge end of the machine and also being an enlarged view of the right-hand portion of Figure 1;

Figure 3 is an enlarged elevation looking at the left-hand end of Figure 1 showing the magazine and showing the chute disposed thereabove partially in cross-section with many of the parts disposed forwardly of the magazine and the chute being omitted for purposes of clarity;

Figures 4, 4-A, 4-B and 4-C are views of the opposite side of the machine from that shown in the respective Figures 2, 2-A, 2-B and 2-C;

Figure 5 is an enlarged front or discharge end view of the machine looking at the right-hand side of Figure 1;

Figures 6, 6-A, 6-B and 6-C are top plan views of substantially the portions of the machine shown in the respective Figures 2, 2-A, 2-B and 2-C and wherein portions of the base of the machine are broken away;

Figure 7 is a fragmentary isometric view of the framework associated with the carrier feeding station and the article depositing station with parts broken away and many of the parts being omitted for purposes of clarity;

Figure 7-A is an extension to the right-hand end of Figure 7 showing the framework associated with the stitching station and the boxing or discharge station of the machine with parts broken away and many other parts being omitted for purposes of clarity;

Figure 8 is a longitudinal vertical sectional view, taken substantially along the line 8—8 in Figure 6, showing the carrier magazine, the carrier feeding means, and the means for initially partially folding each of the carriers in the form of a channel or trough;

Figure 9 is an enlarged elevation of the left-hand portion of Figure 2, with parts broken away and parts in different positions, showing means

for automatically raising the magazine as carrier blanks are fed to the conveyor;

Figure 10 is an enlarged fragmentary vertical sectional view taken substantially along the line 10—10 in Figure 6 showing the carrier blank locator means for positioning the carrier blanks on the conveyor;

Figure 11 is a fragmentary transverse vertical sectional view taken substantially along the line 11—11 in Figure 10 with parts broken away for purposes of clarity;

Figure 12 is a longitudinal vertical sectional view taken substantially along the line 12—12 in Figure 6-A showing, in inoperative position, the means for transferring or depositing a predetermined number of the cylindrical articles into a partially folded carrier disposed beneath the depositing means;

Figure 13 is an enlarged view of the upper portion of Figure 12 showing the article depositing means in lowered or operative position;

Figure 14 is an enlarged transverse vertical sectional view, taken substantially along the line 14—14 in Figure 12, showing the means for initially folding the carrier blank in the form of a trough or channel for reception of a row of cylindrical articles;

Figure 15 is an enlarged fragmentary vertical sectional view, taken substantially along the line 15—15 in Figure 12, showing a carrier after a row of cylindrical articles has been deposited therein and showing the means for folding the back or upper wall or flap so that the handle portions on the first side wall and upper flap of the carrier are disposed in overlapping relation to each other;

Figure 16 is an enlarged fragmentary transverse vertical sectional view, taken substantially along the line 16—16 in Figure 12, showing the manner in which a row of cylindrical articles are deposited in the partially folded carrier;

Figure 17 is a transverse vertical sectional view through the cylindrical article depositing station looking rearwardly substantially along the line 17—17 in Figure 4-A;

Figure 18 is an elevation of the rear end of the cylindrical article depositing station, with parts in cross-section, looking forwardly substantially along the line 18—18 in Figure 4-A;

Figure 19 is a fragmentary vertical sectional view taken substantially along the line 19—19 in Figure 18;

Figure 20 is an enlarged fragmentary vertical sectional view taken substantially along the line 20—20 in Figure 18;

Figure 21 is an enlarged fragmentary elevation looking substantially along the line 21—21 in Figure 17 and showing the cam shaft in cross-section;

Figure 22 is a fragmentary elevation looking substantially along the line 22—22 in Figure 17, showing the cam shaft in cross-section;

Figure 23 is a fragmentary elevation looking substantially along the line 23—23 in Figure 17 and showing the cam shaft in cross-section;

Figure 24 is a fragmentary elevation looking substantially along the line 24—24 in Figure 17 and showing the cam shaft in cross-section;

Figure 25 is a fragmentary elevation looking substantially along the line 25—25 in Figure 18 and showing the cam shaft and the crank pivot shaft in cross-section;

Figure 26 is a fragmentary elevation looking substantially along the line 26—26 in Figure 18 and showing the cam shaft in cross-section;

Figure 27 is a fragmentary elevation looking substantially along the line 27—27 in Figure 18 and showing the cam shaft in cross-section;

Figure 28 is a fragmentary elevation looking substantially along the line 28—28 in Figure 17 and showing the cam shaft in cross-section;

Figure 29 is a vertical sectional view, taken substantially along the line 29—29 in Figure 4-C, showing the means for elevating and stacking the filled carriers at the discharge end of the machine;

Figure 30 is an enlarged fragmentary sectional plan view, taken substantially along the line 30—30 in Figure 2-C, with parts broken away;

Figure 31 is a fragmentary elevation with parts in section looking substantially along the line 31—31 in Figure 29;

Figure 32 is a fragmentary elevation with parts in section looking substantially along the line 32—32 in Figure 29;

Figure 33 is a fragmentary elevation, with parts in section and other parts being broken away, looking substantially along the line 33—33 in Figure 29 but also showing parts above the line 33—33;

Figure 34 is a fragmentary elevation of the clutch mechanism, with parts in section and other parts being broken away, looking substantially along the line 34—34 in Figure 18;

Figure 35 (sheet 14) is a fragmentary elevation with parts in section looking substantially along the line 35—35 in Figure 18;

Figure 36 is a fragmentary inverted plan view, with parts broken away, looking substantially along the line 36—36 in Figure 34;

Figure 37 is a fragmentary vertical sectional view taken substantially along the line 37—37 in Figure 34;

Figure 38 is a fragmentary elevation, looking substantially along the line 38—38 in Figure 29, showing the cam shaft in cross-section;

Figure 39 is a fragmentary elevation, looking substantially along the line 39—39 in Figure 29, showing the cam shaft in cross-section;

Figure 40 is a fragmentary vertical sectional view through the upper reach of the endless conveyor taken substantially along the line 40—40 in Figure 6-B and showing one of the means for gripping the leading portion of each carrier and one of the means for engaging the trailing edge of each carrier to insure that the carriers and the corresponding groups of articles move in unison with the conveyor;

Figure 41 is an isometric view of the carrier conveyor grasping device shown in the left-hand portion of Figure 40;

Figure 42 is an enlarged sectional plan view through the vacuum control valve for the blank transferring mechanism and is taken substantially along the line 42—42 in Figure 9;

Figures 43 and 43-A illustrate a wiring diagram, showing the electrical system of the machine, wherein many of the parts are shown schematically.

Referring more specifically to the drawings, as above-noted the improved packing machine is arranged in a series of sections or stations, which sections perform a series of successive packaging operations and wherein each of the sections performs its particular operation on a corresponding unit simultaneously with the remaining sections performing operations on corresponding units and the units being transferred from one station or section to the next succeeding section following the operation of each of the sections or stations.

For purposes of description, and to assist the reader in readily determining the location of the various elements of the improved packaging machine as they are described, it will be observed in Figure 1 that the machine is divided into four primary serially arranged sections or stations having a somewhat independent frame structure or framework. The framework of the first section or station is broadly designated at 20 and the station defined by this framework 20 may be termed as the carrier blank magazine and feeding station.

Means, to be later described, are provided on the carrier blank magazine and feeding station 15 for supporting a stack of superposed substantially rectangular carriers in sheet or blank form which are generally designated at B in Figures 2 and 3. These carrier blanks and the carriers subsequently formed therefrom are preferably of the 20 type disclosed in my said co-pending applications, Serial Numbers 185,072 and 190,327. When the carrier blanks are placed in the magazine, as shown in Figures 2 and 3, they are in a flat state and are subsequently fed into the machine, one 25 at a time, and are passed into engagement with folding devices to form a bottom wall B-1, which faces downwardly throughout the course of each carrier's movement through the machine, and to also form a first side wall or flap B-2 and a second side wall or flap B-3 (Figures 14 and 15). These side walls B-2 and B-3 are disposed in a substantially vertical position as each carrier B is propelled through the machine.

Each of the carriers also has an upper wall B-4, 35 which is formed as the carrier B passes through the machine, as shown in Figure 15, and a portion of the upper wall B-4 extends beyond the vertical plane of the first side wall B-2, thus defining a handle portion B-5 which coincides with a handle 40 portion B-6 which normally projects laterally from the upper edge of the first side wall B-2 in perpendicular relation thereto.

It is to be noted that the bottom wall B-1, the first and second side walls B-2 and B-3 and the upper walls B-4 are termed as such because of 45 the attitude of these walls throughout movement of each carrier B through the machine. However, after the filled carriers have been stacked and boxed, or during display of the filled carriers, the filled carriers usually rest upon their second 50 walls B-3. Accordingly, the nomenclature of these carriers would then change and the walls of these carriers are termed in said co-pending applications in accordance with the usual relative disposition of the walls.

Now, before the upper wall B-4 is formed, a group of cylindrical articles, such as beer cans and the like, each having a peripheral bead at opposite ends thereof, are deposited upon the bottom wall B-1 of the carrier B between the first 60 and second side walls B-2 and B-3, by means to be later described. The carrier B is then substantially channel-shaped or trough-shaped to permit the group of articles to be deposited therein. Each of the substantially cylindrically-shaped articles is indicated at C in Figures 8, and 65 12 to 15, inclusive, there being a group of six of these cylindrical articles C deposited in each successive carrier as it is positioned at an article depositing or dispensing station generally defined by a framework broadly designated at 21, this framework 21 may also be termed as the second section or framework of the machine.

After each of the carriers B, in their channel-shaped configuration, has had a group of a pre-determined number of the cylindrical articles C

deposited therein, the carrier B with the articles therein is propelled another step through the machine during which the second side wall B-3 is folded intermediate its ends from the substantially vertical position shown in Figure 14 to the substantially horizontal position shown in Figure 15 to form the upper wall B-4 and wherein the carrier B is then in substantially the form of a rectangular tube and the articles C in the carrier are then completely circumscribed by the walls of the carrier B.

Each successive carrier B, with the group of articles C therein, then passes through a third section or framework broadly designated at 22. This third framework defines a stapling, fastening or stitching station wherein the handle portions B-5 and B-6 on each of the carriers B are stitched, stapled or otherwise secured together at a point closely adjacent the juncture of the handle portion B-6 with the first side wall B-2 of the corresponding carrier B. After each of the carriers passes through the stitching station, to be later described, comprising the framework 22, a folding means is provided for folding the handle portion B-6 downwardly against the outer surface of the first side wall B-2 and to simultaneously fold the handle portion B-5 downwardly therewith.

The carriers then successively pass into a filled carrier stacking and boxing station, to be later described, the framework of which is broadly designated at 23. This station comprising the framework 23, may also be termed as the fourth section or framework.

Thus it is necessary that the first, second, third and fourth respective frameworks 20, 21, 22 and 23 are accurately spaced with respect to each other, and, accordingly, it is preferable that each framework be supported on and secured to a common base member 24. However, it is to be understood that these frameworks 20, 21, 22 and 23 may be secured to a floor when the machine is assembled provided that the frameworks 20, 21, 22 and 23 are spaced the required distance from each other.

The framework 20 of the machine and carton or carrier blank feeding station or section comprises right-hand and left-hand upright side frame members 30 and 31 which are preferably of cast construction (Figures 1, 2, 3, 4, 6, 7 and 8) and comprise respective front and rear legs 32 and 33 and 34 and 35. The legs 32 and 33 of the right-hand side frame member 30 are bridged intermediate their ends by a lower horizontal frame portion 36 and are bridged at their upper ends by an upper horizontal frame portion 37.

The legs 34 and 35 of the left-hand side frame member 31 (Figures 4 and 7) are bridged intermediate their ends by a lower horizontal frame portion 40 and are bridged at their upper ends by an upper horizontal frame portion 41. The legs 32 to 35 of the side frame members 30 and 31 of the section or station 20 are suitably secured to the base member 24 as by screws 42. The side frame members 30 and 31 are substantially the same except being opposite hand as is clearly shown in Figure 7.

The legs 32 and 34 of the respective side frame members 30 and 31 are spanned by a vertically disposed plate or frame member 44, disposed at a slightly higher elevation than the lower frame portions 36 and 40 (Figure 8), which is suitably secured, as by screws 45, to angle clips 46 which are, in turn, suitably secured as by screws 47

to the proximate surfaces of the legs 32 and 34.

The front legs 33 and 35 of the respective side frame members 31 and 32 are bridged by a vertically disposed plate or frame member 50 which is also suitably secured, as by screws 51, to angle clips or brackets 52 which are suitably secured, as by screws 53, to the proximate surfaces of the legs 33 and 35 (Figure 8). This frame member 50 is disposed in substantially the same horizontal plane as the frame member 44. Spaced above and forwardly of the transverse frame member 50 is a transverse frame member or bar 54, opposite ends of which are secured to the proximate surfaces of the legs 33 and 35 of the respective side frame members 30 and 31 as by screws 54a (Figures 2 and 4).

This transverse frame member or bar 54 of the first framework 20 supports the rear end of a substantially U-shaped or channel-shaped trackway broadly designated at 55 and which comprises a bottom member 56 and spaced side walls 57 and 58. It will be observed in Figure 8, that the rear end of the bottom wall 56 of the trackway 55 is spaced from the upper surface of the bar or frame member 54 by a spacing block 60 and the trackway 55 and the block 60 are secured to the upper surface of the transverse frame member 54, by any suitable means, such as bolts 61. The trackway 55 extends forwardly and it will be observed in Figure 12 that the trackway 55 rests upon transverse frame members 62 and 63 of the second framework 21.

Opposite ends of the transverse frame member 62 are suitably secured to the proximate surfaces of the legs 64 and 65 of respective right-hand and left-hand side frame members broadly designated at 66 and 67, respectively (Figures 1, 2-A, 6-A and 7). The side frame members 66 and 67 also have front legs 70 and 71 to the front surfaces of which opposite ends of the transverse frame member 63 are suitably secured, as by screws 72. The legs 64 and 70 of the side frame member 66 are bridged adjacent their lower ends by a longitudinally extending lower horizontal frame portion 73. Spaced substantially above the horizontal frame portion 73 is an upper or intermediate horizontal frame portion 74 which also is connected at its rear and front ends to the respective legs 64 and 70.

The left-hand side frame member 67 of the framework 21 is substantially the same as the right-hand frame member 66 except being opposite hand and includes a lower horizontal frame portion 75 and an intermediate horizontal frame portion 76, these frame portions 75 and 76 being connected at opposite ends thereof to the legs 65 and 71 (Figures 4-A and 7).

It will be observed in Figures 2-A, 6-A and 12 that the upper ends of the legs 64 and 65 are bridged by a transverse frame member 77 suitably secured to the proximate surfaces of the legs 64 and 65 of the respective side frame members 66 and 67, as by screws 80. Opposite ends of a transverse frame member 81 are suitably secured to the proximate surfaces of the legs 70 and 71 adjacent the upper ends thereof, as by screws 82. The lower ends of the legs 64, 70 and 65, 71 of the respective side frame members 66 and 67 are suitably secured, as by screws 83, to the upper surface of the base 24. This completes the general description of the skeleton framework 21.

The trackway 55 extends forwardly from the second framework 21 and is supported on a lower leg 90 of a substantially G-shaped hollow frame

member or casting 91 (Figure 7-A) which is a part of the stitching station or third framework 22. The substantially G-shaped casting or frame member 91 is suitably secured, as by screws 92, to the upper surface of a pedestal 93, which is preferably of cast construction, which extends downwardly and is suitably secured, as by screws 94, to the upper surface of the base 24. The stitching station will be further described later in this context.

The trackway 55 extends forwardly from the substantially G-shaped frame member or casting 91 of the third framework 22 and rests upon a pair of transverse upper frame portions 95 and 96 of respective rear and front frame members 100 and 101 (Figure 7-A), which are the primary elements of the filled carrier stacking and boxing station or fourth framework 23. The frame member 101 is spaced forwardly of the rear frame member 100 and the frame member 100 comprises right-hand and left-hand legs 102 and 103 which are bridged adjacent their lower ends by a transverse horizontal frame portion 104 spaced substantially below the transverse frame portion 95. It will be noted that the left-hand leg 103 of the frame member 100 extends substantially higher than the right-hand leg 102 and has a relatively large projection 105 integral therewith and which has an overhanging portion 106 integral therewith spaced substantially above the trackway 55 as is clearly shown in Figures 5 and 7-A.

The front frame member 101 of the framework 23 also has legs 110 and 111, which are bridged adjacent their lower ends by a horizontal frame portion 112 and which are bridged adjacent their upper ends by the horizontal frame portion 96 heretofore described.

The front frame member 101 is of substantially identical configuration to that of the rear frame member 100 and the leg 111 thereof extends substantially above the horizontal plane of the leg 110 and has a projection 113 integral therewith, which, in turn, is provided with an overhanging projection 114 spaced above the trackway 55 as is clearly shown in Figures 5 and 7-A. The legs 102, 103, 110 and 111 of the respective rear and front frame members 100 and 101 are suitably secured to the upper surface of the base 24, as by screws 115.

This completes the description of the primary elements of the frameworks 20, 21, 22 and 23 of the machine.

Primary driving means

Referring to Figures 4-A, 6-A and 43-A, there is shown an electric motor 117 having wires 118 and 119 extending therefrom. The wire 118 extends to one side of a normally open magnetic or solenoid operated switch 116. The opposite side of the switch 116 has one end of a wire 116a connected thereto, the other end of which is connected to a manually controlled master switch 120 and the wire 119 extends to one side of a male plug 121 (Figure 43-A) adapted to be connected to a suitable source of electrical energy, not shown. The other side of the male plug 121 has a wire 122 extending therefrom to the opposite side of the switch 120 from that to which the wire 118 is connected. This switch 120 is suitably secured to a plate 124 (Figures 4-A and 6-A) which is suitably secured, as by screws 125, to the uppermost portions of the legs 65 and 71 of the left-hand side frame member 67 of the second framework 21.

When the switch 120 is closed, the electric motor 117 is energized and this causes rotation to be imparted to a motor shaft 126 extending from the electric motor 117 along with a V-pulley 127 fixed on the shaft 126. This V-pulley 127 is of the variable speed type wherein the opposed side portions of the pulley will move toward and away from each other depending upon the tension in the belt 130 mounted thereon. In order to vary the position of the electric motor 117, the electric motor is mounted on a suitable take-up or variable speed control apparatus generally designated at 131 and which is suitably secured to the upper surface of the base 24.

The V-belt 130 extends forwardly from the V-pulley 127 and is mounted on a relatively large V-pulley 137 which is fixed on the outer end of a shaft 140, the outer portion of which is rotatably mounted in a bearing stand 141 suitably secured, as by screws 142, to the upper surface of the base 24 (Figure 4-A). The shaft 140 extends inwardly and its inner portion is rotatably mounted in the lower horizontal frame portion 75 of the side frame member 67 (Figure 17). Fixed on the inner end of the shaft 140 is a sprocket wheel 143 on which a sprocket chain 144 is mounted (Figure 6-A). The point to which this sprocket chain 144 extends will be later described.

It will be observed in Figure 6-A that the hub of the V-pulley 137 has a pinion 145 integral therewith. This pinion 145 may be fixed on the shaft 140. The pinion 145 meshes with a relatively large gear 146 which is fixed on the outer end of a shaft 147. The shaft 147 is also rotatably mounted in the bearing stand 141 adjacent its outer end and extends inwardly and is also rotatably mounted in the horizontal frame portion 75 of the left-hand side frame member 67 of the framework 21. A pinion 150 is fixed on the shaft 147, intermediate the ends thereof, and this pinion 150 meshes with a relatively large gear 151 (Figures 4-A, 6-A, 17, 18 and 35 to 37) which is rotatably mounted on a main cam shaft 152.

It will be observed in Figure 18 that the right-hand outer end of the main cam shaft 152 is rotatably mounted in the bearing stand 141 and extends through a bearing block 153 suitably secured to the rear edge of the side frame member 67. The left-hand portion of the main cam shaft in Figure 18 is supported for rotation in a substantially semi-circular cavity in the rear edge of the side frame member 66 (Figure 7) in which the main cam shaft 152 is held by a bearing bracket 155 suitably secured to the rear edge of the side frame member 66, as by screws 156. The main cam shaft 152 has a plurality of cams fixed thereon which will be later described.

Now, in order to transmit rotation to the main cam shaft 152 if the various parts of the machine are operating in proper sequence and if the carriers are properly positioned at each of the operating stations, a clutch mechanism is provided, of which the gear 151 is a part. Referring to Figure 35 (sheet 14), it will be observed that the inner face of the gear 151 has a substantially circular clutch plate 157 suitably secured thereto, as by screws 160. The clutch plate 157 has a plurality of circularly spaced cavities 161 in its periphery which are adapted to be engaged by a dog to be presently described (Figures 34 to 37, inclusive).

Fixed on the shaft 152 adjacent the gear 151 (Figures 17, 18 and 34 to 37) is a clutch dog

housing 163 having an arm 164 integral therewith provided with a transverse slot 165 which extends in parallel relation to the axis of the shaft 152. The lower end of the arm 164, as viewed in Figures 36 and 37, has two plates 166 and 167 suitably secured thereto, as by screws 168. The plates 166 and 167 are held in spaced relation by the screws 168 and permit a clutch knife 171 to pass therebetween during the engagement of the knife 171 with the clutch dog 162. The knife 171 is swung into and out of the path of the arm 164 as such arm rotates. The clutch dog 162 is slidably mounted in the slot 165 and has a horizontally disposed hole 172 therein in which is loosely mounted a compression spring 173. The opposite end of the spring 173 normally presses against the inside vertical surface of a cam wheel 174 and forces the clutch dog 162 to the right in Figure 37 thereby forcing it into one of the cavities 161 in the plate 157.

The clutch knife 171 is secured to one end of a lever arm 175 pivotally mounted, as at 176 (Figures 18, 34 and 43), in a standard 177 suitably secured, as by screws 180, to the upper surface of the base 24. The lower end of a tension spring 181 is connected to the end of the lever arm 175 to which the knife 171 is secured and has its upper end connected to the lower horizontal portion 75 of the left-hand side frame member 67 of the second framework 21. Thus, the tension spring 181 normally urges the knife 171 upwardly to operative position.

It might be stated that as the knife 171 moves upwardly in Figure 34, the knife moves into a notch 182 in the outer surface of the dog 162 and, since the free end of the knife 171 and the wall of the notch 182 are provided with mating beveled surfaces (Figure 36) rotation of the arm 164 with the shaft 152 causes the knife 171 to engage the beveled wall of the notch 182 and to thereby move the dog 162 toward the cam wheel 174. This causes the dog 162 to move out of engagement with the corresponding cavity 161 in the periphery of the clutch plate 157 and stops the cam shaft 152.

Of course, when the knife 171 is again moved downwardly in Figures 34, 35 and 37, and as the right-hand end of the lever arm 175 moves downwardly in Figure 34, the dog 162 is again permitted to move into engagement with the next succeeding cavity 161 in the periphery of the plate 157 to again cause rotation to be imparted to the cam shaft 152. Referring to Figure 34, it will be observed that the end of the lever arm 175, remote from the end to which the knife 171 is secured, has the lower end of a solenoid plunger 185 pivotally connected thereto, as at 186. This solenoid plunger 185 is partially surrounded by a solenoid coil 187 which is a part of the electrical circuit to be later described (Figures 43 and 43-A). The solenoid coil 187 is disposed in a suitable housing 190 secured to and depending from a bracket or standard 191 suitably secured, as by screws 192, to the upper surface of the base 24.

In order to limit upward movement of the knife 171, a bumper 193 is adjustably secured to the lower surface of the lever arm 175 adjacent the solenoid plunger 185 and, as the solenoid coil 187 is deenergized in the manner to be described, the tension spring 181 causes the lever arm 175 to move in a counter-clockwise direction (Figures 34 and 43) until the bumper 193 engages the upper surface of a corresponding bumper 194.

suitably mounted on the upper surface of the base 24. This bumper 193 is also preferably adjustably mounted on the base 24 in order to determine the position of the knife 171 when it is in a raised position.

It will be observed in Figures 6-A, 6-B, 17 and 18 that the main cam shaft 152 has a sprocket wheel 195 fixedly mounted thereon on which the front portion of a sprocket chain 196 is mounted (Figure 34). This sprocket chain 196 extends rearwardly and drives a sprocket wheel 197 (Figures 4-C, 6-C and 29) which is fixed on a secondary cam shaft 200 which may also be termed as a filled carrier stacking cam shaft. The cam shaft 200 is rotatably mounted in bearing blocks 201 and 202 which bridge and are suitably secured to the proximate surfaces of the legs 102, 110 and 103, 111 (Figure 29) of the rear and front frame members 100 and 101 of the fourth framework 23. The secondary cam shaft 200 has a plurality of cam wheels thereon to be later described.

The cam shaft 200 is also instrumental in driving a conveyor broadly designated at 205 in a step-by-step manner in timed relation to the operation of the various other operative parts of the machine. Referring to Figures 4-C, 5 and 29, it will be observed that one end of the cam shaft 200 has a crank arm 206 fixed thereon, to the free end of which a longitudinally adjustable connecting rod 207 is pivotally connected as at 210. The connecting rod 207 extends upwardly and rearwardly at an angle in Figure 4-C and is pivotally connected, as at 211, to the lower end of an angularly disposed rack 212, the teeth of which face upwardly in Figure 4-C.

The rack 212 is mounted for longitudinal sliding movement in a pair of spaced guide blocks 215 suitably secured to the outer surface of a bracket 213 which extends rearwardly and is suitably secured, as by screws 214 (Figures 4-C, 5 and 6-C), to the front surface of the front frame member 101. The rack 212 meshes with a pinion 217 (Figure 6-C) rotatably mounted on a front conveyor shaft 220. As is most clearly shown in Figures 5 and 6-C, the shaft 220 is rotatably mounted in the bearing bracket 213 and in a bearing block 221 suitably secured to the front frame member 101 of the front or fourth framework 23, as by screws 222. The left-hand end of the shaft 220, in Figure 5, has a sprocket wheel 223 fixed thereon on which an endless belt or conveyor chain 224 of the conveyor 205 is mounted. The structure of the conveyor will be presently described in detail.

The end of the shaft 220 remote from the conveyor 205 (Figures 4-C, 5 and 6-C) has a flanged hub member 225 fixed thereon. This flanged hub member 225 may also be termed as a ratchet wheel having a pair of substantially diametrically opposite notches 226 and 227 in the periphery thereof (Figure 4-C). It will be noted that the gear or pinion 217 has a pair of substantially diametrically opposite radially extending arms 230 integral with its hub portion on the remote ends of which oppositely facing ratchet pawls or dogs 231 and 232 are pivotally mounted. The free ends of these ratchet pawls 231 and 232 are normally urged into engagement with the periphery of the ratchet wheel 225 by tension springs 233 (Figure 5), there being one of these tension springs 233 connected to each of the ratchet pawls 231 and 232 adjacent the free end thereof and each of the tension springs 233 extending inwardly and being connected at their other ends

13

to the corresponding arm 230 extending from the hub portion of the pinion 217.

Now, assuming the parts to be in the position shown in Figure 4-C, upon further counter-clockwise movement of the cam shaft 200, the rack 212 will move upwardly slightly to thereby cause the pinion 217 to move the arms 230 slightly, in a clockwise direction in Figure 4-C. It is evident that the ratchet pawls 231 and 232 will then drop into the respective notches 226 and 227 and, with further counter-clockwise movement of the shaft 200, the rack 212 will move downwardly or substantially from left to right in Figure 4-C to impart substantially a half revolution in movement to the arms 230 and the pawls 231 and 232 to, accordingly, cause the ratchet wheel 225 to impart a half revolution to the front conveyor shaft 220. Since the sprocket wheel 223 is fixed on the conveyor shaft 220, this will effect a step in movement to the conveyor 205.

Referring to Figures 5 and 6-C, it will be observed that the shaft 220 has a brake drum 235 fixed thereon which is encircled by brake bands 236 and 237, the rear ends of which are connected to a common pin 240 projecting laterally from the bracket 213. The front ends of the brake bands are interconnected by a bolt 241 surrounded by a compression spring 239 to therefore urge the brake bands 236 and 237 into frictional engagement with the periphery of the brake drum 235. The purpose of this braking mechanism, comprising the brake drum 235 and brake bands 236 and 237, is to dampen the movement of the shaft 220 to prevent build up of excess momentum of said shaft and the conveyor 205 to thus relieve the stresses caused by momentum of the conveyor 205 as a step is imparted thereto and to thereby prevent the rack 212 and pinion 217 from becoming worn excessively as a result of the sudden changes in the rate of movement of the rack 212 caused by the crank arm 210 as the pivot pin 210 thereon moves past dead center relative to the cam shaft 200 and as it moves perpendicular to dead center.

It is evident that the rack 212 will move at a much faster rate as the pin 210 moves through an arc perpendicular to dead center relative to the shaft 200, than it will move when the pin 210 is moving in an arc substantially dead center with respect to the shaft 200. In other words, the brake mechanism retards movement of the shaft so that movement is always imparted to the shaft from the rack 212 rather than the shaft 220 imparting or tending to impart movement to the rack 212 due to momentum.

In order to further insure that the conveyor 205 is properly positioned at the termination of each step imparted thereto, it will be observed in Figures 2-C, 5, 29 and 32 that a positive conveyor locking means is provided comprising a pair of diametrically opposite radially extending locking bars 242 and 243 suitably secured to the outer surface of the sprocket wheel 223, as by screws 244. The two locking bars 242 and 243 are provided since the circumference of the sprocket wheel 223 is equal to the distance the conveyor 205 moves upon two steps in movement being imparted thereto.

The outer end of each of the locking bars 242 and 243 has a notch or cavity 245 therein (Figures 2-C and 32) which are adapted to be alternately engaged by a locking latch member 246 fixed on the front end of a lever arm 247. The latch member 246 is normally urged upwardly by a tension spring 250 connected at its lower end

14

to the front portion of the lever arm 247 and being connected at its upper end to the side wall 51 of the trackway 55. In order to direct the latch member 246 into the notch 245 and the corresponding locking bars 242 and 243, each of the locking bars 242 and 243 has an angle clip 251 suitably secured to the leading edge thereof, the outer flange of which is curved substantially to conform to its path of movement about the front conveyor shaft 220.

The lever arm 247 is oscillatably mounted on a stub shaft 252 fixed in a block 253 suitably secured, as by screws 254, to the leg 110 of the front frame member 101 of the framework 23. In order to move the latch member 246 out of engagement with the corresponding locking bar 242 or 243 immediately in advance of each step being imparted to the conveyor 205, the rear end of the lever arm 247 is pivotally connected, as at 256, to the upper end of a longitudinally adjustable connecting rod 257 (Figures 29 and 32).

The lower end of the connecting rod 257 has a yoke member 260 connected thereto, the bifurcated lower end of which straddles the secondary cam shaft 200 and has a cam follower 262 rotatably mounted thereon which is normally urged against the periphery of a cam wheel 263 by the tension spring 250 heretofore described. This cam wheel 263 is fixed on the cam shaft 200. Since the cam shaft 200 is driven to rotate a single revolution as each step is imparted to the conveyor 205, one side of the cam wheel 263 is lower than the other side thereof and, upon the low side of the cam 263 moving into engagement with the cam follower 262, the latch member 246 is permitted to move into engagement with the notch 245 in the corresponding locking bar 242 or 243 to stop the conveyor 205 in the desired position. Of course, when the cam follower 262 moves into engagement with the high side of the cam wheel 263, the connecting rod 257 moves upwardly in Figure 32 to thereby move the latch member 246 out of engagement with the notch 245 in the corresponding locking bar 242 or 243.

45 Conveyer

Referring to Figures 2-B and 4-C in particular, it will be observed that the endless chain 224 of the conveyor 205 has a plurality of equally spaced carrier gripping or clamping devices thereon, each of which is broadly designated at 264 (Figures 40 and 41). These carrier clamping devices 264 are mounted on certain spaced special links on the conveyor chain 224, which special links are indicated at 224a and each of which has a projection 265 thereon. Each of the carrier clamping devices 264 comprises an upper or outer jaw 267 and a lower or inner jaw 268 as is most clearly shown in Figures 40 and 41.

The lower jaw is relatively flat and has a tubular boss portion 271 integral therewith oscillatably mounted on a hinge pin 272. The tubular portion 271 of each of the lower jaws 268 has a screw 273 threadably embedded therein (Figure 40) for securing the lower or inner jaw 268 to the projection 265 on the corresponding special link 224a. Also, fixed on the outer portions of the hinge pin 272 are enlarged boss portions 275 integral with the upper or outer jaw 267.

The outer jaw 267 also has a wing portion or abutment 276, integral with the boss portions 275 thereof, which is disposed in substantially diametrically opposite relation to the outer jaw 267. The purpose of the wing portion or abutment 276 will be later described. The outer or

upper jaw of each of the clamping devices 264 has a pair of clamping projections 277 thereon which are shown in the form of screws threadably penetrating the jaw 267 and normally being urged into engagement with the proximate surface of the lower or inner jaw 268 by compression springs 280.

The compression springs 280 surround guide members in the form of screws 281 and the outer ends thereof bear against the heads of the screws 281, the inner ends thereof bearing against the outer surface of the outer or upper jaw 267. The jaw 267 is provided with suitable holes 282 through which the screws 281 extend and the screws 281 are threadably embedded in the lower or inner jaw 268.

As the carriers B, in blank form, are initially directed to the clamping devices 264, it may sometimes happen that the carrier blanks are not resting tightly against the upper edges of the side walls 56 and 57 of the trackway 55. In this event, the corresponding carrier will be moved forwardly and will engage the rear surfaces of a pair of transversely spaced projections or abutments 284 which project upwardly or outwardly from the outer or upper jaw 267 adjacent the trailing edge thereof. These abutments or projections 284 also assist in confining the cylindrical articles C, as they are deposited in the carrier, to insure that they do not move forwardly at a faster rate than the conveyor 205.

Also, in order to be sure that each of the carriers B is properly positioned, as the front edges thereof are directed between the jaws 267 and 268 in a manner to be later described, the trailing edge of each of the carriers is engaged by a substantially U-shaped confining member 285 which is suitably secured, as by a bolt 286, to the outer surface of a projection 287 on a corresponding special link 224b on the conveyor chain 224. There is one of these special links 224b provided to correspond with each of the special links 224a and there is one of the confining members 285 mounted on each of the special links 224b. These confining members 285 not only engage the rear or trailing edges of the carriers but also serve to prevent the cylindrical articles, which are subsequently deposited in the carriers, from rolling rearwardly relative to the conveyor chain 224. In other words, each group of six cylindrical articles C is positioned between one of the carrier clamping devices 264 and the corresponding confining member 285. The members 264 and 285 are omitted from Figure 1 for purposes of clarity and these members are clearly shown in Figures 6-B, 6-C, 12, and 13. Referring to Figure 1, it will be observed that the lower reach of the endless conveyor chain 224 is exposed throughout its length and the upper reach thereof is confined between the side walls 57 and 58 of the channel-shaped trackway 55. It will be observed in Figure 8 that the rear portion of the conveyor chain 224 is mounted on an idler sprocket wheel 290 rotatably mounted on a stub shaft 291 fixed at one end thereof in a support block 292. The support block 292 is suitably secured to the lower surface of the bottom member 56 of the trackway 55.

Referring to Figure 8, it will be observed that the bottom 56 of the trackway 55 is cut away to provide an opening 293 therein through which the conveyor chain 224 passes as the sprocket wheel 290 moves in a clockwise direction. This opening 293 is of greater width at the point through which the carrier clamping devices 264

pass, since the distance between the side walls 57 and 58 of the trackway 55 is only slightly greater than the width of each of the carrier clamping devices 264.

- 5 It will also be observed in Figures 8 and 17 that the upper reach of the conveyor chain 224 is supported on a relatively thin chain support bar or guide 294 (omitted from Figure 7-A for purposes of clarity) so the upper surface of the jaw 268 of each of the carrier clamping devices 264 is disposed in substantially the same horizontal plane as the upper edges of the side walls 57 and 58 of the trackway 55. This is necessary since the carriers B slide along the upper edges 10 of the side walls 57 and 58 of the trackway 55 as they are advanced through the machine. The chain guide 294 is disposed centrally of the trackway 55 and the lower edge is suitably secured to the upper surface of the bottom member 56 of the trackway 55. This chain support bar 294 extends substantially the entire length of the trackway 55 and terminates at its front and rear ends immediately adjacent the respective sprocket wheels 223 and 290.
- 15 25 In order to relieve the weight of the lower reach of the conveyor chain 224 on the sprocket wheels 223 and 290, it will be observed, in Figures 1, 2-B, 2-C, and 7-A, that there is disposed below the path of travel of the lower reach of the conveyor chain 224 a lower reach support bar 295 which extends longitudinally of the machine and is suitably secured, as by screws 296, to angle bars 297 which are suitably secured, as by screws 300, to the front and rear surfaces of the pedestal 93 of the third or stitching station framework 22. This lower reach support bar 295 is relatively narrow so the legs of the substantially U-shaped confining members 285, the screws 281 and the projections 284 on the clamping devices 264 (Figures 40 and 41) straddle the bar 295 so the boss portions 271 on the carrier clamping devices 264 may slide upon the upper surface of the lower reach support bar 295 as the lower reach of the conveyor chain 224 moves rearwardly.

Magazine and carrier feed mechanism

The magazine broadly designated at M is most clearly shown in Figures 2, 3, 4, 6 and 8. This magazine M comprises a vertically movable magazine base plate 301 which extends transversely of the machine and on which the carriers B in blank or sheet form are placed by an operator. The rear and front edges of the carriers B are confined between vertically disposed plates or walls 302 and 303, respectively, the lower end 50 of the plate 302 being suitably secured to the rear edge of the magazine base plate 301, by any suitable means such as an angle clip 304 and screws 305 (Figures 2, 3, 4 and 8).

The front edge of the magazine base plate 301 moves in sliding engagement with the rear surface of the front plate 303 which is stationary and the upper edge of which terminates substantially short of the horizontal plane of the upper edge of the rear plate 302. This front magazine wall plate 303 is suitably secured, as by screws 306, to an angle plate 307 which is, in turn, suitably secured to a forwardly extending plate 310, by any suitable means such as screws 311. The front portion of the plate 310 is suitably secured, as by screws 313, to the lower surface of the transverse frame member 54 of the first framework 20.

It will be observed, in Figures 6 and 8, that the screws 306 also serve to secure a stripper finger

support bar 314 to the rear surface of the angle plate 307. This support bar 314 has a plurality of resilient stripper members or elements 315 fixed thereto, which project upwardly therefrom, and the free rear edges of which are disposed above the vertical plane of the front edges of the carriers stacked in the magazine M. It will be also observed in Figure 6 that there are three of these stripper elements 315 provided on the bar 314.

These stripper elements 315 are provided to prevent the carrier transfer mechanism, to be presently described, from raising more than one of the carrier blanks at a time as they are fed into the machine, since it is evident that the carriers would tend to adhere to each other due to the air seal therebetween. Thus, as each carrier blank is elevated at its front end (Figure 8), the uppermost carrier blank flexes the stripper elements 315 and immediately after the uppermost carrier blank has moved thereby, the stripper elements engage and retain the next succeeding carrier blank in the magazine M.

As heretofore stated, the magazine base plate 301 is movable vertically and the opposite side edges thereof are guided between a pair of vertically disposed guide plates 316 and 316a supported by the side frame members 30 and 31 of the framework 20 by means of angle bars 317 and screws 318, the angle bars being secured to the rear edges of the legs 32 and 34 of the respective side frame members 30 and 31 as is clearly shown in Figures 3 and 6.

The magazine base plate 301 is preferably made from a light material and, therefore, a reinforcing plate 321 is suitably secured to the lower surface of the magazine base plate 301, to the lower surface of which the upper ends of a pair of transversely spaced vertically disposed racks 322 and 323 are suitably secured, as by welding. Each of the racks 322 and 323 extends downwardly and is guided for vertical sliding movement in a pair of vertically spaced guide blocks 325 suitably secured, as by screws 326, to the rear surface of the transverse plate 44 heretofore described (Figures 4 and 8).

It will be observed in Figure 8 that the base 24 is provided with an opening 327 for the lower end of each of the racks 322 and 323 to enter as the racks move downwardly in Figures 3 and 8. These racks 322 and 323 are provided for raising the magazine base plate 301, along with the rear wall member 302 of the magazine and the carriers B in blank form supported by the magazine base plate 301, as the carriers are fed into the machine, and so the uppermost of the carrier blanks is positioned in substantially the same horizontal plane as the upper edge of the front wall member 303 of the magazine M. To this end, each of the racks 322 and 323 is engaged by a pinion 330 fixed on a transverse shaft 331.

Referring to Figures 2 and 4, it will be observed that opposite end portions of the shaft 331 are rotatably mounted in bearing blocks 332 suitably secured to the rear surfaces of the legs 32 and 34 of the respective side frame members 30 and 31 of the first framework 20. It will be observed in Figure 3 that the right-hand end of the shaft 331 has an intermediate portion of a pawl operating lever 334 oscillatably mounted thereon, the outer surface of which oscillates against the inner surface of a ratchet wheel 335 fixed on the shaft 331. The outer end of the shaft 331 also has a hand wheel 336 fixed thereon, the purpose of which will be later described.

The portion of the pawl operating lever 334 disposed above the shaft 331 has a rearwardly extending portion 337 integral therewith on which the rear end of a ratchet feed pawl arm 340 is pivotally mounted, as at 341 (Figures 2, 3 and 9). This ratchet feed pawl arm 340 has a ratchet feed pawl 342 fixed thereon which engages the teeth in the periphery of the ratchet wheel 335. The ratchet feed pawl 342 rests in engagement with the ratchet wheel 335 due to the weight of the ratchet feed pawl arm 340. The ratchet feed pawl arm 340 has a relatively thin extension 343 integral with the free end thereof which normally rests against a pin 344 projecting from one side of a hold-back pawl arm 345. The pin 344 projects from a medial portion of the ratchet hold-back pawl arm 345 and the lower end of the arm 345 has a hold-back pawl 345a thereon which normally engages the ratchet wheel 335 to prevent reverse movement thereof. The hold-back pawl arm also has a handle portion 346 projecting outwardly therefrom which is adapted to be manipulated by an operator for purposes to be later described.

25 The lower end of the hold-back pawl arm 345 (Figure 9) is pivotally mounted on a shaft 347 which extends inwardly and is fixed in the upper end of a projection 350 extending from the bearing block 332 heretofore described.

30 It will be observed in Figures 2, 3, 9 and 43-A, that the lower end of the pawl operating arm 334 has a hook portion 351 thereon which is adapted to be engaged, at times, by a latch member 352. The latch member extends rearwardly and is pivotally mounted on a stub shaft 353 extending from a bracket 354 which is suitably secured, as by screws 355, to the rear edge of the leg 32 of the right-hand side frame member 30. The latch 352 is normally urged upwardly, into engagement with the hook portion 351 on the lower end of the pawl operating arm 334, by a tension spring 357, connected at its lower end intermediate the ends of the latch 352 and connected at its upper end to the leg 32 of the side frame member 30.

35 The latch 352 functions to, at times, prevent oscillation of the pawl operating arm 334 which, when free of the latch 352, oscillates continuously as long as the main cam shaft 152 (Figure 2-A) is rotating. Now, it is evident that, as each stroke in a clockwise direction is imparted to the pawl operating arm 334 (Figures 2 and 9), by means to be presently described, a step in rotation is imparted to the ratchet wheel 335 and the shaft 331 in a clockwise direction. Thus, each pinion 330 (Figure 8) will also rotate in a clockwise direction to cause a step in movement to be imparted to each of the racks 322 and 323 in Figures 3 and 8 to raise the magazine base plate 301 and the carrier blanks supported thereon.

40 In order to impart oscillatory movement to the pawl operating arm 334 when it is released from the latch 352, the upper end of the pawl operating arm 334 has the rear end of a connecting rod 368 pivotally connected thereto, as at 361, which extends forwardly and downwardly in Figure 2 and Figure 2-A and is pivotally connected, as at 362, to the free end of an arm 363a of a bell crank broadly designated at 363. The bell crank 363 also has an arm 363b extending therefrom, on the free end of which a cam follower 364 is rotatably mounted. The bell crank 363 is pivotally mounted, at the juncture of the arms 363a and 363b, on a stub shaft 365 which projects from

45

50

55

60

65

70

75

the bracket 155 heretofore described (Figures 2-A, 18 and 20).

It will be observed in Figure 19 that the cam follower 364 is normally urged into engagement with the periphery of a cam wheel 366 by a tension spring 367 (Figures 2 and 9) which is connected at its rear end to the lower portion of the pawl operating arm 334 and the front end of which is connected to the horizontal frame portion 36 of the side frame member 30.

The cam wheel 366 has a high surface 366a and a relatively low surface 366b and as the low surface 366b moves into engagement with the cam follower 364, the tension spring 367 causes the pawl operating arm 334 to move in a counter-clockwise direction in Figures 2, 9 and 43-A. On the other hand, when the high surface 366a of the cam wheel 366 moves into engagement with the cam follower 364, the pawl operating arm 334 is moved in a clockwise direction to impart a step in movement to the ratchet wheel 335.

When an operator desires to fill the magazine M with a new supply of carrier blanks, it is merely necessary for the operator to grasp the handle portion 346 and to swing the hold-back pawl arm 345 in a counter-clockwise direction in Figures 2 and 9 to thereby move the hold-back pawl 345a out of engagement with the ratchet wheel 335. Now, as the hold-back arm 345 is moved from right to left in Figures 2 and 9, the pin 344, being in engagement with the extension 343 of the feed pawl arm 340, causes the ratchet feed pawl 342 to move out of engagement with the ratchet wheel 335 to permit the magazine base 301 to move downwardly by gravity until the plate 321 (Figure 8) engages the upper edge of the plate 44. The operator then releases the arm 345 to permit the pawls 342 and 345a to again move into engagement with the ratchet wheel 335.

After the desired number of carrier blanks have been placed in the magazine, the operator then rotates the hand wheel 336 in a clockwise direction in Figures 2 and 9 so the magazine base plate 301 and the carrier blanks resting thereon are moved upwardly to where the uppermost carrier blank is in approximately a position slightly lower than the estimated position that it should occupy for proper operation of the machine.

Now, when the uppermost of the carrier blanks is not at a high enough elevation for proper operation of the machine, the latch 352 is caused to move downwardly automatically, by means to be presently described, to thereby permit oscillation to be imparted to the pawl operating arm 334. It is evident that, when the latch 352 is in engagement with the hook portion 351 on the lower end of the pawl operating arm 334, the cam follower 364 (Figure 19) will be engaged by only the high surface 366a of the cam wheel 366 as this cam wheel continues to rotate.

In order to hold the latch 352 out of engagement with the hook portion 351 on the lower end of the pawl operating arm 334 at the proper time, in the event of the uppermost carrier blank being disposed at too low an elevation for proper operation of the machine, a solenoid coil 370 is energized, by means to be presently described, to move a solenoid plunger 371 downwardly, this solenoid plunger 371 being pivotally connected as at 372 intermediate the ends of the latch arm 352 (Figures 2 and 9). The solenoid coil 370 is mounted in a suitable housing 373 which is suitably secured, as by screws 374, to the outer surface of the leg 32 of the right-hand side frame

member 30. This solenoid coil 370 is controlled by a normally opened sensitive switch 376 which is connected to the solenoid coil 370 by suitable electrical connections to be later described.

Referring to Figures 2, 6 and 9, it will be observed that the sensitive switch 376 is secured to the outer surfaces of a pair of horizontally spaced guide plates 377 which are suitably secured to the outer surface of a substantially vertically disposed projection 380 integral with a carrier feed unit support arm 381 which curves forwardly from the projection 380 and then downwardly and is fixed on a transverse shaft 382. This transverse shaft 382 is oscillatably mounted in bearing blocks 383 suitably secured to the rear surface of the transverse plate 50 rearwardly of the legs 33 and 35 of the respective side frame members 30 and 31. It will be noted in Figures 6 and 9 that the carrier feed support arm 381 is disposed immediately adjacent the outer surface of the side frame member 30 and there is fixed on the end of the shaft 382 adjacent the side frame member 31, a second carrier feed support arm 381a which is identical to the arm 381, except being opposite hand, and which is provided with a substantially vertically disposed projection 380a on the rear upper end thereof and which has spaced guide plates 377a secured to the outer surface thereof. The vertically disposed projections 380 and 380a on the respective arms 381 and 381a are provided with vertically extending grooves 385 (Figure 9) and 385a (Figure 4), respectively, in which respective carrier feed guide bars 386 and 386a are mounted for vertical sliding movement.

A reinforcing member 387, in the form of an angle bar, is suitably secured at opposite ends thereof to the upper ends of the guide bars 386 and 386a for holding the same in proper spaced relation. Disposed immediately below the reinforcing member 387 is a pipe or rigid conduit 390 (Figure 8), opposite ends of which are closed by blocks 391 (Figure 3) and these blocks being secured against the proximate surfaces of the guide bars 386 and 386a by screws 392 (Figures 3 and 6) which slidably penetrate the horizontal flange of the angle bar 387 and are threadably embedded in the blocks 391.

It will be observed, in Figure 6, that the central portion of the transverse reinforcing member or angle bar 387 has an opening 393 therein which is loosely penetrated by a rigid conduit or pipe 394 (Figures 3 and 8), the lower end of which is connected to the transverse pipe 390 for communication therewith. The transverse pipe 390 also serves as a support for a plurality of vacuum controlled carrier blank grasping or transferring devices, each of which is broadly designated at 395, there being three of these shown in Figure 3.

Each of the vacuum control carrier blank grasping devices 395 comprises a rigid conduit or pipe 396, connected at its upper end to the transverse pipe 390 for communication therewith. This pipe 396 has a sleeve 397 connected to the lower end thereof for communicating therewith. A resilient inverted suction cup 400 is suitably secured to the lower surface of the sleeve 397. It will be noted that the sleeve 397, of each of the carrier blank grasping and feeding devices 395, is threadably mounted on the lower end of the corresponding rigid conduit or pipe 396 and is locked in the desired adjusted position by a lock nut 401. This adjustment means for each of the carrier feeding devices

395 is provided to insure that the lower ends of all of the carrier blank feeding or transfer devices 395 are disposed the same distance above the magazine base plate 301 of the magazine M and to also insure that the carrier blank feeding devices 395 are properly positioned for resiliently engaging the upper surface of the uppermost carrier blank in the magazine M for grasping and feeding the latter into the machine.

Referring to Figure 3, it will be observed that the pipe or rigid conduit 394, projecting upwardly from a medial portion of the horizontal pipe 390, has one end of a flexible conduit 402 connected thereto which extends outwardly or to the right in Figure 3 and is connected to one end of a rigid conduit or pipe 403. This pipe 403 extends downwardly and then inwardly and is connected to one side of a housing 404a of a suction control valve 404 which is most clearly shown in Figures 2, 9 and 42.

The control valve housing 404a has a chamber 405 therein with which the pipe 403 communicates and a suction pipe 406 is also connected to the housing 404a for communication with the chamber 405. The pipe 406 is connected to a suitable suction means, such as the suction device 407 shown schematically in Figure 2.

The valve housing 404a has an enlarged upper portion 410 integral therewith fixed on a boss portion 411 projecting from the upper portion of the side frame member 30 adjacent the rearmost edge thereof. This enlarged portion 410 is bifurcated for reception of the upper end of a valve control arm 412 pivotally mounted in the bifurcated upper end of the valve housing 404, as at 413. The valve control arm 412 extends downwardly and has a valve chamber closing plate 414 resiliently mounted thereon by means of a bolt 415 on which the plate 414 is slidably mounted and this bolt 415 slidably penetrates an enlarged portion 417 on the valve control arm 412.

The bolt 415 is surrounded by a compression spring 420, one end of which engages the plate 414 and the other end of which engages the proximate surface of the enlarger portion 417 on the valve control arm 412. Thus, upon the valve control arm 412 being moved from the opened position shown in Figures 9 and 42 to the closed position shown in Figure 2, the plate 414 resiliently engages the valve housing 404a to close the chamber 405 therein. Upon the plate 414 closing the chamber 405, the suction device 407 causes a negative pressure in the pipes 403, 402, 394 and 390, thus creating a suction in each of the carrier blank feed devices 395. It is evident that, upon the plate 414 assuming the opened position shown in Figure 9, there will no longer be a negative pressure in the pipes 403, 402, 394 and 390.

Since the valve 404 must be controlled according to the movement of the carrier blank grasping and feeding devices 395, the lower end of the valve control arm 412 (Figures 2 and 9) has a pin 421 extending outwardly therefrom which fits in a slot 422 in the rear end of a link 423. The link 423 has an adjustment screw 423a in the rear thereof adapted to engage the pin 421. The link 423 extends forwardly and is pivotally connected, as at 424 (Figure 9), to the upper portion of the carrier feed support arm 381 which is controlled by means to be presently described.

Referring to Figures 2, 8 and 9, it will be observed that the shaft 382 has the upper end of a crank arm 425 fixed thereon, to the lower end of which the rear end of a connecting rod 426

is pivotally connected, as at 427, which extends rearwardly from between the side frame members 30 and 31 of the first framework 20 to between the side frame members 66 and 67 of the second framework 21 as is clearly shown in Figures 2 and 2-A. It will be observed in Figures 18 and 23 that the rearmost end of the connecting rod 426 has a yoke member 428 fixed thereon which straddles the main cam shaft 152 and also has a cam follower 431 rotatably mounted thereon.

The cam follower 431 is normally urged into engagement with the periphery of a cam wheel 432 (Figure 23) by a tension spring 433 (Figure 8) which is connected at its rear end to the crank arm 425 and the front end of which is connected to a spring anchor 434 projecting upwardly from the base 24 of the machine. This cam wheel 432 (Figure 23) has a high point 432a and a low point 432b, the low point and the high point 432a and 432b, respectively, of the cam wheel 432 being disposed in substantially diametrically opposite relation to each other.

When the low point 432b of the cam wheel 432 is in engagement with the cam follower 431, the carrier blank feed devices 395 occupy substantially the position shown in Figures 2 and 8. When the high point or the surface 432b of the cam wheel 432 is in engagement with the cam follower 431, the arm 381 and the corresponding guide bars 386 and 386a occupy substantially the position shown in Figure 9.

In order to insure that the arms 381 and 381a stop in the desired rearward position, without the necessity of the low surface 432b on the cam wheel 432 (Figure 23) being accurately located relative to the shaft 152, it will be observed in Figures 2 and 9 that a bumper 435 is adjustably mounted in a block 436 suitably secured to the upper horizontal portion 37 of the side frame member 30. The shank of the bumper 435 threadably penetrates the block 436 and is held in adjusted position by a lock nut 440.

Thus, as the low surface 432b of the cam wheel 432 moves toward the cam follower 431, the arm 381 (Figure 9) moves rearwardly and the projection 380 thereon engages the front surface of the bumper 435 to arrest its rearward movement. Now, as the arms 381 and 381a move forwardly, the carrier blank feed devices 395 also move forwardly therewith and are elevated to raise the uppermost carrier B out of the magazine M and to position the leading edge thereof between upper and lower feed rolls 441 and 442, respectively (Figures 6 and 8). The manner in which the feed rolls 441 and 442 are mounted will be later described.

It is to be noted that the rear portions of the carrier blanks B are held down by a weight rod 443 resting thereupon. Each side plate 316 and 316a has a vertical slot 444 therein in which reduced opposite ends of the weight rod 443 are mounted for vertical sliding movement. The weight rod 443 causes the leading portion of each successive carrier blank to be biased upwardly when grasped by the carrier blank feeding devices 395, thereby assisting in retaining the remaining carrier blanks in the magazine M.

The carrier feed devices 395 are normally urged downwardly by a tension spring 445 connected at its upper end to a spring anchor 446 (Figures 2 and 9) which extends forwardly from the guide bar 386. The lower end of the tension spring 445 is connected to a spring anchor 447 projecting from the front surface of the guide 377 of the

projection 380 integral with the carrier feed support arm 381. Thus, the tension spring 445 normally urges the guide bar 386 downwardly and, accordingly, urges the carrier feed devices 395 downwardly.

In the event the uppermost carrier blank in the magazine M is not positioned at the proper level to be properly grasped by the suction cups 400 on the lower ends of the carrier blank feeding devices 395, the lower end of a switch actuating bumper 450 engages and depresses the plunger 376a of the sensitive switch 376 thus closing the same. This switch actuating bumper 450 is shown in the form of an adjustment screw which threadably penetrates an angle clip 451 suitably secured to the outer surface of the guide bar 386. This adjustment screw 450 is held in the desired position by a lock nut 452.

As heretofore stated, upon the bumper 450 closing the switch 376, the solenoid coil 370 is energized to thus move the latch 352 out of engagement with the hook portion 351 on the lower end of the pawl operating lever 334 to permit the ratchet wheel 335 to be rotated in a step-by-step manner, as heretofore described, to raise the magazine base plate 301 and the carrier blanks supported thereby until the uppermost of the carrier blanks has engaged the lower surfaces of the carrier blank feed devices 395 and elevated the same sufficiently to move the switch actuating bumper 450 out of engagement with the plunger 376a of the switch 376 (Figure 9).

Referring to Figures 2, 9 and 4, it will be observed that the lower ends of the guide bars 386 and 386a project substantially below the lower edges of the guide plates 377 and 377a and have respective cam followers 452 and 452a rotatably mounted thereon which, upon forward movement of the arms 381 and 381a, move into engagement with respective cam surfaces 453 and 453a of respective crank arms 454 and 454a. These crank arms 454 and 454a extend forwardly and are fixed on the opposite ends of a shaft 456 oscillatably mounted in bearing blocks 457 suitably secured to the front surfaces of the legs 33 and 34 of the respective side frame members 30 and 31 of the first or rear framework 20.

The upper end of a crank arm 460 is fixed on the shaft 456 adjacent the outer surface of the side frame member 30 and the lower end thereof has the rear end of a connecting rod 461 pivotally connected thereto, as at 462 (Figures 1, 2, 4 and 9).

Referring to Figures 1, 2, 2-A, 18 and 20, it will be observed that the connecting rod 461 extends forwardly and downwardly at a slight angle relative to the horizontal and is connected to a yoke 463 having a cam follower 464 thereon which engages the periphery of an irregularly-shaped cam wheel 465. The yoke 463 extends beyond the cam follower 464 and straddles the main cam shaft 152. The cam wheel 465 is so shaped that, as the arms 381 and 381a move forwardly, the crank arms 454 and 454a move upwardly to thus elevate the respective guide bars 386 and 386a.

It is evident that this causes the carrier blank feed devices 395 to move upwardly and forwardly simultaneously to direct the leading edge of the uppermost carrier blank between the feed rolls 441 and 442. Now, when the leading edge of the uppermost carrier blank has been directed between the feed rolls 441 and 442 in the aforesaid manner, the adjustment screw 423a (Figure 9) engages the rear surface of the pin 421, thus

moving the valve control arm 412 forwardly to move the closure plate 414 out of engagement with the valve housing 404a. This permits the atmosphere to enter the pipes 403, 402, 394 and 390 thus permitting the suction cups 400 to release the corresponding carrier blank as the leading edge thereof is positioned between the rotating feed rolls 441 and 442.

The bottom feed rolls 442, of which there are two shown in Figure 3, are fixed on a shaft 466 rotatably mounted in the side frame members 30 and 31 of the rear or first framework 20. There are two of the upper feed rolls 441 shown in Figures 3 and 6 which coincide with the lower feed rolls 442. These two upper feed rolls 441 are fixed on a shaft 467 rotatably mounted at opposite ends thereof in floating bearing blocks 470 and 470'.

Both of the bearing blocks 470 and 470' (Figures 2, 3, 4, 6, 8 and 9) are identical and only the bearing block 470 will be described in detail and like parts associated with the bearing block 470' will bear the same reference characters with the prime notation added. The bearing block 470 extends rearwardly and is pivotally mounted intermediate its ends, as at 472, on a bracket 473 suitably secured to the upper surface of the upper horizontal portion 31 of the side frame member 30. The rear portion of the bearing block 470 is urged upwardly by a compression spring 474 (Figure 9), the upper end of which bears against the upper surface of the bearing block 470 and the lower end of which bears against the upper surface of the bracket 473.

The rearmost end of the bearing block 470 is slidably penetrated by a screw 475 having an adjustment nut 476 threadably mounted thereon, the lower end of the screw 475 being fixed in the bracket 473. The nut 476 is provided to limit the downward movement of the upper rolls 441 on the shaft 467, to which position they are normally urged by the compression spring 474 as is clearly evident from the illustration in Figure 9.

Referring to Figure 6, it will be observed that the portion of the shaft 467 disposed between the feed rolls 441 is spaced above a carrier feed plate 477 which has suitable openings 488 therein through which the upper portions of the bottom feed rolls 442 project in order to grasp the leading edge of the corresponding carrier as it is directed between the upper and lower feed rolls 441 and 442, to subsequently feed the corresponding carrier blank along the upper surface of the carrier feed plate 477.

The upper and lower feed rolls 441 and 442 are driven in opposite directions, simultaneously, by means of intermeshing pinions 481 and 482, fixed on the respective shafts 467 and 466 (Figures 3, 4 and 6), which are disposed adjacent the left-hand side frame member 31 of the first framework 20. The shaft 466 also has a sprocket wheel 483 fixed thereon, engaged by a sprocket chain 484 which extends downwardly in Figures 3 and 4 and engages a sprocket wheel 485.

The sprocket wheel 485 is fixed on a transverse shaft 486 rotatably mounted in bearing blocks 487 suitably secured to the front surfaces of the legs 33 and 35 (Figures 2 and 4) of the respective side frame members 30 and 31. The transverse shaft 486 has a sprocket wheel 490 fixed thereon which is engaged by the endless sprocket chain 44, which is driven in the manner described and as is clearly shown in Figures 4, 4-A and 6-A. It is thus seen that the feed rolls 441 and 442 rotate continuously although the clutch mechanism,

shown in the upper right-hand portion of Figure 6-A and in Figures 35 to 37, inclusive, may be disengaged and the main cam shaft 152 may not be rotating.

In order to insure that the leading edge of each carrier is properly positioned between the jaws 267 and 268 of the corresponding carrier grasping device 264 on the conveyor chain 224, a carrier blank guide rail 491 is suitably secured to the upper surface of the carrier blank feed plate 477 adjacent the right-hand edge thereof or the edge nearest the observer in Figure 2. This carrier blank guide bar 491 is also shown in Figure 6.

Means are provided for engaging the trailing edge of each of the carrier blanks after they have passed between the upper and lower feed rolls 441 and 442 to thereby force the leading edge thereof into position between the jaws 267 and 268 (Figures 40 and 41) and to insure that the leading edge of each carrier abuts against the screws 281 in the corresponding carrier blank grasping device 264. The jaws 267 and 268 are held in opened position with respect to each other at this time by means to be later described. Also, at the time that each carrier blank B is thrown forwardly against the screws 281 in the corresponding carrier blank grasping device 264, means are provided for urging the corresponding edge of the carrier blank against the carrier blank guide bar 491 on the carrier feed plate 477.

This means for adding impetus to the forward movement of each carrier blank and the locating means for urging the corresponding carrier blank against the carrier blank guide bar 491 will now be described.

Referring to Figures 6, 8, 10 and 11, there will be observed a pair of goose-neck throw arms 492 and 493 whose upper ends are normally positioned immediately below the level of the upper surface of the carrier feed plate 477 and immediately above the shaft 486 on which the bottom feed rolls 442 are mounted. These goose-neck throw arms 492 and 493 curve rearwardly and downwardly and then forwardly and are fixedly mounted on a transverse shaft 484 oscillatably mounted in the side frame members 39 and 31 of the rear framework 20.

The goose-neck throw arms 492 and 493 are of substantially the same configuration. However, the throw arm 493 differs from the throw arm 492 in that it has a forwardly extending abutment 495 projecting therefrom (Figure 10), the upper surface of which is engaged by an abutment 496 shown in the form of an adjustment screw. The adjustment screw 496 threadably penetrates an arm 500 which extends substantially laterally from a medial portion of a carrier blank locator bracket 501 which extends downwardly and is oscillatably mounted on a stub shaft 502, as is most clearly shown in Figures 10 and 11.

The stub shaft 502 extends rearwardly and is fixed in a block 503 secured to the upper surface of the transverse frame member 54, by any suitable means such as screws 504. The locator bracket extends upwardly above the horizontal plane of the carrier feed plate 477 and past one edge thereof and has suitably secured to the inner face thereof a carrier blank locator bar 506 which extends forwardly and rearwardly from the bracket 501.

This carrier blank locator bar 506 is normally urged inwardly by a tension spring 507 connected at its outer end to the bracket 501 and is connected at its inner end to a projection 510 depending from the lower surface of the carrier

feed plate 477. The tension spring 507 also normally urges the adjustment screw 496 against the upper surface of the abutment 495 projecting from the goose-neck throw arm 493.

5 However, since it is necessary that the inner face of the locator bar 506 moves inwardly to a position in predetermined spaced relation to the guide bar 491 on the carrier feed plate 477, the projection 510 on the lower surface of the carrier feed plate 477 also has an abutment 511 thereon which is in the form of an adjustment screw, the outer end of which is engaged by the inner surface of the bracket 501 as it is urged inwardly by the tension spring 507 upon downward movement of the abutment 495 (Figure 10) which is controlled in a manner to be later described.

Fixed on the shaft 486, intermediate the ends thereof, is a crank arm 513 to the outer end of which the rear end of a connecting rod 514 is pivotally connected as at 515 (Figures 2, 4, 8 and 10). The connecting rod 514 extends rearwardly and downwardly at an angle in Figures 2 and 2-A and, it will be observed in Figures 17, 18 and 27 that the front end of the connecting rod 514 has a yoke member 516 thereon which straddles the main cam shaft 152 and has a cam follower 517 thereon which engages the periphery of a cam wheel broadly designated at 520 fixed on the cam shaft 152.

30 The cam wheel 520 has a high point 521 and a low point 522, which points are disposed in substantially diametrically opposite relation to each other. It will be observed in Figure 10 that the connecting rod 514 is normally urged forwardly to, in turn, urge the cam follower 513 (Figure 27) against the periphery of the cam wheel 520, by means of a tension spring 523 connected at one end thereof to the free end of the crank arm 513 and connected at its other end to a suitable spring anchor 524 depending from the transverse frame member 54.

Thus, upon the low point 522 of the cam wheel 520 (Figure 27) being in engagement with the cam wheel 517, the tension spring 523 causes the goose-neck throw arms 492 and 493 to assume the positions shown in Figures 8 and 10. It is evident that, upon the high point 521 of the cam wheel 520 moving into engagement with the cam follower 517 (Figure 27), the throw arms 492 and 493 are caused to move forwardly and upwardly at their free upper ends, about the axis of the shaft 486, to thereby engage the rear or trailing edge of the carrier blank previously positioned on the feed plate 477 and to suddenly throw the same forwardly into the space between the open jaws 267 and 268 of the corresponding carrier clamping device 264.

Now, as heretofore stated, the locator bar 506 also moves inwardly towards the center of the machine at the same time that the throw arms 492 and 493 move forwardly to thus insure that the carrier blank is properly positioned on the feed plate with its corresponding edge against the inner surface of the guide bar 491. In order to maintain the carrier blank in engagement with the upper surface of the carrier feed plate 477, a relatively thin hold-down plate 525 (Figures 2, 4, 8 and 9) normally rests against the upper surface of substantially the front half of the carrier feed plate 477.

This hold-down plate 525 is substantially the same width as the carrier feed plate 477 and extends upwardly and rearwardly at an angle, as at 525a (Figures 8 and 10) and is then bent hori-

zontally and suitably secured to the upper surface of a transverse hold-down plate support bar 526, as by screws 527.

The hold-down plate support bar 526 extends beyond the outer surfaces of the side frame members 30 and 31 of the rear framework 20 and is pivotally mounted at opposed ends thereof in the upper ends of brackets 530 which extend downwardly and are suitably secured to the outer surfaces of the side frame members 30 and 31 by the screws 54a heretofore described (Figures 2, 4, 6 and 9).

The angular portion 525a of the hold-down plate 525 is particularly provided to engage the leading edge of each carrier blank as it passes between the feed rolls 441 and 442 and to thus direct the leading edge of the carrier blank downwardly beneath the plate 525 and against the upper surface of the carrier feed plate 471. It is evident that, since the hold-down plate support bar 526 is pivotally mounted in the brackets 530, the hold-down plate 525 will be readily raised slightly as the leading edge of each successive carrier blank is directed downwardly by the angularly disposed portion 525a of the hold-down plate 525 to permit the carrier blank to pass between the plates 525 and 471.

Now, at the cessation of each step imparted to the conveyor 205, a corresponding one of the carrier clamping devices 264 moves through an arc of approximately 180 degrees from a point at the bottom of the sprocket wheel 290 (Figures 2 and 8) to a point at the top of the sprocket wheel 290 to occupy a position substantially as shown in Figure 8 and whereupon the lowermost jaw 268 of the corresponding carrier clamping device 264 (Figures 40 and 41) is positioned at the same or slightly below the level of the upper surface of the carrier feed plate 471. The carrier feed plate 471 and the carrier hold-down plate 525 are provided with coinciding openings 531 (Figures 6 and 8) through which the carrier clamping devices 264 pass as they move upwardly about the sprocket wheel 290.

As each of the carrier clamping devices 264 occupies a position adjacent the openings 531 in the plates 525 and 471, the uppermost or outer jaw 267 thereon is moved upwardly to opened position in timed relation to movement of the carrier blank along the carrier feed plate 471 by means to be presently described. The jaw opening means comprises a pressure applying clip or member 532, disposed above the wing portion 276 of the corresponding clamping device 264 (Figures 6 and 8), which extends upwardly and is suitably secured to a transverse bar 533, opposite ends of which are supported in a pair of substantially L-shaped brackets 534 disposed adjacent and forwardly of the side frame members 30 and 31.

These brackets 534 extend rearwardly and then downwardly and are fixed on a transverse shaft 535 oscillatably mounted in a pair of transversely spaced bearing brackets 536 and 537 (Figures 2, 4 and 8) which extend rearwardly and downwardly at an angle, and are suitably secured to the upper surface of the transverse frame member 54 heretofore described. It will be observed in Figures 2, 4 and 8 that the bearing blocks 536 and 537 also serve to support the outer portions of the carrier feed plate 471, to which the carrier feed plate 471 is suitably secured, as by screws 540.

Of course, the central portion of the plate 471

rests upon the upper edges of the side walls 57 and 58 of the trackway 55, the upper edges of these walls 57 and 58 being cut slightly lower at the point on which the carrier feed plate 471 rests to insure that the upper edges of the major portions of the side walls are disposed in substantially the same horizontal plane as the upper surface of the carrier feed plate 471.

The pressure applying element 532 (Figures 6 and 8) is controlled by means of a crank arm 541, most clearly illustrated in Figures 2, 4 and 8. This crank arm 541 is fixed on the transverse shaft 535 adjacent the side wall 58 and extends downwardly therefrom. A tension spring 542 is connected at one end thereof intermediate the ends of the crank arm 541 and extends forwardly and is connected, as at 543, to the side wall 58 of the trackway 55.

The lower or free end of the crank arm 541 has the rear end of a connecting rod 544 pivotally connected thereto, as at 545. It will be observed in Figures 4 and 4-A that the connecting rod 544 extends forwardly and downwardly at an angle from the crank arm 541 and has a yoke member 546 on the rear end thereof (Figures 17, 18 and 24). This yoke member 546 straddles the cam shaft 152 and has a cam follower 547 thereon which engages the periphery of a cam wheel broadly designated at 550. The cam wheel 550 has a high point 550a and a low point 550b thereon, which points are disposed in substantially diametrically opposite relation to each other. The cam wheel 550 is fixed on the cam shaft 152.

It is thus seen that the tension spring 542 (Figure 4) normally urges the cam follower 547 into engagement with the periphery of the cam wheel 550 and, in so doing, normally urges the pressure applying element 532 to a raised or inoperative position. It is evident that the cam follower 547 is in engagement with the low point 550b of the cam wheel 550 (Figure 24) when the pressure applying element 532 is in inoperative position. However, as each of the carrier clamping devices 264 moves into position beneath the pressure applying element 532, the high point 550a of the cam wheel (Figure 24) moves into engagement with the cam follower 547, causing the pressure applying element 532 to move downwardly into engagement with the wing portion 276 (Figure 41) of the corresponding carrier clamping device 264.

This causes the outer jaw 267 to pivot about the shaft 272 to compress the compression springs 280 as it moves away from the lower or inner jaw 268. As the outer jaw 267 moves to open position relative to the inner jaw 268, the leading edge of the corresponding carrier blank is positioned between the jaws 267 and 268. The high point 550a of the cam wheel 550 then moves out of engagement with the cam follower 547, permitting the pressure applying element 532 to move out of engagement with the wing portion 276 of the corresponding carrier clamping device 264.

The compression springs 280 then cause the clamping projections 277 to move into engagement with the upper surface of the corresponding carrier blank to clamp the same against the proximate surface of the inner jaw 268. The conveyor chain 224 then advances another step, whereupon the corresponding carrier is pulled forwardly by the carrier grasping device 264.

As heretofore stated, as the clamping device 75 264 advances another step, the next succeeding

U-shaped confining member 285 engages the rear or trailing edge (Figure 13) of the carrier to insure that the same is advanced along the trackway 55 in the event that the leading portion thereof is not properly clamped between the projections 277 on the upper or outer jaw 267 and the lower or inner jaw 268.

First folding means

Hereinafter, the various steps through which a single carrier passes in its course through the machine to the boxing station will be described, although it is to be understood that all of the stations operate upon corresponding carriers simultaneously. The manner in which the carrier is directed to the carrier clamping device 264 shall be considered as the first step in movement of the carrier B and the conveyor 205 through the machine.

Upon the second step in movement of the conveyor 205, the carrier is slid along the upper edges of the side walls 57 and 58 of the trackway 55 and beneath an inverted channel-shaped folding die 560 (Figures 2, 4, 8, 12 and 14). This folding die 560 extends longitudinally of and in parallel spaced relation to the side walls 57 and 58 of the trackway 55 and is somewhat shorter than the carrier B. The folding die 560 is suspended above the trackway 55 by means of an angle clip 561 and a bracket 562. The bracket 562 extends upwardly and is suitably secured, as by a screw 562a (Figures 3, 4 and 12), to the lower surface of a bottom wall 563 of a closed chute broadly designated at 564. This closed chute 564 also comprises an upper wall 565 and spaced side walls 566.

The chute 564 may be of any desired length and it will be noted that it extends downwardly and forwardly at an angle from a trough or channel-shaped chute extension 567 (Figure 1) in which the cylindrical articles C may be placed by an operator. Thus these articles C will move downwardly along the chute 564 by gravity into an article depositing or transferring means to be later described (Figures 12, 13 and 16). Any suitable conveying means may be used to direct the articles C to the article depositing or dispensing means.

After the leading edge of the carrier has moved to a position adjacent the front end of the folding die 560, the conveyor chain 224 momentarily ceases its movement, whereupon a pair of external folding bars 570 and 571 (Figures 2-A, 4 and 14) move upwardly adjacent the outer surfaces of the folding die 560 to thereby move the side walls B-2 and B-3 of the carrier to occupy substantially vertical positions perpendicular to the bottom wall B-1, as is clearly shown in Figure 14. These external folding bars 570 and 571 extend forwardly and rearwardly and are fixed on the upper end of respective exterior folder guide bars 572 and 573.

It will be observed in Figure 14 that these guide bars 572 and 573 are mounted for vertical sliding movement in respective guide blocks 574 and 575 suitably secured, as by screws 576, to the transverse frame member 62 of the second or depositing station framework 21. The inner or proximate faces of the guide blocks 574 and 575 are open as is clearly shown in Figure 12, and the guide bars 572 and 573 have the upper ends of respective connecting rods 580 and 581 pivotally connected thereto, as at 582.

These connecting rods 580 and 581 extend downwardly in Figures 12 and 14 and are pivotally

5

connected, as at 583, to the rear ends of transversely spaced arms 584 and 585. The arms 584 and 585 are integral parts of a bell crank broadly designated at 586 (Figures 2-A, 4, 4-A and 12), the arm 584 being substantially L-shaped in plan and being connected intermediate the ends of the arm 585. The bell crank 586 is oscillatably mounted on a transverse shaft 587 which is oscillatably mounted in projections on the legs 64 and 65 of the respective side frame members 66 and 67 of the second framework 21 (Figures 1, 2-A, 4-A, 7 and 12).

The bell crank 586 also has an arm 588 extending therefrom, at an acute angle relative to the arms 584 and 585, to the free end of which the rear end of a connecting rod 589 is pivotally connected, as at 590 (Figure 12).

The connecting rod 589 extends forwardly and downwardly at an angle and has a yoke member 593 on the front end thereof which straddles the cam shaft 152 and which has a cam follower 594 thereon. The cam follower 594 is normally urged into engagement with the periphery of a cam wheel broadly designated at 596 (Figures 12, 17 and 18) by means of a tension spring 597 (Figure 14), connected at its upper end to the guide bar 573 and the lower end of which is connected to the guide block 575. The cam wheel 596 is irregularly-shaped and provided with a relatively low surface 596a and a relatively high surface 596b.

As the high surface 596b of the cam wheel 596 (Figure 12) moves into engagement with the cam follower 594, the external folding bars 571 move from a position below the horizontal plane of the upper edges of the side walls 57 and 58 of the trackway 55 to substantially the position shown in Figure 14. It will be observed in Figures 6-A and 14 that the inner folding die 560 of the initial folding station has a lateral flap folding plate 600 suitably secured to the upper surface thereof and extending outwardly therefrom and the outer edge of this lateral flap folding plate 600 terminates a predetermined distance from the corresponding side wall of the folding die 560 so that the side wall B-2 and the handle portion extending therefrom in alignment therewith will extend in a straight line from the juncture of the bottom wall B-1 and the side wall B-2 of the carrier B as the folding bar 573 moves upwardly.

At substantially the same time that the folding bars 570, 571 move upwardly, a movable flap folding bar 601 moves inwardly beneath and in closely spaced relation to the lateral flap folding plate 600. Now, as stated in said co-pending application, Serial No. 185,072, the carrier is scored or creased at the juncture of the handle portion B-6 and the side wall B-2 of the carrier B and, as the flap folding bar 601 moves inwardly, the carrier B is folded to form the handle portion B-6 so it extends laterally from the side wall B-2 of the carrier B.

In order to control the movable flap folding bar 601, the plate 600 has an opening 600a therein (Figure 14) to provide space for movement of an arm 602a of a bell crank broadly designated at 602. The lower end of the arm 602a projects inwardly and has the movable flap folding bar 601 suitably secured thereto, as by screws 604, only one of which is shown in Figure 14.

The bell crank 602 is oscillatably mounted on a stub shaft 603, one end of which is fixed in a bracket 605 suitably secured, as by screws 605a (Figures 1, 2-A and 6-A), to the rear surface of

the transverse frame member 77 of the second framework 21.

The bell crank 602 also has a bifurcated arm 602b extending outwardly therefrom which is substantially narrower than the arm 602a and to which the upper end of a connecting rod 606 is pivotally connected, as at 607. It will be observed in Figures 2-A and 4-A that the connecting rod 606 extends downwardly and is pivotally connected, as at 610, to the rear end of a crank arm 611 which extends forwardly and is fixed on the shaft 587 heretofore described.

It will be observed in Figures 1 and 2-A that one end of the shaft 587 has a crank arm 612 fixed thereon which extends upwardly and has the rear end of a connecting rod 613 pivotally connected thereto, as at 614. This connecting rod 613 extends forwardly and is pivotally connected, as at 615, to the free end of a bell crank arm 616. The bell crank arm 616 is pivotally mounted on a stub shaft 617 projecting from the bracket 155 (Figures 2-A, 17, 18 and 20) and this bell crank arm 616 has a bell crank arm 620 integral therewith, which has a cam follower 621 mounted on the free end thereof.

The cam follower 621 engages the periphery of a cam wheel broadly designated at 622 (Figure 2-A), which has a high surface or point and a low surface or point designated at 622a and 622b, respectively. The cam follower 621 is held in engagement with the periphery of the cam wheel 622 by means of a tension spring 623, the upper end of which is connected intermediate the ends of the crank arm 611 and the lower end of which is connected to a suitable spring anchor 624 projecting from the base 24 of the machine.

Cylindrical article retaining and depositing station

Referring to Figures 2-A, 4-A, 8, 12 and 13, it will be observed that the lower portion of the chute 564 is supported by a bracket 630 suitably secured to the upper wall 565 of the chute 564, as by screws 631. This bracket extends upwardly and forwardly at an angle and is suitably secured to the rear surface of the transverse frame member 77, as by screws 632. Referring to Figures 12, 13 and 16, it will be observed that the lower edges of the upper and lower walls 565 and 563 of the chute 564 terminate in substantially the same vertical plane between the rear portions of a pair of transversely spaced vertically disposed article guide plates 633 and 634, to which they are suitably secured, as by welding.

The article guide plates 633 and 634 define walls of the article depositing or dispensing station. It will be noted that the side walls 566 of the chute 564 terminate short of the lower ends of the upper and lower walls 565 and 563 of the chute 564 in order to accommodate the article guide 633 and 634. These article guide plates 633 and 634 are spaced substantially the same distance apart from each other as the side walls of the chute 564.

The article guide plates are most clearly shown in Figures 12, 13, 16 and 17 where it will be observed that the lower edges thereof terminate in spaced relation above the upper edges of the side walls 57 and 58 of the trackway 55. Since the upwardly extending first and second flap portions B-2 and B-3 of the carrier B straddle the lower portions of the article guide plates 633 and 634, the lower portions of the article guide plates

633 and 634 are tapered inwardly at the outer surfaces thereof so that the lower edges thereof are relatively sharp.

As the third step in movement is imparted to the conveyor 205, the corresponding carrier clamping device 264 slides the carrier forwardly along the upper edges of the walls 57 and 58 of the trackway 55 to position the bottom wall B-1 beneath the articles C which are retained or supported in the article depositing station by means to be later described. The opposite side walls B-2 and B-3 of the carrier B having been positioned to extend substantially vertical from opposite edges of the bottom wall B-1 as the walls B-2 and B-3 of the carrier B move forwardly beyond the folding die 568 and the external folding bars 570 and 571, the wall B-3 is supported in a slightly angular position, relative to the vertical, by a second flap retaining bar or plate 635, the rear edge of which terminates closely adjacent the front edge of the folding bar 571.

This second flap retaining bar 635 may also be termed a guide bar for the second flap of the carrier B and has its upper edge positioned substantially above the horizontal plane of the upper edge of the trackway 55. It will be observed in Figure 16 that the rear end of this second flap retaining bar 635 is adjustably secured to the outer surface of the side wall 58 of the trackway 55 by any suitable means, such as a screw 636 and lock nuts 637.

The front end of the second flap retaining bar 635 terminates in substantially the same horizontal plane as the article guide plate 634 and the rear edge of the leg 71 of the side frame member 67 (Figure 4-A). The second flap retaining bar also converges inwardly as it extends forwardly so that the front end thereof is disposed closer to the side wall 58 than the rear edge thereof. The front portion of the second flap retaining bar 635 is also adjustably secured to the side wall 58 of the trackway 55 by an adjustment screw 640 and lock nut 641 (Figures 4-A and 17).

The first flap or wall B-2 of the carrier B is also guided and retained in a manner similar to that in which the second flap or wall B-3 is supported as the carrier B moves into and through the article depositing station comprising the article guide plates 633 and 634. To this end, a first flap guiding and retaining bar or plate 642 is suitably secured to the outer surface of the side wall 57 of the track way 55, in spaced parallel relation thereto, as by screws 643 which penetrate the first flap retaining bar 642 and a spacing bar 644 disposed between the bar 642 and the side wall 57 of the trackway 55, each of the screws 643 being threadably embedded in the side wall 57.

Since the upper edge of the vertically extending first wall B-2 of the carrier B has the handle portion B-6 extending outwardly therefrom, the upper edge of the first flap retaining bar 642 has the inner edge of a handle flap supporting bar 645 suitably secured thereto as by welding. This bar 645 is disposed at substantially the same level as the upper edge of the second flap retaining bar 635 (Figures 15, 16 and 17) and the upper surface of the flap folding bar 601 (Figure 14).

The handle flap support bar 645 is so positioned that the handle flap B-6 on the carrier B, which was previously positioned to extend horizontally from the upper edge of the first

flap or wall B-2, rests upon the same as the carrier B passes through subsequent operations. In order to insure that the flap does not bend upwardly due to its inherent tension, there is spaced slightly above the handle flap supporting bar 645 a handle flap retaining bar or hold-down plate 646 which is suitably secured, as by welding, to a spacing bar 647, suitably secured to the upper surface of the handle flap supporting bar 645 adjacent the outer edge thereof.

It will be observed in Figures 6-A and 16 that the inner edge of the handle flap retaining bar 646 terminates short of the vertical plane of the inner surface of the first flap retaining bar 642, and the front edge of this handle flap retaining bar 646 terminates slightly forwardly of the vertical plane of the transverse frame member 81. Disposed forwardly of and immediately adjacent the front edge of the handle flap retaining plate 646 is a second handle flap retaining bar or plate 650 which is of a relatively thin material, such as sheet metal and is suitably secured to the upper surface of the handle flap supporting bar 645, as by welding, this plate 650 being spaced above the bar 645 by a spacing bar 651 (Figures 2-A, 6-A and 15), this bar 651 being substantially the same as the spacing bar 647 (Figure 16).

The second handle flap retaining bar 650 also supports the uppermost handle flap B-5, as shown in Figure 15, after the carrier B has advanced beyond the article depositing station. It will be observed in Figures 2-B, 6-A and 6-B that the second handle flap retaining plate 650 terminates short of the stitching station as does the spacing bar 651. However, the handle flap retaining bar 645 extends through the stitching station as will be later described.

As the cylindrical articles move down the chute 584, by gravity, they pass forwardly between the article guide plates 633 and 634 and, in so doing, the annular ribs at opposite ends of the cylindrical articles ride upon inwardly and outwardly movable article retaining tracks 652 and 653 (Figures 12, 13 and 16) which extend longitudinally of the machine, the plates 633 and 634 each being provided with an elongated slot or opening 654 therethrough which the article retaining tracks 652 and 653 project. The proximate edges of the article retaining tracks 652 and 653 normally assume a position inwardly of the proximate surfaces of the article guide plates 633 and 634, to which position they are normally urged by means to be later described.

The remote or outer edges of the article retaining tracks 652 and 653 are suitably secured, as by welding, to the proximate surfaces of article track support plates 656 and 657, respectively. These support plates 656 and 657 extend upwardly in Figures 2-A, 4-A, 16 and 17 and their rear portions are suitably secured to the lower portions of vertically extending arms or bell cranks 660 and 661, respectively. The front portions of the plates 656 and 657 are supported by arms 662 and 663 (Figures 2-A, 4-A and 6-A). The bell cranks 660 and 661 and the arms 662 and 663 are fixedly mounted on respective longitudinally extending shafts 664 and 665 (Figures 6-A and 16).

Referring to Figures 2-A, 6-A, 12 and 17, it will be observed that shafts 664 and 665 are oscillatably mounted at their rear ends in a bracket 666 (Figure 12) and the front portions of the shafts 664 and 665 are oscillatably mounted in opposite ends of an inverted T-shaped bracket 667. The brackets 666 and 667 are identical and each has

an upwardly extending portion 670 (Figure 2-A) integral therewith, intermediate the ends thereof, which is suitably secured to one side of a longitudinally extending frame member 671 suitably secured at its rear and front ends to the respective transverse frame members 71 and 81 of the second framework 21. Suitably secured to the proximate surfaces of the article track support plates 656 and 657, above the horizontal plane of the upper edges of the article guide plates 633 and 634, are article guide bars 672 and 673, respectively (Figure 16), which extend in spaced parallel relation to the tracks 652 and 653 to prevent the cylindrical articles C from bouncing upwardly as they move from the chute 584 onto the article retaining tracks 652 and 653.

It will be observed in Figure 16 that the vertical arms of the bell cranks 660 and 661 have opposite ends of a tension spring 674 suitably connected thereto to normally urge the vertical arms of the bell cranks 660 and 661, along with the article retaining tracks 652 and 653, inwardly or to the position shown in Figure 17.

The horizontal arms of the bell cranks 660 and 661 in Figure 16 extend past each other and the proximate portions of the upper surfaces of the horizontal arms of the bell cranks 660 and 661 are engaged by respective abutments 675 and 676 (Figures 6-A, 13 and 16) which are shown in the form of adjustment screws, the upper portions of which threadably penetrate the free end of a lever arm 677 which extends outwardly towards the left-hand side of the machine and is fixedly mounted intermediate its ends on a shaft 680.

The shaft 680 is oscillatably mounted in bearing blocks 681 suitably secured to the proximate surfaces of the transverse frame members 71 and 81 (Figures 6-A and 13). It will be observed in Figures 6-A and 16 that the outer portion of the lever arm 677 is bifurcated and has a pivot pin 682 oscillatably mounted therein which is slidably penetrated by the upper portion of a connecting rod 683 (Figures 16 and 17).

The portion of the connecting rod 683 above the pivot pin 682 in Figure 16 has a pair of lock nuts 684 threadably mounted thereon which are employed to adjust a pressure applying sleeve 686 slidably mounted on the connecting rod 683, the lower surface of this sleeve 686 normally being urged into engagement with the upper surface of the pivot pin 682 by a compression spring 687. The compression spring 687 surrounds the connecting rod 683 and its upper end engages the lower surface of the pivot pin 682. The lower end of the spring 687 engages a pair of lock nuts 688 for adjusting the pressure of the compression spring 687. The purpose of mounting the upper end of the connecting rod 683 in this manner will be later described.

Referring to Figures 4-A, 17, 18 and 26, it will be observed that the lower end of the connecting rod 683 is pivotally connected, as at 683a, to the free or outer end of an arm 690a of a bell crank broadly designated at 690. This bell crank 690 is oscillatably mounted on a stub shaft 691 which extends outwardly and is secured in a block 692 (Figures 17 and 18) suitably secured to the inner surface of the leg 71 of the side frame member 67.

The bell crank 690 also has an arm 690b (Figure 26) which extends at an angle relative to the arm 690a and on the free end of which a cam follower 693 is rotatably mounted. The cam follower 693 is normally urged into engagement with the periphery of a segmental cam

wheel 694 by the tension spring 674 in Figure 16. The segmental cam wheel 694 is fixed on the main cam shaft 152.

It is thus seen that, upon the segmental cam wheel 694 moving into engagement with the cam follower 693, the connecting rod 683 is moved upwardly and normally imparts movement, in a clockwise direction, to the lever arm 677 in Figure 16 to thereby cause the article retaining tracks 652 and 653 to assume the position shown in Figure 16. As these article retaining tracks 652 and 653 move outwardly from the position shown in Figure 17 to the position shown in Figure 16, the cylindrical articles disposed upon the tracks 652 and 653 will be released, permitting the same to fall downwardly between the article guide plates 633 and 634 and to be deposited upon the bottom wall B-1 of the corresponding carrier B.

Means, to be later described, are provided to prevent the group of articles on the article retaining tracks 652 and 653 from being released therefrom in the event that an insufficient number of the articles C is supported by the tracks 652 and 653 and, also, in the event that the carrier B is not positioned properly for reception of the group of articles disposed on the tracks 652 and 653.

Referring to Figures 4-A, 6-A, 17 and 18, it will be observed that the shaft 680 also has a crank arm 694 fixed thereon which extends laterally from the shaft 680 towards the side frame member 66 and has an abutment 695, in the form of an adjustment screw, projecting downwardly therefrom intermediate the ends thereof. This abutment 695 engages the upper surface of a longitudinally extending bar 696 (Figures 4-A, 17 and 18), which is secured intermediate its ends to a vertically disposed article locator guide bar 697 mounted for vertical sliding movement in a guide block 700 suitably secured to one side of the longitudinally extending frame member 671, this guide block being suitably grooved in its face remote from the frame member 671 in order to accommodate the means for securing the horizontal bar 696 to the vertical guide bar 697.

It will be observed in Figures 2-A, 4-A, 12, 13 and 17 that the lower end of the vertical guide bar 697 terminates substantially below the lower surface of the guide block 700 and has a bridging plate 701 suitably secured thereto on opposite side edges of which a pair of forwardly and rearwardly extending article locator bars 702 are suitably secured, as by welding. It will be observed in Figures 16 and 17 that the lower edges of the article locator bars 702 are normally disposed in substantially the same horizontal plane as the lower surfaces of the article guide bars 673 and are spaced slightly inwardly of the article guide bars 673.

Since each cylindrical article usually has a peripheral bead at each end thereof, it is evident that the portions of the cylindrical articles between opposite ends thereof would assume a lower position than the opposite ends thereof at their uppermost surfaces as they are disposed upon the article retaining tracks 652 and 653. Therefore, the lower edges of the article locator bars 702 are normally spaced from the group of articles C resting upon the article retaining tracks 652 and 653.

Now, simultaneously with the movement of the articles retaining tracks 652 and 653 outwardly, from the position shown in Figure 17 to that

shown in Figure 16, the article locator bars 702 are caused to move downwardly, in a manner to be presently described, to insure that all of the articles C which were previously positioned upon the tracks 652 and 653 are positioned in a straight horizontal line upon the upper surface of the horizontal bottom wall B-1 of the corresponding carrier B.

Thus, as the segmental cam wheel 694 (Figure 26) moves into engagement with the cam follower 693, the lever arm 677 (Figures 16 and 17) would be prevented from moving in a clockwise direction unless the guide bar 697 had previously been permitted to move downwardly or moved downwardly simultaneously with movement of the lever arm 677 and the crank arm 694 in a clockwise direction in Figure 17, since the abutment 695 would engage the horizontal bar 696. In this instance, the spring 687 would be additionally compressed as the connecting rod moved upwardly relative to the pivot pin 682.

Now, in the event that the horizontal bar 696 and the associated parts have moved downwardly sufficiently, the lever arm 677 and the crank arm 694 would then be permitted to move in a clockwise direction in Figures 16 and 17. In order to insure that the article retaining tracks 652 and 653 are not moved outwardly beyond predetermined limits relative to the article guide plates 633 and 634, the free end of the crank arm 694 also has an abutment 703 thereon (Figure 18), which is shown in the form of an adjustment screw, and which engages the upper surface of the longitudinally extending frame member 671 (Figure 6-A) upon each downward stroke thereof.

It is thus seen that, although the upward stroke of the connecting rod 683 may be such that the abutments 675 and 676 (Figures 13 and 16) on the free end of the lever arm 677 would ordinarily cause the lower edges of the plates 656 and 657 to move outwardly to such an extent that the lower edges of the plate 657 might engage the corresponding upwardly extending portion of the carrier B, the abutment 703 from the crank arm 694 would prevent this from happening, since it engages the longitudinally extending frame member 671 and, accordingly, the connecting rod 683 would then continue its upward movement relative to the pivot pin 682 in the manner heretofore described.

In order to control the vertical movement of the article locator bars 702, the guide bar 697 extends substantially above the horizontal plane of the bracket 700 and has a pivoted lug or block 704 pivotally mounted thereon (Figures 4-A and 13), which is engaged by the bifurcated front end of a crank arm 705. The crank arm 705 extends rearwardly and is fixed on a shaft 706 oscillatably mounted at opposite ends thereof in a pair of bearing blocks 707 suitably secured to the front surface of the transverse frame member 77 (Figures 2-A, 4-A and 6-A).

It will be observed in Figures 2-A and 6-A that the end of the shaft 705 adjacent the side frame member 66 has one end of a crank arm 710 fixed thereon which extends upwardly and forwardly, at an angle, and has the upper end of a connecting rod 711 pivotally connected thereto as at 712.

In Figures 2-A, 17 and 21, the connecting rod 711 extends downwardly and forwardly at an angle and has a yoke member 713 fixed thereon, the bifurcated lower end of which straddles the main cam shaft 152 (Figure 21). The yoke mem-

ber 713 has a cam follower 714 rotatably mounted thereon which is normally urged into engagement with the periphery of a cam wheel, broadly designated at 715, by a tension spring 716 (Figures 2-A and 6-A). The upper end of the tension spring 716 is connected to the upper end of the connecting rod 711 and the lower end thereof is connected to a spring anchor 717 projecting upwardly from the upper horizontal frame portion 74 of the side frame member 66.

The cam wheel 715 has a low surface 715a and a high surface 715b, the high surface 715b extending through a substantially greater arc than the low surface 715a. These surfaces 715a and 715b are disposed in diametrically opposite relation to each other (Figure 21). It is thus seen that, as the low surface 715a of the cam wheel 715 moves into engagement with the cam follower 714, the guide bar 697 is caused to move downwardly to, in turn, move the article locator bar 702 downwardly to move the articles into proper position in the trough-shaped carrier B as shown in Figure 13. Of course, as the high surface 715b of the cam wheel 715 moves into engagement with the cam follower 714, the article locator bars return to the elevated or inoperative position shown in Figures 12 and 16.

Article depositing stop motions

Referring to Figures 12, 13 and 17, it will be observed that the vertically disposed guide bar 697 has a cavity, passageway or opening 720 therein in which a locking plunger 721 is periodically disposed. The locking plunger 721 is mounted for lateral sliding movement relative to the framework 21 in an enlarged portion 700a (Figure 17) of the bracket 700 heretofore described. This enlarged portion has a cavity 700b therein in which the plunger 721 has longitudinal sliding movement and the plunger has a reduced portion which slidably penetrates a restricted outer portion of the cavity 700b and is pivotally connected to one end of a solenoid plunger 723.

The solenoid plunger 723 is surrounded by a solenoid coil 724 suitably supported in a solenoid housing 725 which is suitably secured to an angle bracket 726, the horizontal leg of which extends inwardly and is secured to the upper surface of the longitudinally extending frame member 671. This solenoid, comprising parts 723, 724 and 725, is part of the electrical circuit to be later described. A compression spring 727 disposed within the cavity 700b normally urges the locking plunger 721 outwardly relative to the bracket 700 and into the cavity 720 in the vertical guide bar 697.

It is thus seen that the vertical guide bar 697 and associated parts will be prevented from moving downwardly while the locking plunger 721 is disposed in the cavity 720. In this event, it is evident that the compression spring 727 (Figure 2-A) will permit the guide bar 697 to remain in elevated position although the low surface 715a of the cam wheel 715 (Figure 21) may be in register with the cam follower 714.

Of course, the compression spring 687 (Figure 16) will also permit the connecting rod 683 to move upwardly relative to the pivot pin 682, since clockwise movement of the lever arm 677 and the arm 694 (Figures 6 and 8) will be prevented by virtue of the abutment 695 engaging the horizontal bar 696 secured to the vertically disposed guide bar 697. In other words, the locking plunger 721, when in the cavity 720 in the guide

bar 697, prevents the article retaining tracks 652 and 653 from moving outwardly to release the group of articles C supported thereby in the event that a predetermined number of articles C are not positioned on the article retaining tracks 652 and 653 and, also, in the event that a carrier B is not positioned beneath the lower edges of the article guide plate 633 and 634.

In order to energize the solenoid coil 724 to 10 cause the locking plunger 721 to move out of engagement with the cavity 720 in the guide bar 697, it is necessary that a normally opened switch 732 (Figures 2-A, 18 and 43-A) is closed, by means to be later described, since this switch 732 15 controls the solenoid coil 724 (Figure 17) as is clearly shown in Figure 43-A. Also, in order to insure that a predetermined number of articles are positioned on the tracks 652 and 653, normally opened switches 730 and 731 are provided 20 (Figures 6-A and 13). The switches 730 and 731 are closed only when there is an article properly positioned between the extreme forward ends of the article retaining tracks 652 and 653. The switch 732 is closed only when a carrier is positioned beneath the group of articles supported 25 by the article retaining tracks.

Referring to Figures 2-A, 4-A, 6-A, 12 and 13, it will be observed that the foremost article in 30 each group of cylindrical articles directed to the article retaining tracks 652 and 653 engages a stop member 733 integral with a bracket 734 and, in so doing, this foremost cylindrical article engages and effects movement of a pair of switch 35 operating levers 735, each of which is pivotally mounted intermediate the upper and lower ends thereof in a bifurcated projection 736 integral with the bracket 734. The lower portion of this bracket 734 also supports the front portions of the article guide plates 633 and 634.

40 The upper portion of the bracket 734 is suitably secured to the lower portion of the transverse frame member 81 of the second framework 21 as is clearly shown in Figures 12 and 13. A pair of these switch operating levers 735 are provided in order to insure that the axis of the foremost cylindrical article C extends in substantially right-angular relation to the article guide plates 633 and 634. The lower portions of the switch actuating levers 735 are disposed in the horizontal plane as the endmost portions of the 45 foremost cylindrical article C.

50 The uppermost end of each of the switch actuating levers 735 has an angle clip 737 suitably secured thereto, which may be integral therewith, and which extend outwardly with respect 55 to each other and are adapted to engage the spring loaded plungers of the switches 730 and 731 as the upper ends of the switch actuating levers move rearwardly under impact of the foremost of the cylindrical articles C in the group positioned on the article retaining tracks 652 and 653. The tracks 652 and 653 are of such length as to support six of the cylindrical articles in the particular instance illustrated in the drawings. It is to be understood, however, that the machine may be made to accommodate a greater or lesser number of articles in each group positioned on the article retaining tracks 652 and 653, if desired.

60 It is thus seen that the foremost article C, in a group of articles positioned upon the tracks 652 and 653, will cause the switches 730 and 731 to close, provided that the foremost article is properly positioned in right-angular relation to the 65 article guide plates 633 and 634. Each of the

switches 730 and 731 is suitably secured to a forwardly and rearwardly extending leg of an angle bracket 740 suitably secured to the transverse frame member 81 of the second framework 21 (Figures 2-A, 6-A, 12 and 13).

Referring to Figures 2-A and 6-A, it will be observed that the handle flap supporting bar 645 and handle flap retaining plate 646 are provided with coinciding openings 741 and, as the carrier B advances from the external folding members 570 and 571 to a point beneath the lower edges of the article guide plates 633 and 634, the handle flap B-6, projecting outwardly from the carrier B, passes between the plates 645 and 646, thus, closing the opening 741. Registering with the openings 741 in the plates 645 and 646 is an operating follower 742 of the normally opened switch 732 heretofore described and which is normally urged upwardly by the spring loaded plunger of the switch 732.

The switch 732 is fixed on the free end of an arm 743a of a bell crank broadly designated at 743. The bell crank 743 is oscillatably mounted on a stub shaft 744 which extends inwardly and is fixed in a block 745 suitably secured to the wall 57 of the trackway 55 (Figures 2-A and 18). The bell crank 743 also has an arm 743b projecting therefrom, at an angle relative to the arm 743a, in which the upper end of a connecting rod 746 is pivotally connected, as at 747. It will be observed in Figures 2-A, 17, 18 and 22 that the connecting rod 746 extends downwardly and has a yoke member 750 fixed on the lower end thereof, the bifurcated lower end of which straddles the main cam shaft 152. The yoke member has a cam follower 751 thereon which engages the periphery of a cam wheel, broadly designated at 752, having a high surface 752a and a low surface 752b. The cam wheel 752 is fixed on the main cam shaft 152.

The cam follower 751 is normally urged into engagement with the periphery of the cam wheel 752 by a tension spring 753 (Figure 2-A), the lower end of which is connected intermediate the ends of the arm 743a of the bell crank 743 and the upper end of which is connected to the outer surface of the top flap retaining bar 642. It is evident that movement of the low surface 752b of the cam wheel 752 (Figure 22) into engagement with the cam follower 751 causes the follower 742 on the switch 732 to move into the opening 741 in the handle flap supporting bar 645.

Now, if the handle flap B-6 of the carrier B is positioned between the handle flap supporting bar 645 and the handle flap retaining plate 646 at the opening 741, the follower 742 (Figure 2-A) will move relative to the switch 732 to move the spring loaded plunger thereof in order to close the switch 732.

At this time, it may happen that the low surface 715a of the cam wheel 715 (Figure 21) is disposed in the plane of the cam follower 714, with the result that the tension spring 716 would cause the arm 705 (Figure 4-A) and the vertical guide bar 697 to move downwardly slightly, immediately upon energization of the solenoid coil 724 (Figure 17). This downward movement of the vertical guide bar 697 would then cause the article retaining tracks 652 and 653 (Figures 16 and 17) to be moved outwardly so the articles supported thereby would move downwardly, by gravity, before the carrier B was properly positioned beneath the article guide plates 633 and 634.

Thus, the cam wheel 752 (Figure 22) controls

the movement of the switch 732 in timed relation to the movement of the conveyor 205 to insure that the carrier has been fully advanced into the article depositing station before the follower 742 engages the handle flap B-6 of the carrier B. Since the switches 730, 731 are normally open, the main cam shaft 152 would not rotate until a sufficient number of articles C were positioned on the tracks 652 and 653. Thus the conveyor 205 may sometimes stop momentarily upon a step in movement thereof and, also, upon a complete cycle of each movable element of the machine. Ordinarily, the switches 730, 731 do not remain open long enough, in the course of each cycle in operation of the machine, for the arm 163 of the clutch dog housing 164 to move adjacent the knife 171 before the solenoid 187 is again energized. Thus, the cam shaft 152 will ordinarily rotate continuously. By this time, it is assumed that there would be a sufficient number of articles C resting upon the article retaining tracks 652 and 653 to properly fill the carrier B, which is then in the form of a trough.

It will be noted that, as the articles C are moved downwardly, in the manner heretofore described, into the carrier B disposed therebeneath, the group of articles positioned in the carrier B are prevented from rolling or otherwise moving lengthwise of the upper reach of the conveyor 205, in either direction relative to the conveyor 205, by the bars 284 which project upwardly from the upper jaw 267 of the carrier grasping device 264 (Figures 40 and 41) and are also confined by the corresponding U-shaped confining member 285.

Since the cylindrical articles C move from the chute 564, by gravity, onto the article retaining tracks 652 and 653, a means is provided for preventing the articles within the chute from moving forwardly between the article guide plates 633 and 634, while the articles previously positioned on the tracks 652 and 653 are released therefrom and permitted to fall between the article guide plates 633 and 634. This structure is most clearly shown in Figures 12 and 13. An article control gate 760 is provided at the open lower end of the chute 564 which is adapted to have vertical movement between the article guide plates 633 and 634.

The article control gate 760 is shown in a raised position in Figure 12 and in a lowered or operative position in Figure 13. The gate 760 terminates substantially above the bottom wall 563 of the chute 564 when in an operative position, in which position the gate 760 engages the leading cylindrical article C disposed within the chute. The gate 760 extends upwardly and is fixed on the free end of an arm 761 pivotally mounted, as at 762, on a projection 700a depending from the lower portion of the guide block 700.

The rear end of the gate 760 also has a stop block 763 projecting therefrom which is adapted to engage the upper surface of the upper wall 565 of the chute 564 when the gate 760 is moved from the position shown in Figure 12 to that shown in Figure 13 by means to be presently described. Pivotally connected intermediate the ends of the arm 761, as at 764, is the lower end of a vertically disposed gate actuating bar 765 provided with a vertically extending slot 766 therein. Slidably penetrating the slot 766 is a headed gate raising element or pin 767 which projects from the horizontal bar 696 secured to

the vertically disposed guide bar 697 as heretofore described.

The gate actuating bar has an adjustable abutment or adjustment screw 770 threadably mounted therein which projects into the upper end of the slot 766 in the bar 765. Disposed adjacent and rearwardly of the vertically disposed gate actuating bar 765 is a vertically disposed guide block 771 (Figures 12 and 13) suitably secured to the inner surface of the longitudinally extending frame member 671, as by welding, (Figure 6-A).

The guide block 771 is of tubular construction and has the upper portion of a compression spring 772 therein, the lower portion of which bears against the upper surface of the arm 761 and the upper surface of which bears against the lower surface of an adjustment screw 773 threadably mounted in the tubular guide block 771. Thus, the compression spring 772 normally urges the arm 761 and its gate 760 downwardly.

In operation, assuming the parts to be in the position shown in Figure 12, as the guide bar 681 moves downwardly, in moving the articles which were resting upon the tracks 652 and 653 downwardly onto the bottom wall B-1 of the carrier B, the longitudinally extending bar 696, moves downwardly therewith and, in so doing, the pin 767 moves downwardly therewith thus permitting the compression spring 772 to move the gate 760 downwardly to the position shown in Figure 13, whereupon the stop block 763 engages the upper surface of the upper wall 565 of the chute 564.

Now, after the stop block 763 has engaged the wall 565 of the chute 564, the pin 767 is permitted to continue its downward movement since the stroke of the bar 697 is substantially greater than the downward stroke of the gate actuating bar 765. As the guide bar 697 subsequently returns to its uppermost position, the pin 767 moves upwardly until it engages the lower end of the adjustment screw 770 to again cause the gate 760 to move upwardly.

It is thus seen that the gate 760 is moved into operative position to prevent the cylindrical articles C in the chute 564 from entering the article depositing station between the plates 633 and 634 as the group of cylindrical articles previously positioned upon the article retaining tracks 652 and 653 are lowered into the carrier B. On the other hand, as the next step in movement is being imparted to the conveyor 205, the article locating bars 702 move upwardly and the article retaining tracks 652 and 653 again move inwardly to the position shown in Figure 17, whereupon the gate 760 is elevated to permit another group of articles C to move downwardly along the chute and finally onto the article retaining tracks 652 and 653 preparatory to a repeat operation of the article depositing station.

Fourth step in movement of a carrier

After the group of cylindrical articles C has been deposited on the bottom wall B-1 of the carrier B, and as the article locating bars 702 move upwardly, a fourth step is imparted to the conveyor 205 to thus move the carrier B, which has been in a form of a trough, forwardly along with the corresponding group of cylindrical articles C. Now, as heretofore stated, the second flap retaining bar 635 converges forwardly towards the side wall 58 of the trackway 55 and causes the corresponding second flap of the carrier to move from the slightly angularly disposed position shown in Figure 14 to a vertical position and, in so doing, the handle portion B-5 on the

upper end of the second flap is disposed at a higher elevation than the transverse frame member 81 of the second framework 21.

Therefore, it will be observed in Figures 17 and 18 that the transverse frame member 81 has a notch 775 in the lower portion thereof, one side wall of which has an inwardly and forwardly curved flap guide member 776 thereon whose front end is bent outwardly and suitably secured to the front surface of the transverse frame member 81, as by screws 777 (Figure 18). The upper portion of the corresponding flap of the carrier B engages this curved guide 776 to assist in positioning the same more closely to a vertical position as the carrier B moves past this point.

Now, referring to Figure 4-A, it will be observed that the front end of the second flap retaining plate 635 terminates in substantially the same vertical plane as the transverse frame member 81 and there is disposed immediately adjacent the front end of this second flap retaining plate 635, a carrier guide plate 780, which, extends above the horizontal plane of the wall 58 of the trackway 55, is spaced outwardly of the wall 58 and is secured to the outer surface of the wall 58, as by welding, there being a suitable spacing bar 781 between the lower portion of the carrier guide plate 780 and the wall 58 of the trackway 55 (Figure 15).

Referring to Figures 6-A, 6-B, 15, 17 and 18, there is shown a second folding means comprising a laterally movable upper folding plate 782 which is spaced at a slightly higher level than the level of the second handle flap retaining plate 650 as shown in Figure 15. This folding plate 782 is provided for folding the second flap B-3 to form the flap or upper wall B-4 extending across the upper surfaces of the articles C disposed in the carrier B so the carrier B is in the form of an elongated rectangular tube as shown in Figure 15.

It will be observed in Figures 6-A and 6-B that the rear corner of the plate 782 adjacent the second flap supporting plate 650 is formed at an angle, as at 782a, to thus engage the carrier B and form the flap or upper wall B-4, bending the same downwardly as the leading edge thereof moves forwardly in the course of the fourth step of the carrier B as imparted thereto by the conveyor 205. It is to be understood that the folding plate 782 also moves inwardly from the position shown in Figure 6-A to the position shown in Figure 6-B after the carrier B had advanced in its fourth step to a point beyond the article depositing station.

The upper folding plate 782 extends to the left in Figure 15 and is fixed to the upper surface of a block 785, by any suitable means such as a screw 786. The block 785 is fixed to the upper surface of the inner portion of a laterally movable slide 787 mounted for lateral sliding movement in a guide block 799.

The guide block 799 is preferably of cast construction and has a rearwardly extending portion 799a integral therewith which is suitably secured to the inner surface of the leg 71 of the side frame member 67, as by screws 791 (Figures 4-A, 6-A, 6-B and 17). The slide 787 is relatively broad horizontally and narrow in thickness and extends outwardly substantially beyond the guide block 799 and has the inner end of a link 792 pivotally connected thereto, as at 793 (Figures 4-A, 17 and 18). The outer end of the link 792 is pivotally connected, as at 794, to the upper end of a substantially inverted L-shaped arm 795a of a bell crank

195 is pivotally mounted on a stub shaft 196 (Figures 4-A, 17 and 18) projecting forwardly from a bracket 197 suitably secured, as by screws 800, to the outer surface of the leg 71 of the side frame member 67.

The bell crank 195 also has an arm 195b which projects inwardly at substantially 90 degrees from the arm 195a and is pivotally connected, as at 801, to the upper end of a connecting rod 802. The connecting rod 802 has a yoke member 803 fixed to the lower end thereof which, as shown in Figures 18, 28 and 34, extends downwardly and the bifurcated lower end of which straddles the main cam shaft 152. The yoke member 803 has a cam follower 805 mounted thereon which engages the periphery of the cam wheel 174.

The cam wheel 174 has a relatively high peripheral surface 174a and a relatively low peripheral surface 174b disposed in diametrically opposite relation to the high surface 174a. The cam follower 805 is normally urged against the periphery of the cam wheel 174 by a tension spring 807 (Figures 6-B, 17 and 18) connected at its outer end intermediate the ends of the bell crank arm 195a and the inner end of which is connected to the transverse frame member 63 of the second framework 21.

Now, during operation of the machine, it may sometimes happen that one of the cylindrical articles would be disposed at a higher elevation than the folding plate 782 due to various reasons, such as the articles overriding one another. In this instance, the inner edge of the folding plate 782 would engage this cylindrical article or other obstruction whereupon the spring 807 would permit the low surface of the cam wheel 805b to move past the cam follower 805 without engaging the same.

In order to stop the machine in the event of the folding plate 782 engaging an obstruction, there is provided a normally closed switch 810 (Figures 6-A and 18) which has electrical connections therefrom for controlling the magnetic switch 116 (Figure 43-A) for stopping the machine, in the manner heretofore described, upon the switch 810 being opened. Now, this switch 810 is fixed on one end of a lever 811 pivotally mounted intermediate its ends, as at 812, on a projection extending from the lower portion of the guide block 790. This lever 811 extends inwardly and has the upper end of a connecting rod 813 pivotally connected thereto, as at 814 (Figures 4-A, 12, 17, 18 and 25).

The lower end of the connecting rod 813 is pivotally connected to the front end of a crank arm 815, as at 816 (Figures 12, 18 and 25). The crank arm 815 extends rearwardly and is oscillatably mounted on the stub shaft 691 heretofore described. It will be observed in Figures 12 and 25 that the crank arm 815 has a downwardly projecting portion 815a intermediate its ends which has a cam follower 817 mounted thereon.

The cam follower 817 rests against the periphery of a substantially circular cam wheel 820 which is provided with a notch 820a in the periphery thereof. The cam wheel 820 is fixed on the main cam shaft 152 and the spring loaded plunger of the switch 810 is disposed in the same vertical plane as the slide 787 when the slide is in its outermost position as shown in Figure 18.

The notch 820a is so positioned, relative to the low surface 174b of the cam wheel 174 (Figures 28 and 34), that the switch 810 moves upwardly as the low surface 174b of the cam wheel 174 reg-

isters with the cam follower 805. The switch 810 is caused to move upwardly upon the notch 820a (Figure 25) moving into engagement with the cam follower 817, due to the weight of the crank arm 815.

Now, as the slide 787 moves inwardly, the switch 810 moves upwardly and, in the event of the slide 787 being free to move inwardly to the limit of its normal stroke, the plunger of the switch 810 will merely extend past the slide 787. On the other hand, if there is an obstruction in the path of the plate 782 (Figure 15) as it moves inwardly, then the slide 787 will be prevented from moving inwardly to its fully operative position and the plunger of the switch 810 will engage the slide 787, thus opening the switch 810 to deenergize the magnetic switch 116 to thereby stop the machine.

Stitching station

Upon the fifth step in movement being imparted to the conveyor 205 and the corresponding carrier B, the carrier B moves into position beneath the stitching mechanism generally designated at 825 (Figures 1, 2-B, 4-B, 6-B and 7-A). There are various types of stitching devices which may be employed and, in the present instance, the stitching device is a form of stapling machine which may be of a type substantially as disclosed in Patent Numbers 1,983,384 and 2,088,428 to H. T. McClure, among others. This stitching mechanism is of a type substantially as is manufactured by Boston Wire Stitcher Company, Portland, Maine.

Therefore, only a brief description will be given of the stitching device 825. As disclosed in said co-pending applications, the handle flaps B-5 and B-6 of the carrier B are stitched together at four points, and, therefore, the particular stitching device 825 shown in the drawings includes four stitching units, each of which has a spool 826 from which wire W extends and which wire W is subsequently cut into lengths and formed as staples by conventional means, not shown, to be ejected as such at the stitching elements indicated at 827 in Figures 2-B and 4-B.

Conventional means are provided for feeding the wire W and operating the stitching device and this includes a shaft 830 (Figure 2-B) which projects laterally, through the G-shaped housing 91, from the stitching device 825 and on which a V-pulley 831 is fixedly mounted. The V-pulley 831 is engaged by a V-belt 832 (Figures 1 and 2-B) which engages a relatively small V-pulley 833 fixed on a shaft 834 projecting from an electric motor 835. The electric motor 835 has wires 836 and 837 extending therefrom which are adapted to be connected to a suitable source of electrical energy, not shown. The electric motor 835 is suitably secured to a bracket 840, as by screws 841. The bracket 840 is of substantially L-shaped construction and is suitably secured, as by screws 842, to the front face of the hollow casting 91.

Now, as clearly disclosed in said Patent No. 2,088,428, the stitching mechanism is controlled, as to its operation, by a linkage which is indicated in the present drawings at 843. This linkage 843 constitutes a solenoid plunger in the present instance, the lower portion of which is surrounded by a solenoid coil 844 (Figure 43) disposed within a solenoid housing 845 (Figure 2-B). The solenoid 845 is suitably supported on the third framework 22 and has suitable elec-

trical connections, to be later described, which are connected in series to a switch 846 and a switch 847 (Figures 2-A, 21, 43 and 43-A).

Both of the switches 846 and 847 are normally open and the electrical connections between these switches and the solenoid coil 844 will be later described. It will be observed in Figures 2-A and 21 that the resilient plunger of the switch 847 is controlled by a follower arm 847a having a follower 847b on the free end thereof which is adapted to be intermittently engaged by a cam member 850 suitably secured to one side of the cam wheel 715, so the cam member 850 will engage the follower 847b to close the switch 847 in timed relation to movement of the conveyor chain 224, the cam shaft 152 and, of course, the carrier B.

The switch 847 is supported in proper spaced relation to the cam shaft 152 on a standard 851 which extends downwardly and is suitably secured to the upper surface of the base 24 of the machine. Referring to Figures 4-B and 6-B, it will be observed that the switch 846 is suitably secured to the outer surface of the carrier guide plate 780 and this plate 780 has an opening 852 therein through which a follower 853 and an arm 854 is normally urged by the spring loaded or resilient plunger of the switch 846.

Now, it is evident that, as the filled carrier B moves into position beneath the stitching device 825, the follower 853 will be engaged thereby to thus close the switch 846. The cam member 850 (Figure 21) is so positioned relative to the means for imparting movement to the conveyor 205, heretofore described, that the cam 850 will close the switch 847 after the switch 846 has been closed thereby insuring that the filled carrier B is in the proper position beneath the stitching device 825 before both of the switches are closed because, at this time, the solenoid coil 844 disposed within the housing 845 will be energized to move the linkage 843 downwardly in Figure 2-B, thereby causing the stitching device to operate for stitching the handle portions B-5 and B-6 of the carrier B together. Since the electric motor 835 is energized continuously during operation of the machine, this electric motor has been omitted from the wiring diagram in Figures 43 and 43-A.

It will be noted that in Figures 2-B, 4-B and 6-B the carrier guide plate 780 has a carrier flap hold-down plate 855 suitably secured to the upper surface thereof, as by screws 856, there being a suitable spacer between the lower surface of the plate 855 and the upper edge of the guide plate 780 so the lower surface of the plate 855 is disposed in substantially the same horizontal plane as the lower surface of the second handle flap retaining plate 650 (Figure 2-B).

The rear edge of the plate 855 is flared upwardly to insure that the portions B-4 and B-5 of the carrier B previously folded horizontally by the folding plate 782 remain in a horizontal position as the carrier B moves into position beneath the stitching device 825.

It will be noted that the upper portion of the stitching device 825 is omitted in Figure 6-B in order to clearly illustrate the plate 855. The plate 855 has suitable openings 855a through which the stitching elements 827 pass in stitching the handle flaps B-5 and B-6 of the carrier B together. It will be observed in Figures 2-B, 6-B and 7-A that the stitching device 825 has conventional anvils 828 thereon which project through suitable openings in the member 645 in

alignment with the stitching elements 827 for crimping the staples as the flaps of the carrier are stitched together.

Upon the next step in movement by the conveyor 205, that is, the sixth step in movement by the carrier, the handle flaps B-5 and B-6 of the carrier B, which were stitched together at the stitching station, are caused to pass beneath a spirally bent handle flap folding bar 857, suitably connected to the front end portion of the handle flap support bar 645 (Figures 2-B and 6-B) by means of a strap member 860 and screws 861. The rear edge of this handle flap folding bar 857 is spaced slightly above the member 645 and extends horizontally in parallel relation to the handle flap support bar 645 and then curves inwardly to where the front portion thereof is disposed slightly outwardly of the vertical plane of the side wall 57 of the trackway 55.

The front portion of this handle flap holding bar 857 is suitably secured to the lower end of a strap member 862 (Figures 2-C and 30) which extends upwardly and is suitably secured at its upper end to a portion of a filled carrier accumulating or stacking and boxing mechanism to be later described. It will be noted that a trackway guide plate 863 is secured to the outer surface of the wall 57 of the trackway 55, the rear end of which coincides with the front end of the first flap retaining bar 642 and the front end of which terminates in substantially the same vertical plane as the front end of the handle flap folding bar 857 (Figures 2-B and 2-C). The upper portion of the trackway guide plate 863 projects above the upper edge of the wall 57 a lesser distance than the first flap retaining bar 642, but sufficiently to confine the corresponding wall of the carrier B on the trackway 55. It is thus seen that, as the filled carrier moves forwardly in its sixth step of movement, the handle flaps B-5 and B-6 are folded against the vertically disposed first wall B-2 so the handle flaps B-5 and B-6 do not project outwardly from the filled carrier B.

Filled carrier stacking and boxing station

After the handle flaps B-5 and B-6 have been folded against the first wall of the carrier B, the carrier is advanced a seventh step by the conveyor 205 whereupon a means, to be later described, moves the carrier B to one side of its normal path of travel and another means elevates the filled carrier to position the same within a filled carrier accumulating or stacking mechanism. Each successive filled carrier is then positioned in the filled carrier accumulating mechanism beneath the previously positioned carrier and these carriers are moved upwardly and stacked in superposed relation. After a predetermined number of carriers have been directed into the filled carrier accumulating mechanism, suitable means are provided for moving a predetermined number of the carriers laterally into a suitable carton or box, the accumulator mechanism having a wall provided with an opening with flanges around the opening for supporting the box into which the filled carriers are fed in stacked relation.

The box is usually held in position on the flanges of the accumulator mechanism by an operator and upon a stack of filled carriers being directed thereinto, the operator then removes the box full of filled carriers and places another

box in position for receiving another group or stack of filled carriers.

The mechanism for stacking the filled carriers and directing the same into boxes is most clearly shown in Figures 1, 2-C, 4-C, 5, 6-C, 7-A, 29 and 30.

As the filled carrier B is advanced to a position beneath the overhanging portions 106 and 114 of the respective frame members 102 and 110 (Figures 7-A, 29 and 30), the upper or outer jaw 267 of the carrier grasping device 264 is moved to open position relative to the inner or lower jaw 268 to thus release the carrier B therefrom. To this end, a second jaw opening device is provided in the form of a pressure applying arm 865 which is cut away at its medial portion in Figure 5 to clear the upper edges of the U-shaped confining members 285.

The pressure applying arm 865 extends to the right in Figure 5 and it will be observed in Figures 4-C and 30 that this arm is suitably secured to the front end of a crank arm 866. The crank arm 866 extends rearwardly and is pivotally mounted on a stub shaft 867 fixed in a block 870 suitably secured to the front surface of the front frame member 101, as by screws 871 (Figures 4-C, 5, 6-C and 30). The upper end of a connecting rod 872 is pivotally connected intermediate the ends of the crank arm 866, as at 873, and the lower end of this connecting rod 872 is pivotally connected, as at 874, to the free end of a control lever 875.

The control lever 875 is oscillatably mounted intermediate its ends on a stub shaft 876 fixed in a block 877 suitably secured to the front surface of the frame member 101, as by screws 880 (Figures 4-C and 5). It will be observed in Figures 4-C and 33 that the control lever 875 extends rearwardly and has a cam follower 881 rotatably mounted thereon which engages the periphery of a cam wheel broadly designated at 882 having a high surface 882a and a low surface 882b disposed in diametrically opposite relation to each other.

It will be observed in Figures 4-C and 5 that the cam follower 881 (Figure 33) is urged against the periphery of the cam wheel 882 by a tension spring 883 connected at its lower end to the control lever 875, forwardly of the stub shaft 876, and connected at its upper end to the side wall 58 of the trackway 55. Thus, the tension spring 883 also normally urges the pressure applying arm 865 to an elevated or inoperative position.

When the high surface 882a of the cam wheel 882 moves into engagement with the cam follower 881, the pressure applying arm 865 moves downwardly and engages the wing portion 276 (Figures 40 and 41) of the corresponding carrier clamping device 264 to move the jaw 267 away from the jaw 268 thus releasing the carrier therefrom. Immediately upon the carrier B being released from the jaws 267 and 268 of the carrier clamping device 264, the vertically disposed second side wall B-3 of the corresponding filled carrier B is engaged by a transfer member in the form of a plate 885 (Figures 29 and 30).

It will be observed in Figure 29 that the plate 885 is disposed above the horizontal plane of the upper edges of the side walls 57 and 58 of the trackway 55 and is propelled, by means to be presently described, to and fro transversely of the trackway 55 between the position shown in Figure 29 and the position shown in Figure 30. As each successive filled carrier B is moved in its eighth step into the filled carrier stacking

and boxing station, it moves beyond the front end of the carrier guide plate 780 and the handle flap folding bar 857 and into alignment with the plate 885, whereupon the transfer plate 885 moves from right to left in Figure 29 or from the position shown in Figure 30 to the position shown in Figure 29, by means to be presently described, to transfer the filled carrier B onto an elevator or stacking plate 886 (Figures 2-C, 29 and 30).

The transfer plate 885 has depending therefrom a plurality of substantially L-shaped hook members 887 and the side walls 57 and 58 of the trackway 55 are provided with corresponding notches 890 in the upper edges thereof (Figures 7-A and 30) through which these L-shaped hook members 887 pass as the transfer plate 885 moves to and fro. The lateral portions of these L-shaped hook members 887 are disposed slightly below or in substantially the same horizontal plane as the upper edges of the side walls 57 and 58 of the trackway 55 and the lower surfaces thereof are disposed above the horizontal plane of the upper reach of the endless chain 224 of the conveyor 205.

Thus, as the transfer plate 885 moves from the position shown in Figure 30 to that shown in Figure 29, the L-shaped hook members 887 support the corresponding edge of the filled carrier to insure that the carrier is maintained in a substantially level position as it is transferred onto the elevator or stacking plate 886. The transfer plate 885 is suitably secured to one end of a guide bar 891 by means of an angle clip 892 and screws 893 (Figures 29 and 30) and this guide bar extends to the right in Figure 29 and away from the observer in Figure 30 and is slidably mounted in a guide bracket 894 suitably secured to the rear surface of the front frame member 101 of the fourth framework 23 as shown in Figures 4-C and 30.

It will be most clearly observed in Figure 30 that the outer end of the guide bar 891 is bifurcated and has pivotally mounted therein, as at 895, the inner end of a link 896. The outer end of the link 896 is pivotally connected, as at 897, to the upper end of an arm 900a of a bell crank 900. The bell crank 900 is oscillatably mounted on a longitudinally extending shaft 898 which is fixed in projections 899 extending from the legs 103 and 111 of the respective frame members 100 and 101. It will be observed, in Figures 29 and 30, that the bell crank 900 also has a bifurcated arm 900b extending therefrom, to which the upper end of a connecting rod 901 is pivotally connected, as at 902.

The connecting rod 901 extends downwardly in Figures 4-C, 29 and 39 and is fixed in the upper end of a yoke member 903 which straddles the secondary cam shaft 200 for guiding the same as a cam follower 904 thereon is urged against the periphery of a cam wheel broadly designated at 905 by means of a tension spring 906 (Figures 29 and 39). The outer end of the tension spring 906 is connected intermediate the ends of the arm 900a of the bell crank 900 and the other end thereof is connected to a guide bracket 907 to be later described.

Thus, the tension spring 906 normally urges the transfer plate 885 from right to left in Figure 29 upon the low surface 905a of the bell crank 905 moving into alignment with the cam follower 904. Of course, when the cam follower 904 is in engagement with the high surface 905b of the cam wheel 905, the transfer plate 885 assumes the position shown in Figure 30, to one side of the

path of travel of the filled carrier B. In the event of there being any obstruction in the path of travel of the filled carrier B, as it is transferred from the trackway 55, and the elevator or stacking plate 886, such as the carrier becoming tilted and engaging other parts of the machine, there is provided a safety switch 910 disposed in the vertical plane of the guide bar 891 when the guide bar is in the withdrawn position shown in Figure 30.

This safety switch 910 is fixed on one end of a lever arm 911 (Figure 29) pivotally mounted, as at 912, on the bracket 894. The end of the lever arm 911 remote from the safety switch 910 is pivotally connected, as at 913 (Figure 31), to the upper end of a connecting rod 914. The connecting rod 914 extends downwardly in Figures 29 and 31 and is fixed in the upper end of a yoke member 915 which straddles the secondary cam shaft 200 and is guided thereon. The yoke member 915 has a cam follower 916 thereon which is urged, by any suitable means such as gravity, against the periphery of a cam wheel broadly designated at 917 which has a low surface 917a and a high surface 917b.

It will be noted in Figure 31 that the low surface 917a is relatively short in comparison to the lineal length of the periphery of the cam wheel 917 and, as the low surface 905a of the cam wheel 905 moves into engagement with or into the vertical plane of the cam follower 904, the cam follower 916 in Figure 31 drops into the notch 917a thus causing the safety switch 910 to move upwardly in Figure 29. However, in the event of there being an obstruction in the path of the filled carriers B as they are moved laterally from the upper edges of the side walls 57 and 58 of the trackway 55, the cam follower 916 (Figure 31) will be prevented from moving into the notch or low surface 917a because of the spring loaded plunger of the normally closed safety switch 910 coming into engagement with the lower surface of the guide bar 891.

The safety switch 910 is disposed in the circuit between the source of electrical energy and the magnetic switch 116, as will be later described, and, therefore, upon the plunger of the safety switch 910 being depressed as it engages the lower surface of the guide bar 891, this will open the circuit to the solenoid coil associated with the magnetic switch 116 shown in Figures 43-A to deenergize the electric motor 117 and to stop the machine. It is evident that the transfer plate 885 moves from the position shown in Figure 30 to that shown in Figure 29 and then returns to the position shown in Figure 30 in the interim between successive steps in movement by the conveyor 205.

As the corresponding carrier is moved from the trackway 55 to a position upon the elevator or stacking plate 886, it is moved resiliently against a stop plate 920 by virtue of the tension spring 906. The stop plate 920 is suitably secured, as by welding, to upwardly extending projections 921 integral with bearing brackets 322, the lower portions of which extend inwardly and are suitably secured to the remote surfaces of the frame members 100 and 101. The elevator or stacking plate 886 is suitably secured to the upper end of a guide bar 923 mounted for vertical sliding movement in the guide block 907, heretofore described. The guide block 907 is suitably secured, as by screws 907a (Figure 30) to the rear surface of the front frame member 101.

It will be observed in Figures 2-C and 29 that

the lower end of the guide bar 923 is bifurcated and has the upper end of a connecting rod 924 pivotally connected thereto, as at 925. The lower end of the connecting rod 924 is pivotally connected, as at 926, to a crank arm 927. This crank arm 927 is oscillatably mounted on a forwardly and rearwardly extending shaft 930 (Figures 2-C, 29 and 30) which is secured at opposite ends thereof in projections 931 integral with the frame members 100 and 101.

The crank arm 927 has the upper end of a connecting rod 933 pivotally connected thereto by means of a pivot pin 932 (Figure 29) which, on occasion, may be overridden by the connecting rod 933 in the event of there being an obstruction to prevent vertical movement of the elevator plate 886. To this end, the connecting rod 933 is suitably notched as at 932a to pass over the pin 932 and this pin 932 is held in engagement with the notch in the connecting rod 933 by a plate or bar 934 which is engaged by a compression spring 935 surrounding a headed pin or bolt 936. This bolt 936 slidably penetrates the bar 934 and the upper portion of the connecting rod 933 and, thus, the compression spring 935 normally urges the connecting rod 933 into engagement with the bar 934.

The lower end of the bar 934 is fixed to the upper end of a yoke member 937 and the lower end of the connecting rod 933 is pivotally connected, as at 933a, to the yoke member 937, thus permitting the connecting rod 933 to pivot outwardly in the event of an obstruction being disposed in the path of the carrier disposed upon the elevator or stacking plate 886 in the course of its upward movement.

Now, the upper end of the connecting rod 933 in Figure 29 has a switch 938 suitably secured thereto, the plunger of which is normally engaged by the fixed bar 934 to maintain the switch 938 in closed position. The switch 938 is also interposed in the circuit between the source of electrical energy and the coil of the magnetic switch 116 shown in Figure 43-A and, accordingly, upon the connecting rod 933 overriding the pin 932 in the manner heretofore described, the switch 938 will move away from the bar 934, thus permitting the same to open. This deenergizes the solenoid coil (Figure 43-A) of the switch 116 to stop the machine.

The yoke member 937 straddles and is guided upon the secondary cam shaft 200 (Figures 2-C and 29). A cam follower 940 carried by the yoke 937 is normally urged by gravity against the periphery of a cam wheel broadly designated at 941. The cam wheel 941 has a generated curved low surface 941a and a generated curved high surface 941b. It is evident that, when the low surface 941a is in engagement with the cam follower 940, as is shown in Figure 2-C, the elevator or stacking plate 886 assumes the position shown in Figures 2-C and 29. Upon the high surface 941b being in engagement with the cam follower 940, the elevator or stacking plate 886 moves to a position in the same horizontal plane as a pair of filled carrier or stack retaining bars 942 and 943 or slightly above. Of course, if there is an obstruction in the path of movement of either the filled carrier disposed upon the elevator plate 886 or the plate 886, the connecting rod 933 will override the pin 932 in its course of upward movement.

It will be observed in Figure 29 that the upper edges of the transfer plate 885 and the stop plate 920 are spaced below the lower edges of a pair

of corresponding stacking guide plates 944 and 945 which are provided with respective openings 946 and 947 therein. These openings 946 and 947 are preferably rectangular to correspond to the shape of the box or other container into which the stack of filled carriers B are moved in a manner to be later described. It will be noted that the opening 947 in the innermost stacking guide plate 945 is relatively smaller than the opening 946 in the outermost stacking guide plate 944.

Thus, the filled carrier retaining bars 942 and 943 are normally positioned between the upper edges of the transfer plate 885 and the stop plate 920 and the lower edges of the stacking guide plates 944 and 945, with the inner edges of the stack retaining bars disposed inwardly of the vertical planes of the respective second and first stacking guide plates 944 and 945. It will be noted that the inner edges of these stack retaining bars 942 and 943 are slanted or beveled from the upper edge downwardly in diverging relation to each other so that, upon a filled carrier being moved upwardly therebetween by the elevator or stacking plate 886, these filled carrier retaining bars 942 and 943 are biased apart until the filled carrier passes thereby, whereupon they again move inwardly to the position shown in Figure 29 to support the corresponding carrier B as the elevator or stacking plate 886 returns to the position shown in Figure 29.

The outermost filled carrier retaining bar 942 is fixed on a plate 950, as by welding, and the plate 950 is suitably secured, as by screws 951, to a pair of substantially inverted L-shaped support arms 952. These support arms 952 extend downwardly and are pivotally mounted on a longitudinally extending shaft 953 fixed adjacent opposed ends thereof in the bearing brackets 922 heretofore described.

It will be observed in Figures 2-C and 29 that there are disposed adjacent the upper and side walls of the opening 946 in the second stacking guide plate 944 suitable locator bars 954, 955 and 956, which are shown in the form of angle bars being suitably secured to the outer surface of the stacking guide plate 944, as by screws 957. Positioned below the bottom wall of the opening 946 in the stacking guide plate 944 is a box guide plate 960 which extends outwardly and is then bent downwardly at an angle to assist in guiding a suitable box or other container, indicated at 961 in Figure 29, into position surrounding the opening 946 and with the top and side walls thereof resting against or in close proximity to the locator bars 954 to 956, inclusive.

Thus, the open end of the box 961 is positioned in communication with the opening 946 in the stacking guide plate 944. It will be observed in Figure 29 that the box guide plate 960 is bent downwardly and secured against the outer surface of the stacking guide plate 944 by any suitable means, such as welding.

Now, each of the arms 952 has the outer end of a tension spring 962 connected thereto which extends inwardly and is connected to the outer wall 57 of the trackway 55 by means of a spring anchor 963 (Figure 29). The tension springs 962 normally urge the filled carrier retaining bar 942 inwardly to where adjustable stop members 964, shown in the form of adjustment screws, engage the outer surface of the box guide plate 960 adjacent the stacking guide plate 944, or, if so desired, the adjustable stop members 964 may bear directly against the outer surface

of the stacking guide plate 944. These adjustment screws 964 are threadably mounted in the plate 950 above the upper ends of the arms 952 as shown in Figures 2-C and 29.

5 The filled carrier retaining bar 943 is suitably secured to the lower ends of a pair of levers 965, as by welding (Figures 4-C, 5 and 29), which extend upwardly and are pivotally mounted adjacent the front surfaces of the frame members 100 and 101 on a forwardly and rearwardly extending shaft 966. The shaft 966 is fixed in a pair of blocks 967 suitably secured, as by screws 970, to the corresponding frame members 100 and 101.

10 15 The upper end of each of the lever arms 965 has one end of a tension spring 971 connected thereto, the other end of which is connected to a suitable spring anchor shown in the form of an angle clip 972. Each of the angle clips 972 is secured to the corresponding frame members 100 and 101, by any suitable means such as a screw 973 (Figures 5 and 29).

20 25 The inner stacking guide plate 945 is preferably of relatively thin material and, accordingly, is provided with a pair of vertically spaced reenforcing members 974 and 974a (Figures 4-C, 5 and 29) which are suitably secured thereto, as by welding. These bars or reenforcing members 974 and 974a have respective pairs of brackets 975 and 976 suitably secured thereto, as by screws 977. The brackets 975 and 976 are shown as angle plates which extend inwardly and are suitably secured, as by screws 980, to the remote surfaces of the overhanging portions 106 and 114 of the 30 35 respective frame members 100 and 101 of the front or fourth framework 23.

At least one of the levers 965, to which the filled carrier retaining bar 943 is secured, has an adjustable stop member 981 thereon, shown in the 40 form of an adjustment screw threadably penetrating the corresponding lever arm 965 and one end of which is normally urged into engagement with the reenforcing member 974a of the inner or first stacking guide plate 945 by the tension springs 971. Thus, the adjustment screw 981 limits movement of the corresponding filled carrier retaining bar 943 towards the filled carrier retaining bar 942.

It is thus seen that, as each filled carrier is 50 positioned in the horizontal plane of the transfer plate 885 while in the position shown in Figure 30, the transfer plate 885 transfers the corresponding filled carrier onto the elevator or stacking plate 886 which, in turn, elevates the corresponding carrier to position the same upon the filled carrier retaining bars 942 and 943. As each successive carrier is moved upwardly, it is evident that the upper surface of the carrier will engage the lower surface of the preceding carrier to move the same upwardly thus forming 55 a stack of filled carriers B between the stacking guide plates 944 and 945. The outer stacking guide plate 944 is supported in fixed relation to the inner stacking guide plate 945 by means of

60 transverse plates 982 and 983 which form rear and front respective walls of the carrier stacker housing, these plates 982 and 983 being suitably secured to the proximate surfaces of the stacking guide plates 944 and 945 by means of angle bars 984 and screws 985 (Figures 5, 6-C and 29).

65 70 Since the filled carriers B are thrust upwardly rather suddenly by the elevator or stacking plate 886, upon a predetermined number of filled carriers B being stacked between the stacking guide plates 944 and 945, the next succeeding filled car-

rier moved upwardly by the elevator plate 886 will cause the uppermost carrier in said stack to move against a pair of stop bars 986 which are shown in the form of angle bars in Figure 29 and are suitably secured to the inner surface of the stacking guide plates 944 and 945 adjacent the upper wall of the opening 946 in the stacking guide plate 944. These stop bars 986 prevent the uppermost filled carrier from moving beyond the horizontal plane of the upper wall of the opening 946.

The stop bars 986 are spaced transversely of each other to provide an opening therebetween in which a switch actuating follower 987 is normally disposed. This switch actuating follower 987 is mounted at one end of a switch actuating arm 990 which, when moved upwardly, is adapted to close a normally opened switch 991, the housing of which is suitably secured to the inner stacking guide plate 945 as shown in Figure 29. This switch 991 is interposed in a circuit connected to a solenoid coil 992 (Figures 29 and 43), as will be later described, and the solenoid coil 992 is carried by a housing 993 suitably secured to the rear surface of the overhanging portion 114 of the front frame member 101, as by welding (Figures 4-C, 6-C and 29).

The solenoid coil 992 surrounds a solenoid plunger 994 to which the upper end of a locking pin 995 is pivotally connected. The solenoid plunger 994 is located above a laterally extending guide bar 996 slidably mounted in a guide block 997 suitably secured to the inner surface of the front frame member 101, as by screws 1001 (Figures 4-C and 29). One end of the guide bar 996 has a stack transfer member 1002, in the form of a vertically disposed substantially rectangular plate, suitably secured thereto, as by angle clips 1003 and screws 1004. This stack transfer member registers with the opening 947 in the stacking guide plate 945. The guide bar 996 has a cavity or opening 1005 therein in which the locking pin 995 is loosely disposed when the stack transfer member 1002 is in the position shown in Figure 29.

Upon the uppermost carrier in a stack of carriers engaging and imparting movement to the follower 987, the switch actuating bar 990 closes the switch 991 to energize the solenoid coil 992, thereby causing the locking pin 995 to move upwardly out of engagement with the guide bar 996. The guide bar 996 can then move inwardly by means to be presently described.

The guide bar 996 is bifurcated at its outer end and has the inner end of a connecting rod 1006 pivotally connected thereto, as at 1007 (Figure 29). The outer end of the connecting rod 1006 is pivotally connected, as at 1010, to the upper end of an arm 1011a of a bell crank broadly designated at 1011. The bell crank 1011 also has an arm 1011b extending inwardly therefrom in substantially right angular relation to the arm 1011a and to the free end of which the upper end of a pair of tension springs 1012 are connected. The tension springs 1012 extend downwardly and are connected to a suitable spring anchor 1013 which is shown in the form of an angle clip suitably secured to the upper surface of the base 24 of the machine, as by screws 1014.

The bell crank 1011 is oscillatably mounted on a forwardly and rearwardly extending shaft 1015, opposite ends of which are suitably secured to the frame members 100 and 101 of the front framework 23. Pivotedly connected intermediate the ends of the arm 1011b of the bell crank 1011,

as at 1016, is the upper end of a connecting rod 1017 (Figures 29 and 38), the lower end of which is fixed to the upper end of a yoke member 1020.

The yoke member 1020 straddles and is guided by the secondary cam shaft 200 and has a cam follower 1021 therein which is normally urged into engagement with the periphery of a cam wheel broadly designated at 1022 by the tension springs 1012. The cam wheel 1022 has a low surface 1022a and a high surface 1022b. The cam wheel 1022 is fixed on the secondary cam shaft 200.

Now, when the high surface 1022b of the cam wheel 1022 is in engagement with the cam follower 1021, the stack transfer plate 1002 assumes the position shown in Figure 29. Upon the low surface 1022a of the cam wheel 1022 moving into the vertical plane of the cam follower 1021, the tension springs 1012 are then permitted to move the stack transfer plate 1002 from right to left in Figure 29 immediately upon energization of the solenoid coil 992 which, of course, causes the locking pin 995 to move out of engagement with the cavity 1005 in the guide bar 996.

It is thus seen that immediately upon the uppermost carrier in a stack of carriers engaging the follower 987 (Figure 29) and closing the switch 991, the stack transfer plate 1002 will move from right to left under the tension of the tension springs 1012 to thereby transfer the corresponding stack of filled carriers into the box 961 which may be held in position on the locator bars 954 to 958, inclusive, by an operator.

Wiring diagram

Referring to Figure 43-A, it will be observed that the lead wires 118 and 119 have respective wires or conductors 1030 and 1031 connected thereto, the end of the wire 1030 remote from the lead wire 118 being connected to one end of the solenoid coil 724 (see Figures 17 and 18). The opposite end of the solenoid coil 724 has a wire 1032 connected thereto, the other end of which is connected to one side of the switch 732 (see Figure 2-A). The switch 732 is a normally opened switch, as heretofore stated, and has a wire 1033 connected to the side thereof remote from the side to which the wire 1032 is connected.

The end of the wire 1033 remote from the switch 732 is connected intermediate the ends of the wire 1031. Corresponding sides of the switches 730 and 731 are connected to opposite ends of a wire 1034. The side of the switch 730 opposite the side to which the wire 1034 is connected has one end of a wire 1034a connected thereto. The other end of the wire 1034a is connected to one side of the solenoid coil 187 in Figure 43. The side of the switch 731 opposite the side to which the wire 1034 is connected has a wire 1035 connected thereto whose end remote from the switch 731 is connected intermediate the ends of the wire 1031.

One end of a wire 1036 is connected intermediate the ends of the wire 1030, its other end being connected to one side of the switch 376 (see Figures 2 and 9). One end of a wire 1037 is connected to the other side of the switch 376. The other end of the wire 1037 is connected to one side of the solenoid coil 370. The other side of the solenoid coil 370 has one end of a wire 1040 connected thereto which extends from Figure 43-A to Figure 43 and is connected to one side of the normally open switch 991 (see Figures 2-C, 6-C and 29). The end of the wire 1031

remote from the wire 119 is connected intermediate the ends of the wire 1043. The other side of the switch 991 has a wire 1041 connected thereto, the other end of which is connected to one side of the solenoid coil 992. The side of the solenoid coil 992 remote from the wire 1041 has one end of a wire 1042 connected thereto which extends from Figure 43 to Figure 43-A and is connected intermediate the ends of a wire 1043.

One end of the wire 1043 is connected intermediate the ends of a wire 1044 and the other end thereof is connected to one side of the normally open switch 847 (see Figure 21). The side of the switch 847 remote from the side to which the wire 1043 is connected has one end of a wire 1045 connected thereto which extends from Figure 43-A to Figure 43 and the opposite end of which is connected to one side of the normally open switch 846 (see Figures 4-B and 6-B). The normally open switch 846 has one end of a wire 1046 connected to the side thereof remote from the side to which the wire 1045 is connected. The end of the wire 1046 remote from the switch 846 is connected to one end of the solenoid coil 844 (see Figure 2-B). The opposite end of the solenoid coil 844 has a wire 1047 connected thereto which is connected at its other end intermediate the ends of the wire 1040 heretofore described.

Referring to Figure 43-A, one end of the wire 1044 is connected intermediate the ends of the wire 1030 and its other end (Figure 43) is connected to the opposite side of the solenoid coil 187 from that to which the wire 1034a is connected (see Figures 4-A and 34). A wire 1050 is connected at one end thereof intermediate the ends of the wire 1040. The other end of the wire 1050 is connected to one side of the normally closed switch 910 (see Figure 29). The side of the normally closed switch 910 remote from the side to which the wire 1050 is connected has one end of a wire 1051 connected thereto whose other end is connected to one side of the normally closed switch 938 (Figures 2-C and 29). The other side of the switch 938 has one end of a wire 1052 connected thereto which extends from Figure 43 to Figure 43-A and is connected to one side of the normally closed switch 810 (see Figures 4-A, 6-A and 18). The other side of the normally closed switch 810 has one end of a wire 1053 connected thereto whose other end is connected to one side of a solenoid coil 1054 of the magnetic or solenoid switch 116. The other side of the coil 1054 is connected to wire 116a by a wire 1055.

Brief summary of method of operation

Assuming the master switch 120 and switches 810, 910 and 938 to be closed, the electric motor 117 is then energized and remains energized throughout the operation of the machine so the gear 151 associated with the clutch mechanism shown in Figures 6-A, 6-B, 35, 36 and 37 will rotate continuously and so the upper and lower carrier blank feed rolls 441 and 442 will rotate continuously in opposite direction by the means heretofore described.

Now, in order for the machine to operate, it is necessary that a sufficient number of cylindrical articles C are placed in the chute 564 and that a sufficient number of carriers in blank form are positioned in the magazine M. As heretofore stated, upon the uppermost of the carriers in blank form in the magazine being disposed at

such a low elevation as to not be properly grasped by the vacuum controlled grasping devices 395 (Figures 3 and 8), the adjustment screw 450 on the angle clip 451 on the corresponding carrier feed guide bar 386 (Figures 2, 9 and 43-A) engages the spring loaded plunger of the normally opened switch 376 to close the same whereupon current flows from the lead wire 118, through the wires 1030 and 1036, to the switch 376, through the wire 1037, through the solenoid coil 370 (Figures 2, 3, 9 and 43-A) and through the wires 1040 and 1031 to the lead wire 119 thus energizing the solenoid coil 370 to move the latch member 352 out of engagement with the projection 351 on the lower end of the pawl take-up lever 334. Since the solenoid coil 187 (Figure 43) is normally energized, in the manner to be presently described, the clutch dog 162 (Figures 36 and 37) will be in engagement with one of the notches or cavities 151 in the clutch disc 157 to cause the gear 151 to impart rotation to the main cam shaft 152, and this will cause oscillation of the pawl take-up member 334 to elevate the carriers in blank form, in the manner heretofore described, until the adjustment screw 450 moves out of engagement with the plunger of the switch 376.

The solenoid coil 187 is normally energized as current flows from the lead wire 118 (Figure 43-A), through the wires 1030 and 1044, through the solenoid coil 187, through the wire 1034a, through the normally open switch 730, through the wire 1034, through the normally open switch 731, which switches 730 and 731 will then be closed by the articles C (Figures 6-A and 43-A), through the wires 1035 and 1031 to the lead wire 119.

Now, assuming there to be a sufficient number of carrier blanks in the magazine M, the suction cups 400, associated with the vacuum controlled grasping devices 395 (Figures 3 and 8), move downwardly and then upwardly and forwardly in the manner heretofore described, and transfer the uppermost of the carrier blanks into engagement with the feed rolls 441 and 442 (Figures 2, 3, 4, 8 and 9). As heretofore stated, the conveyor chain 224 of the conveyor 205 moves in a step-by-step manner as rotation is imparted to the main cam shaft 152 and, as the carrier is fed forwardly by the feed rolls 441 and 442, the jaws 267 and 268 (Figures 40 and 41) of the corresponding carrier clamping device 264 on the conveyor 205 are opened by the means shown in Figure 8, in the manner heretofore described, whereupon the leading edge of the carrier blank is directed into position between the jaws of the grasping device 264 and is located accurately by means of the goose-neck member 492 and 493 (Figures 6, 8, 9 and 11). The carrier blank is also positioned properly in alignment with the conveyor 205 by the carrier blank locator 506 (Figures 4, 6 and 11).

A second step is imparted to the conveyor 205, since the movement of the carrier blank into position between the jaws of the grasping device 264 is considered a first step, and upon cessation of this second step in movement by the carrier, the flaps B-2 and B-3 of the carrier B are formed in a substantially vertical position in perpendicular relation to the horizontally disposed bottom wall B-1 of the carrier B. This folding of the walls B-2 and B-3 of the carrier B is performed by the external folding bars 570 and 571 (Figures 2, 2-A, 4, 4-A and 14).

As the external folding bar 570 moves up-

wardly, the handle flap B-5 and the side flap B-2 are disposed in alinement with each other and the upper surface of the handle flap B-6 engages the outer surface of the external flap folding plate 609. The flap folding bar 601 then moves inwardly to the position shown in Figure 14, and, since the carrier is creased or scored at the juncture of the handle flap B-6 and the wall B-2, as is clearly set forth in said copending application, the inward movement of the external folding bar 601 causes the handle flap B-6 to project in substantially right-angular relation to the vertically disposed side wall or flap B-2 of the partially folded carrier B.

As heretofore stated, upon a sufficient number of cylindrical containers or articles C being positioned upon the article retaining tracks 652 and 653 (Figures 12, 13 and 16), the leading cylindrical article C engages the switch operating levers 735 causing the same to close the normally opened switches 730 and 731 (Figure 43-A). The carrier, which is then in channel-shaped form, is then moved another or third step in which the flaps B-2 and B-3 assume the positions shown in Figure 16 and, in so doing, the handle flap B-6 closes the coinciding openings 741 in the members 645 and 646.

After the conveyor 205 has ceased its movement in which a third step in movement is imparted to the carrier B, the switch 732 (Figure 2-A) is moved upwardly in the manner heretofore described, whereupon the normally opened switch 732 is closed by virtue of the follower 742 engaging the handle flap B-6 of the carrier B. Now, referring to Figure 43-A, it will be observed that upon the switch 732 being closed, electrical energy will flow from the lead wire 118, through the wire 1030, through the solenoid coil 724, through the wire 1032, through the switch 732 and through the wires 1033 and 1031 to the lead wire 119 to thus energize the solenoid coil 724.

As heretofore stated, it is evident that, upon the cylindrical articles being improperly positioned on the article retaining tracks 652 and 653, or there being an insufficient number of the articles C on the tracks 652 and 653, the switches 730 and 731 or either one of the same may not be closed. Also, upon failure of a carrier to be properly positioned for closing the coinciding openings 741 (Figure 6-A) in the members 645 and 646, the switch 732 would remain open although the switch 732 is raised by the arm 143a of the bell crank 743 in Figure 2-A.

Upon the solenoid coil 724 being energized, the locking pin 721 (Figure 17) moves out of engagement with the cavity 720 in the vertically disposed guide bar 697 to permit the same to be moved downwardly in the manner heretofore described. This also permits the arm 677 in Figure 16 to move downwardly, thereby moving the tracks 652 and 653 apart from each other to permit the row of articles C to move downwardly into the carrier B. The article locator bar 702 also moves downwardly at this time to insure that the corresponding group of cylindrical articles C is properly seated in the corresponding carrier B.

The gate 760 (Figure 13) also moves downwardly at this time to prevent additional cylindrical articles C from moving downwardly between the article guide plates 633 and 634 until the article locator bars 702 have returned to the raised position shown in Figure 16 and until the article retaining tracks 652 and 653 have again moved inwardly from the position shown in Fig-

ure 16 to the operative position shown in Figure 17.

It is evident that, as the leading cylindrical article C in Figure 12 moves downwardly to the position shown in Figure 13, the plungers of the switches 730 and 731, which are spring loaded in the usual manner of some switches, such as microswitches, cause the levers 735 to move in a clockwise direction from the position shown in Figure 12 to that shown in Figure 13 thus opening the switches 730 and 731 to deenergize the solenoid coil 187 (Figures 6-A, 17 and 43-A). However, the arm 164 of the clutch dog housing 163 is so positioned that the cam shaft 152 will continue to rotate until the locator bars 702 have returned to the elevated position shown in Figure 12. Ordinarily, by the time the arm 164 has moved into position adjacent the knife 171, the leading article C will have again closed the switches 730 and 731. The switch 732 then moves downwardly and, thus, as the vertically disposed guide bar 697 returns to the elevated position shown in Figures 4-A, 12 and 17, the compression spring 727 (Figure 17) causes the locking pin or plunger 721 to enter the cavity 720 in the vertically disposed guide bar 697 preparatory to a repeat operation of the article dispensing or transferring mechanism as described.

The carrier B is then advanced a fourth step 30 by the conveyor 205, in the course of which the substantially vertically disposed side flap B-3 and the corresponding top flap B-4 and the handle flap B-5, which are disposed in alinement with the side flap B-3 at this time (see Figures 14 and 16), are moved from the slightly angular position, relative to the vertical, shown in Figures 14 and 16 to a position more closely approaching the vertical by means of the flap guide member 776 (Figures 16 and 17) and also by means of the flap 35 retaining bar 635 and the carrier guide plate 780 (Figure 15).

Upon the filled carrier B having reached the end of its movement in the course of said fourth step, the laterally movable folding plate 782 (Figures 4-B, 6-A, 6-B, 13, 17 and 18) is moved transversely of and above the upper edges of the side walls 57 and 58 of the trackway 55, from the position shown in Figure 6-A to the position shown in Figures 6-B and 15. This inward movement of 45 the laterally movable folding plate 782 is caused by the tension spring 607 in Figure 18 as the cam follower 805 is engaged by the relatively low surface 174b (Figure 28) of the cam wheel 174 (Figures 18, 28 and 34).

Now, as heretofore stated, in the event of there being an obstruction in the path of the laterally movable folding plate 782 as it moves from the position shown in Figure 6-A to the position shown in Figure 6-B, such as one of the cylindrical articles C not being properly seated upon the bottom wall B-1 of the carrier B, the plunger of the normally closed switch 810 (Figures 6-A, 18 and 43-A) will engage the lower surface of the laterally movable slide or guide bar 781 in Figure 18, 50 due to the cam follower 817 in Figure 25 dropping into the notch 820a of the cam wheel 820. Upon the plunger of the switch 810 engaging the slide 781, the switch 810 will be opened and this will open the circuit to the solenoid coil 1054 associated with the switch 116 (Figures 6-B and 43-A).

Upon the switch 810 being opened, the coil 1054 is deenergized permitting the switch 116 to open to deenergize the electric motor 117, thus stopping the machine.

In order to remove an obstruction from the

path of the laterally movable folding plate 782, it would merely be necessary for the operator to grasp the crank arm 795a (Figure 18) and move the folding plate 782 outwardly. After removing the obstruction, the operator could release the arm 795a thereby permitting the plate 782 to move inwardly and to form the top flap B-4 in the substantially horizontal position shown in Figure 15. The carrier B is creased or scored at the juncture of the top flap B-4 and side wall B-3, as is clearly disclosed in said co-pending applications, to insure that the flap or top wall B-4 will be folded evenly so the carrier encompasses the cylindrical articles C therein. Of course, as the slide 787 is permitted to move inwardly, it moves out of engagement with the plunger of the switch 810, permitting the switch 810 to close and again energizing the electric motor 117 to permit the main cam shaft 152 to continue its rotation.

The filled carrier B is then moved a fifth step by the conveyor 205, in the course of which the filled carrier closes the normally opened switch 846 (Figures 6-A and 43). After the filled carrier has been advanced a fifth step and the conveyor 205 has ceased its movement, the cam member 850 (Figures 21 and 43-A) closes the switch 847, whereupon the circuit is completed to the solenoid coil 844 in the housing 845 (Figures 2-B and 43). Current then flows from the lead wire 118 (Figure 43-A), through the wires 1030, 1044 and 1043, through the switch 847, through the wire 1045, through switch 846 (Figure 43), through the wire 1046, through the solenoid coil 844, through the wires 1047, 1040 and 1031 (Figures 43 and 43-A) to the lead wire 119.

It will be noted that the cam member 850 closes the switch 847 only momentarily since it is necessary to complete the circuit to the solenoid coil 844 only momentarily. Upon the circuit being completed to the solenoid coil 844, the solenoid plunger 843 is caused to move downwardly in Figure 2-B to actuate the conventional means, not shown, associated with the stitching device 825 (Figures 2-B and 4-B) which, in this instance, will staple the handle flaps B-5 and B-6 together adjacent their junctures with the corresponding walls B-4 and B-2 of the carrier B.

After the handle flaps B-5 and B-6 have been stitched together, the conveyor 205 advances the carrier a sixth step in the course of which the uppermost handle flap B-5 passes beneath the spirally bent handle flap folding bar 857 (Figures 2-B and 6-B) to hold the handle flaps B-5 and B-6 downwardly to where the handle flap B-6 is pressed against the outer surface of the side wall B-2 of the filled carrier B, these handle flaps B-5 and B-6 being suitably scored to facilitate the folding of the same against the vertically disposed side wall B-2 of the filled carrier B.

The conveyor 205 then ceases its movement momentarily, after which the filled carrier is advanced its seventh step to where the outer surface of the side wall B-3 of the filled carrier B is disposed adjacent or against the transfer plate 885 (Figures 29 and 30). The transfer plate 885 is then moved from right to left in Figure 29 or towards the observer in Figure 30 by means of the tension spring 906 and because of the low surface 905a of the cam wheel 905 (Figure 39) moving into engagement with the cam follower 904.

Now, as heretofore stated, in the event of there being an obstruction in the path of the filled carrier B, the movement from right to left of the

transfer plate 885 in Figure 29 may be limited, and consequently, the plunger of the normally closed switch 910 will engage the lower surface of the guide bar 891 because of the low surface 917b of the cam wheel 917 (Figure 31) moving into engagement with the cam follower 916.

Since the switch 910 is interposed in the circuit to the solenoid coil 1054, this will cause de-energization of the electric motor 117 to thus stop the machine. However, in the absence of an obstruction being disposed in the path of both the transfer plate 885 and the filled carrier B, the transfer plate 885 will move from the position shown in Figure 30 to that shown in Figure 29 to transfer the corresponding carrier B onto the elevator or stacking plate 886.

The filled carrier stacking plate 886 is then moved upwardly by means heretofore described (Figures 2-C, 29 and 30) and, in the course of which, the side walls of the carrier B will engage the angular proximate surfaces of the filler carrier retaining bars 942 and 943 and then move past the same, after which the filled carrier retaining bars 942 and 943 will again move inwardly to the position shown in Figure 29 to support the corresponding filled carrier.

Now, in the event that the filled carrier B is not properly positioned upon the elevator or stacking plate 886 or there is some obstruction in the path of the upward movement of either the carrier or the elevator plate 886, the connecting rod 933 will override the pivot pin 932 in the manner heretofore described, thereby permitting the switch 938, which is normally held in a closed position by the plate 934, to be opened, whereupon the circuit to the solenoid coil 1054 will again be broken (Figure 43-A) to stop the machine.

It is to be understood that as a particular carrier is advanced through each of said steps, succeeding carriers are disposed in all of the positions previously successively occupied by the carrier B as it moves through the previous steps. In other words, all of the various instrumentalities associated with each of the steps through which the carrier passes operates simultaneously. Therefore, as each carrier is moved upwardly to be positioned upon the filled carrier retaining bars 942 and 943 in Figure 29, the transfer bar or plate 885 moves outwardly, whereupon another step in movement is imparted to the conveyor 205 to position a succeeding filled carrier in alignment therewith for transferring the same onto the elevator or stacking plate 886.

The succeeding carriers are then moved upwardly, one at a time, in the manner heretofore described, whereupon the upper wall thereof, which is the horizontally disposed top wall B-4, engages the lower surface of the preceding filled carrier to move the same upwardly therewith. These carriers move upwardly between the guide plates 944 and 945 in the manner heretofore described and upon their being a predetermined number of carriers positioned between these plates 944 and 945, there being five carriers in this instance, the uppermost carrier engages the follower 987 (Figure 29) and closes the switch 991.

It will be observed in Figures 43 and 43-A that current then flows from the lead wire 118 through the wires 1044, 1043, and 1042, through the solenoid coil 992, through the wire 1041, through the switch 991, through the wires 1040 and 1031 to the lead wire 119, thus completing the circuit to the solenoid coil 992. As heretofore stated, upon energization of the coil 992, the locking pin 995

(Figure 29) is caused to move upwardly out of engagement with the cavity 1005 in the guide bar 996.

The lower surface 1022a (Figure 38) of the cam wheel 1022 will have moved into the vertical plane of the cam follower 1021, thus placing the guide bar 996 under tension of the tension springs 1012 (Figure 29) and, therefore, as the plunger or locking pin 995 is moved upwardly, the transfer plate 1002 will move from right to left in Figure 29 through the opening 947 to move the corresponding stack of filled carriers B through the opening 946 in the stacking guide plate 944 and into the box or carton 961. This carton or box 961 will have previously been positioned in alignment with the opening 946 in the manner heretofore described.

Of course, as the carriers disposed in the same horizontal plane as the stack transfer member or plate 1002 are moved through the opening 946 into the box or carton 961, the lowermost filled carrier remains resting upon the filled carrier retaining bars 942 and 943 as the carriers thereabove are moved into the carton or box 961. Also, the follower 987 is permitted to move downwardly in Figure 29 thus opening the switch 981 and de-energizing the solenoid 992.

As the guide bar 996 returns to the position shown in Figure 29, the locking pin 995 then falls into the opening or cavity 1005 in the bar 996 to again lock the same in position preparatory to a repeat operation in the manner heretofore described. The filled carrier transfer plate 885, the elevator or stacking plate 886 and the stack transfer member 1002 operate in rapid succession, during the course of which the filled carrier transfer plate 885 returns to the position shown in Figure 30 prior to the next succeeding step in movement being imparted to the conveyor 205, thus permitting the conveyor to continue its step-by-step movement at uniform intervals.

It is evident that the stack transfer plate 1002 will operate only upon a predetermined number of steps being imparted to the conveyor 205 and, consequently, although the low surface 1022a of the cam wheel 1022 (Figure 38) moves into the vertical plane of the cam follower 1021 as each step is imparted to the conveyor 205, the locking pin 995 (Figure 29) will prevent the stack transfer plate 1002 from moving until a predetermined number of the filled carriers have been stacked between the stacking guide plates 944 and 945. In this instance, there is sufficient space between the upper surfaces of the filled carrier retaining bars 942 and 943 and the lower surfaces of the stop bars 936 to accommodate five superposed filled carriers and the four uppermost filled carriers are transferred into the carton or box 961 by the stack transfer plate 1002.

The facilitation of stacking this number of filled carriers in the carton or box 961 is desirable because this particular machine is designed to position six cylindrical articles in each of the carriers thus providing twenty-four cylindrical articles C in each box or carton 961, this being the usual number of cylindrical articles to a case of articles, such as cans of beer and other commodities as vended in commercial establishments.

It is evident, however, that the machine may be readily adapted to facilitate the placing of any desired number of cylindrical articles or similarly-shaped articles in a carrier and for stacking any predetermined number of carriers and inserting the same in a box or carton.

We claim:

1. A machine for forming a carrier from a flat substantially rectangular blank and for placing articles in said carrier comprising means for directing articles into the machine to a predetermined position, means for successively conveying the carriers in blank form into the machine one at a time, means for folding spaced portions of each successive carrier to form upwardly extending first and second flaps on the carrier and wherein the first flap is relatively shorter than the second flap, an article dispensing station disposed forwardly of the means for folding spaced portions of the carriers, said article dispensing station including means for supporting groups of articles in a row, means for successively positioning the carriers beneath corresponding groups of the articles, means for lowering a predetermined number of said articles defining each of said groups into the corresponding carrier, means for maintaining the first and second flaps in a substantially vertical position as the articles are lowered therebetween, means for advancing the successive carriers beyond the point at which the articles are lowered thereinto, means for folding a portion of the second flap across the upper surfaces of the articles previously lowered into the carrier to form the carrier in the shape of a substantially rectangular tube, means for fastening the last-named portion of the second flap to the upper portion of the first flap, said means for advancing the carrier also being operable to advance the carrier beyond the means for fastening said flaps together, means for stacking the successive filled carriers in superposed relation to each other, means operable automatically upon a predetermined number of filled carriers being stacked for moving said predetermined number of filled carriers to one side of their normal path of travel, whereby a box may be positioned to one side of the path of travel of the filled carriers and the filled carriers may be moved into said box.

2. Apparatus for forming carriers from carrier blanks in sheet form and packaging articles therein comprising a magazine for containing a supply of carriers in blank form, an intermittently driven conveyor positioned adjacent the magazine, means operable automatically in timed relation to movement of said conveyor for successively feeding the carriers in blank form to the conveyor as the conveyor is advanced a first step, means operable automatically upon said conveyor being advanced a second step for folding the opposite side portions of the carrier so they extend upwardly to shape the carrier in substantially the form of a flat-bottomed channel, means for containing a supply of cylindrical articles, means operable automatically upon a third step being imparted to said conveyor for positioning a predetermined number of articles in the carrier in its channel-shaped form, means for folding a portion of said carrier over the articles in said carrier as a fourth step is imparted to said conveyor, means operable automatically for fastening the portion of the carrier disposed above the articles to the portion of the carrier disposed at the opposite side of the articles to that whence the portion positioned above the articles extends as a fifth step is imparted to said conveyor, means operable automatically upon a step being imparted to the conveyor subsequent to the step at which the portions of the carrier are fastened for moving the corresponding carrier off of the conveyor, means for stacking successive carriers in superposed position as they are moved away from said conveyor

successively, means for supporting an open-ended box or the like adjacent the means for stacking successive carriers and means operable automatically upon a predetermined number of carriers being stacked for transferring the carriers from the position in which they were stacked into the box thereby providing a box of juxtaposed carriers filled with the articles.

3. A machine for forming carriers from flat substantially rectangular blanks and placing articles in the carriers as they are formed comprising means for conveying the carriers in blank form into the machine, an article dispensing station, means for feeding the articles to the article dispensing station in the form of a row of articles, means in advance of the article dispensing station for folding each successive carrier in blank form into the form of a channel having first and second flaps and wherein the first flap is of substantially less height than the second flap, means for positioning the carrier in channel-shaped form beneath the article dispensing station, means for dispensing a predetermined number of the articles disposed at the end of said row into said carrier in channel-shaped form, means for folding an upper portion of said second flap across the upper surfaces of the articles previously positioned in said carrier to form a substantially tubular member being substantially rectangular in cross-section, means operable automatically to secure the corresponding portion of the second flap to the upper edge of the first flap, means for elevating each successive filled carrier beneath each preceding filled carrier to form a stack of filled carriers, at least one stacking guide plate past which the carriers move as they are elevated in forming said stack, said stacking guide plate having an opening therein in communication with which the open end of an open-ended box may be positioned by an operator, and means operable automatically upon a predetermined number of the filled carriers being stacked for moving a predetermined number of the carriers through the opening in said stacking guide plate and into the box.

4. A machine for forming carriers from flat substantially rectangular blanks and placing articles in the carriers as they are formed comprising means for conveying the carriers in blank form into the machine, an article dispensing station, means for feeding the articles to the article dispensing station in the form of a row of articles, means in advance of the article dispensing station for folding each successive carrier in blank form into the form of a channel having first and second flaps and wherein the first flap portion is of substantially less height than the second flap, means for folding the upper portion of the first flap to form a handle flap portion projecting outwardly therefrom, means for positioning the carrier in channel-shaped form beneath the article dispensing station, means for dispensing a predetermined number of the articles disposed at the end of said row into said carrier in channel-shaped form, means for folding an upper portion of said second flap across the upper surfaces of the articles previously positioned in said carrier so the end of said upper portion of said first flap remote from the fold thereof defines another handle flap disposed in overlapping relation to the handle flap on the first flap to form a substantially tubular member being substantially rectangular in cross-section, means operable automatically to secure the handle flap on the first flap to the handle flap on the second flap, means to fold the handle flaps

in parallel relation to the lower portion of the first flap with the handle flaps against the lower portion of the first flap, means for elevating each successive filled carrier beneath each preceding filled carrier to form a stack of filled carriers, at least one stacking guide plate past which the carriers move as they are elevated in forming said stack, said stacking guide plate having an opening therein in communication with which the open end of an open-ended box may be positioned by an operator, and means operable automatically upon a predetermined number of the filled carriers being stacked for moving a predetermined number of the carriers through the opening in said stacking guide plate and into the box.

5. Apparatus for forming carriers from flat substantially rectangular sheets of paperboard and the like while filling each carrier with a row of cylindrical articles comprising a magazine for supporting a stack of superposed substantially rectangular sheets therein, an intermittently driven conveyor disposed forwardly of said magazine, means for successively feeding the rectangular sheets, one at a time, onto the conveyor upon a first step being imparted to the conveyor, a first folding means disposed adjacent the conveyor forwardly of the point at which the successive sheets are fed to the conveyor and being operable upon a second step being imparted to the conveyor for folding opposite side portions of the corresponding sheet upwardly to form a substantially channel-shaped carrier, article retaining tracks disposed above the conveyor forwardly of said first folding means, means for directing a row of cylindrical articles onto the article retaining tracks, means operable automatically upon a third step being imparted to the conveyor for moving the article retaining tracks away from the articles disposed thereon to permit the articles to fall into the substantially channel-shaped carrier, a second folding means disposed forwardly of the article retaining tracks, means operable automatically upon a fourth step being imparted to the conveyor for folding at least one of said previously formed side portions of the carrier horizontally across the upper surfaces of the articles positioned therein to form a substantially rectangular tube, stitching means operable automatically upon a fifth step being imparted to the conveyor for stitching the horizontal portion of the last-named side portion to the upper portion of the other of the side portions, a horizontally disposed stacking plate disposed to one side of the conveyor and normally being disposed in substantially the same horizontal plane as the conveyor, means operable automatically upon a subsequent step being imparted to the conveyor for moving each successive filled carrier onto the stacking plate, means operable automatically in timed relation to the movement of each successive filled carrier onto the stacking plate for elevating and lowering the stacking plate, filled carrier retaining means disposed above the stacking plate for retaining each successive carrier elevated by the stacking plate as said stacking plate returns to its normal position in the horizontal plane of the conveyor, a stack transfer member normally disposed to one side of and above the horizontal plane of the filled carrier retaining means, and means operable automatically in response to a predetermined number of filled carriers being stacked upon the filled carrier retaining means for moving at least some of the filled carriers off of the filled carrier retaining means simultaneously whereby an open-ended box may be positioned in alignment with

the means for moving the filled carriers off of the filled carrier retaining means and the filled carriers may be ejected into the box.

6. Apparatus for forming carriers from flat substantially rectangular blanks and packaging cylindrical articles therein comprising a magazine for containing a stack of superposed blanks, an article dispensing station, a stitching station and a filled carrier stacking station arranged seriatim, said article dispensing station having an inclined chute for directing a row of articles thereto by gravity, means for successively advancing the blanks to the article dispensing station beneath one end of the row of articles directed to the article dispensing station, first folding means disposed between the magazine and the article dispensing station, said first folding means including means for folding opposite side portions of each successive blank upwardly to form first and second side walls and wherein the second side wall is of substantially greater vertical length than the first side wall, said first folding means also including means for folding the first side wall intermediate the upper and lower edges thereof to form an outwardly projecting handle flap thereon, means operable automatically for feeding a predetermined number of articles from the article dispensing station downwardly between the first and second side walls of the carrier upon the carrier being advanced to a position beneath the article dispensing station, means for advancing each successive carrier to the stitching station, a second folding means disposed between the article dispensing station and the stitching station for folding the second wall at a point intermediate its upper and lower edges to form a flap extending across the upper surfaces of the articles in the carrier and thereby forming each successive carrier in the shape of a substantially rectangular tube, the second folding means being so positioned relative to the first folding means to form the overlying portion of the second wall so it overlaps the handle flap formed on the first wall, said stitching station being operable automatically upon each corresponding carrier being advanced thereto for stitching the handle flap projecting from the first wall to the overlapping portion of the second wall, means for advancing each successive carrier from the stitching station to the stacking station, a third folding means disposed between the stitching station and the stacking station and having means for engaging and folding the handle flap and the corresponding overlapping portion of the second wall against the outer surface of the first wall, said stacking station including a vertically movable stacking plate disposed to one side of the normal path of movement of the carrier, means operable automatically upon each successive carrier being advanced to the stacking station for transferring the carriers to one side of their normal path of travel and onto the stacking plate, means operable automatically upon each successive carrier being positioned upon the stacking plate for elevating and then lowering the stacking plate, carrier retaining means disposed above the stacking plate and comprising at least one resiliently mounted filled carrier retaining bar, means engageable by each successive carrier as it is elevated by the stacking plate for moving the filled carrier retaining bar outwardly and whereupon the stack retaining bar will move into position beneath the corresponding carrier upon the carrier being moved upwardly beyond the filled carrier retaining bar, a stack transfer member disposed to one side of and above

the stack retaining bar, and means operable automatically upon a predetermined number of filled carriers being moved upwardly past the filled carrier retaining bar for imparting movement to

- 5 the stack transfer member transversely of the vertical path of movement of the filled carriers whereby an open-ended container may be positioned adjacent the stack of carriers and the stack transfer member will move the stack of carriers into the open-ended container.
7. A machine for packaging individual rows of articles in carriers and arranging the carriers in a stack and packaging stacks of carriers in a container comprising a driven horizontal conveyor, 15 means for feeding flat substantially rectangular carrier blanks to the conveyor in timed relation to movement of the conveyor, an article dispensing station disposed above the path of travel of the conveyor and comprising a pair of longitudinally extending transversely spaced article retaining tracks, means for guiding a row of articles onto the article retaining tracks, a first folding means disposed in advance of the article dispensing station for folding each successive carrier 20 blank to form a carrier having first and second spaced side walls extending upwardly from opposite edges of a bottom wall, said first folding means being so positioned relative to the feeding means as to form the first wall of substantially 25 less height than the second wall, said first folding means also including means for forming a handle flap projecting outwardly from the upper edge of the first wall, means operable automatically upon each successive carrier being advanced 30 on the conveyor to a position below the article retaining tracks for imparting relative outward movement to the article retaining tracks to permit a predetermined number of articles to move 35 downwardly by gravity between the first and second walls and onto the bottom of said carrier, a second folding means disposed forwardly of the article dispensing station for folding the second wall intermediate its upper and lower edges to form an upper flap extending across the upper 40 surfaces of the articles previously positioned in the carrier and also overlapping the outwardly projecting handle flap of the first wall as the conveyor advances the corresponding carrier forwardly beyond the article dispensing station, 45 means for stitching the overlapping portion of the second wall to the handle flap on the first wall upon the conveyor advancing each successive carrier beyond the second folding means, third folding means disposed forwardly of the means 50 for stitching the overlapping portion of the second wall to the handle flap of the first wall for folding the handle flap of the first wall and the corresponding overlapping portion of the second wall against the outer surface of the first wall to 55 form a handle flap from the portion of the second wall which overlaps the handle flap of the first wall, a stacking station disposed forwardly of the third folding means and comprising a vertically reciprocable stacking plate normally positioned in 60 substantially the same horizontal plane as the upper surface of the conveyor, means operable automatically upon each successive carrier being advanced to a position in alignment with the stacking plate for moving each successive carrier 65 off of the conveyor and onto the stacking plate, means operable in timed relation to the movement of each successive carrier onto the stacking plate for elevating and then lowering the stacking plate, means for retaining each successive carrier 70 off of the conveyor and onto the stacking plate, means operable automatically upon each successive carrier being advanced to a position in alignment with the stacking plate for moving each successive carrier 75 off of the conveyor and onto the stacking plate, means operable in timed relation to the movement of each successive carrier onto the stacking plate for elevating and then lowering the stacking plate, means for retaining each successive carrier elevated by the stacking plate in a predetermined

position spaced above the normal lowered position of the stacking plate whereby each successive carrier elevated by the stacking plate will engage the carrier disposed thereabove to elevate the same, and stack transfer means operable automatically upon a predetermined number of articles being stacked above the stacking plate for transferring the stack of carriers to one side of the vertical plane of the stacking plate, whereby a container may be positioned opposite the stack transfer means for receiving the stack of filled carriers transferred by the stack transfer means.

8. In a structure according to claim 7, said first folding means comprising a stationary folding die closely spaced above the path of travel of the conveyor and having spaced parallel opposite side edges, a pair of vertically movable horizontally disposed flap folding bars normally disposed below the horizontal plane of the upper surface of the conveyor and adjacent opposite sides of the conveyor, means operable automatically upon each successive blank being advanced to a position beneath the folding die for moving said folding bars upwardly at least partially past and adjacent opposite sides of the folding die to fold the blank in the form of the substantially channel-shaped carrier having first and second spaced side walls.

9. In a structure according to claim 8, said folding die having an outwardly extending lateral flap folding plate thereon projecting outwardly beyond one of its side edges, a laterally movable flap folding bar spaced immediately below the lateral flap folding plate, and means operable automatically upon said external flap folding bars moving upwardly and forming the side walls of the channel-shaped carrier for moving said flap folding bar inwardly beneath the lateral flap folding plate to thereby fold the corresponding side wall of the carrier intermediate its upper and lower edges to form the handle flap projecting from the upper edge of the first side wall of the carrier.

10. A machine for packaging individual rows of articles in carriers while forming said carriers from relatively thin flat substantially rectangular blanks and for stacking said carriers in superposed relation comprising a driven horizontally disposed conveyor, a magazine for containing a supply of said blanks, means for successively feeding the blanks from the magazine to the conveyor, one at a time, in timed relation to movement of the conveyor, means disposed forwardly of the magazine for forming each successive blank in the shape of a substantially channel-shaped carrier having spaced first and second side walls and wherein the second side wall is of substantially greater height than the first side wall, an article dispensing station disposed forwardly of the means for forming each successive blank in the shape of a substantially channel-shaped carrier, said article dispensing station comprising means for supporting a row of articles thereon at a point spaced above the conveyor, means operable automatically upon each successive carrier in channel-shaped form moving to a position beneath the means for supporting the row of articles for directing a predetermined number of articles in said row downwardly between the first and second side walls of the carrier, means for folding each successive carrier in the form of a substantially rectangular tube at a point forwardly of the article dispensing station upon forward movement of the conveyor, a carrier stacking station disposed forwardly of the means for forming each successive carrier in the shape of a substantially rectangular tube and comprising

a stacking plate disposed to one side of the conveyor and normally being disposed in substantially the same horizontal plane as the conveyor, means operable automatically upon each successive carrier being advanced to the carrier stacking station for moving the same off of the conveyor and onto the stacking plate, means operable automatically upon each carrier being positioned upon the stacking plate for moving the stacking plate upwardly and then returning the same to its normal position, means for retaining each successive carrier in the position to which it is raised by the stacking plate to thereby form a stack of superposed carriers spaced above the normal position of the stacking plate, a vertically disposed stacking guide plate having an opening therein past which the carriers move as they are stacked by the stacking plate, means for supporting an open-ended container in alignment with the opening in said stacking guide plate, and means operable automatically upon a predetermined number of carriers being stacked by the stacking plate for moving the stack of carriers through the opening in the stacking guide plate and thus into the container.

11. In a structure according to claim 10, said magazine comprising a magazine base plate for supporting a stack of blanks, at least one set of driven upper and lower feed rolls disposed forwardly of and above the magazine base plate, a horizontal carrier feed plate having its rear edge disposed adjacent the feed rolls and having its front edge disposed adjacent the conveyor, a carrier feed grasping device disposed above the blanks, means operable automatically in timed relation to movement of the conveyor for actuating the grasping device to move the same forwardly and upwardly and to then return the carrier feed grasping device to its original position, said grasping device having means thereon for grasping the uppermost blank in said stack and elevating the same as it is moved forwardly into engagement with the feed rolls to subsequently be fed by the feed rolls onto the carrier feed plate and thus onto the conveyor, and means operable automatically for raising the magazine base plate upon the uppermost blank thereon being spaced a predetermined distance from the carrier feed grasping device to thereby position the uppermost blank in the magazine at an elevation to be properly engaged by the carrier feed grasping device.

12. In a structure according to claim 11, said conveyor being endless, a plurality of equally spaced carrier clamping devices mounted on said conveyor, said carrier clamping devices each comprising an inner jaw and an outer jaw, resilient means normally urging the jaws on each of the clamping devices to closed position with respect to each other, means operable automatically upon each successive carrier clamping device being positioned adjacent the front edge of the carrier feed plate for successively opening and closing the jaws of the carrier clamping devices to thereby permit the leading edge of each successive carrier to be clamped between the jaws of the corresponding carrier clamping devices to thereby insure that each successive carrier is maintained in position relative to the conveyor with movement of the conveyor.

13. A machine for packaging cylindrical articles in carriers while forming said carriers from flat substantially rectangular blanks comprising an intermittently driven horizontal conveyor, a magazine disposed rearwardly of said conveyor

for containing a supply of blanks, means operable automatically in timed relation to the intermittent movement of said conveyor for successively feeding blanks from the magazine, one at a time, to the conveyor, an article dispensing station spaced forwardly from the magazine, means between the article dispensing station and the magazine for forming each successive blank as a carrier substantially in the shape of an open-ended channel having a bottom wall and spaced side walls, said article dispensing station comprising means for positioning a row of articles, including a predetermined number of said articles, in each successive carrier in timed relation to movement of said conveyor, means for forming each successive carrier substantially in the shape of an open-ended substantially rectangular tube with the row of articles therein, means operable automatically for securing opposite edges of the carrier together to maintain them in said tubular shape, means operable automatically for stacking the carriers in superposed relation, means for supporting a box having one end open adjacent the point at which the carriers are stacked, and means operable automatically upon a predetermined number of carriers being stacked for transferring the stack of carriers into said box.

14. In a structure according to claim 13, said article dispensing station also comprising a pair of vertically disposed transversely spaced article guide plates astride which the side walls of the carrier are positioned upon each successive carrier being advanced to the article dispensing station, an inclined chute having top and bottom walls and spaced side walls, the lower ends of the top and bottom walls terminating adjacent the rear portions of the article guide plates, each of said article guide plates having a longitudinally extending opening therein, an article retaining track disposed in each of said openings and normally projecting therethrough inwardly of the vertical plane of the corresponding article guide plate, said tracks being disposed in substantially the same horizontal plane as the lowermost end of the bottom wall of the chute, whereby the articles may be placed in the chute and will move downwardly along the chute, by gravity, and then onto the article retaining tracks to form a row of articles supported by said article retaining tracks, at least one vertically movable article locator bar normally spaced in a horizontal plane substantially above the article retaining tracks and being disposed in a vertical plane between the article retaining tracks, means operable automatically upon each successive carrier being properly positioned in the article dispensing station for simultaneously moving the article retaining tracks apart from each other and moving the article locator bar downwardly to permit the row of articles previously supported by the article retaining tracks to move downwardly onto the bottom wall of the carrier and to be properly located thereon by the locator bar, a gate normally positioned adjacent the open lower end of the inclined chute, means operable automatically upon said article retaining tracks moving outwardly apart from each other for moving the gate into the path of the articles in the chute to thereby prevent the articles from moving between the article guide plates while the articles previously positioned on the article retaining tracks are being positioned on the lower wall of the carrier, and means operable automatically upon said article

retaining tracks and the article locator bar returning to their original position for moving said gate away from the open lower end of the chute to permit articles in the chute to move onto said article retaining tracks for a repeat operation.

15. In a structure according to claim 14, said conveyor comprising an endless belt having a plurality of equally spaced carrier clamping devices thereon, each comprising an inner jaw and an outer jaw, spring means normally urging the jaws to closed position with respect to each other, means operable automatically in timed relation to movement of said conveyor for momentarily opening the jaws upon each blank being fed to the conveyor and then closing the same so the leading edge of each successive blank is clamped between said jaws, the outer jaw associated with each of said clamping devices having at least one retaining projection thereon for limiting movement of the articles positioned upon the bottom wall of the corresponding carrier at the article depositing station, and said conveyor also having a plurality of equally spaced article retaining members thereon each being spaced a predetermined distance from a corresponding clamping device for also retaining the articles on the bottom wall of the carrier as the articles are deposited between the article retaining member and the article retaining projection on the corresponding clamping device, to thereby insure that the articles and the corresponding carrier are advanced in unison by the conveyor.

16. In a structure according to claim 14, means preventing said article retaining tracks from moving apart from each other as a corresponding carrier is positioned therebeneath in the event of there being less than a predetermined number of articles positioned on the article retaining tracks.

17. In a structure according to claim 14, means preventing the article retaining tracks from moving apart from each other in the event of the foremost article in a row directed to the tracks from the chute being disposed in a skewed position relative to the direction of travel of the conveyor.

18. A machine for packaging cylindrical articles in carriers while forming said carriers from flat substantially rectangular blanks comprising an intermittently driven horizontal conveyor, a magazine disposed rearwardly of said conveyor for containing a supply of blanks, means operable automatically in timed relation to the intermittent movement of said conveyor for successively feeding blanks from the magazine, one at a time, onto the conveyor, an article dispensing station spaced forwardly from the magazine, means between the article dispensing station and the magazine for forming each successive blank as a carrier substantially in the shape of an open-ended channel having a bottom wall and spaced side walls as each blank is advanced by the conveyor, said article dispensing station comprising a pair of vertically disposed transversely spaced article guide plates astride which the side walls of the carrier are positioned upon each successive carrier being advanced to the article dispensing station by the conveyor, an inclined chute having top and bottom walls and spaced side walls, the lower ends of the top and bottom walls terminating adjacent the rear portions of the article guide plates, each of said article guide plates having a longitudinally extending opening therein, an article retaining track disposed in each of said

71

openings and normally projecting therethrough inwardly of the vertical plane of the corresponding article guide plate, said tracks being disposed in substantially the same horizontal plane as the lowermost end of the bottom wall of the chute, whereby the articles may be placed in the chute and will move downwardly along the chute, by gravity, and then onto the article retaining tracks to form a row of articles supported by said article retaining tracks, at least one vertically movable article locator bar normally spaced in a horizontal plane substantially above the article retaining tracks and being disposed in a vertical plane between the article retaining tracks, means operable automatically upon cessation of each step in movement by the conveyor for simultaneously moving the article retaining tracks apart from each other and moving the article locator bar downwardly to permit the row of articles previously supported by the article retaining tracks to move downwardly onto the bottom wall of the corresponding carrier and to be properly located thereon by the locator bar, a gate normally positioned adjacent the open lower end of the inclined chute, means operable automatically upon said article retaining tracks moving outwardly apart from each other for moving the gate into the path of the articles in the chute to thereby prevent the articles from moving between the article guide plates while the articles previously positioned on the article retaining tracks are positioned on the lower wall of the carrier, means operable automatically upon said article retaining tracks and the article locator bar returning to their original position for moving said gate away from the open lower end of the chute to permit the articles in the chute to move onto said article retaining tracks for a repeat operation, means for forming each successive carrier substantially in the shape of an open-ended substantially rectangular tube with the row of articles therein, means operable automatically for securing opposite edges of the carrier together to maintain said tubular shape, means operable automatically for stacking the carriers in superposed relation, means for supporting a box having one end open adjacent the point at which the carriers are stacked, and means operable automatically upon a predetermined number of carriers being stacked for transferring the stack of carriers into said box.

19. In a structure according to claim 18, means operable automatically upon the absence of a carrier on that portion of the conveyor disposed beneath the article retaining tracks upon cessation of a step in movement by the conveyor to prevent the article retaining tracks from moving outwardly and for preventing the article locator bar from moving downwardly.

20. A machine for packaging cylindrical articles in carriers while forming said carriers from flat substantially rectangular blanks comprising an intermittently driven horizontal conveyor, a magazine disposed rearwardly of said conveyor for containing a supply of blanks, means operable automatically in timed relation to the intermittent movement of said conveyor for successively feeding blanks from the magazine, one at a time, to the conveyor, an article dispensing station spaced forwardly from the magazine, means between the article dispensing station and the magazine for forming each successive blank as a carrier substantially in the shape of an open-ended channel having a bot-

72

tom wall and spaced side walls as each blank is advanced by the conveyor, said article dispensing station comprising a pair of vertically disposed transversely spaced article guide plates astride which the side walls of the carrier are positioned upon each successive carrier being advanced to the article dispensing station by the conveyor, an inclined chute having a bottom wall and spaced side walls, the lower end of the bottom wall of said chute terminating adjacent the rear portions of the article guide plates, each of said article guide plates having a longitudinally extending opening therein, an article retaining track disposed in each of said openings and normally projecting therethrough inwardly of the vertical plane of the corresponding article guide plate, said tracks being disposed in substantially the same horizontal plane as the lowermost end of the bottom wall of the chute whereby the articles may be placed in the chute and will move downwardly along the chute, by gravity, and thus onto the article retaining tracks to form a row of articles supported by said article retaining tracks, means operable automatically upon each successive carrier being properly positioned in the article dispensing station for simultaneously moving the article retaining tracks apart from each other to permit the row of articles previously supported by the article retaining tracks to move downwardly, by gravity, onto the bottom wall of the carrier, a gate normally positioned adjacent the open lower end of the inclined chute, means operable automatically upon said article retaining tracks moving outwardly apart from each other for moving the gate into the path of the articles in the chute to thereby prevent the articles in the chute from moving between the article guide plates while the article retaining tracks are in an outward position relative to the article guide plates, means operable automatically upon said article retaining tracks returning to their original position for moving said gate away from the open lower end of the chute to permit articles in the chute to move onto said article retaining tracks for a repeat operation, means for forming each successive carrier substantially in the shape of an open-ended substantially rectangular tube with the row of articles therein upon the conveyor moving the carriers forwardly beyond the article dispensing station, means operable automatically for securing opposite edges of the successive carriers together upon the conveyor moving the carriers forwardly beyond the last-named means to maintain the carriers in said tubular shape, means operable automatically, disposed forwardly of the securing means, for stacking the carriers in superposed relation, means for supporting a box having one end open adjacent the point at which the carriers are stacked, and means operable automatically upon a predetermined number of carriers being stacked for transferring the stack of carriers into said box.

21. A machine for successively forming carriers from flat substantially rectangular blanks and for placing articles in said carriers comprising means for directing the articles into the machine to a predetermined position, means for successively feeding the blanks into the machine one at a time, means for folding spaced portions of each successive blank to form a carrier having upwardly extending first and second flaps and wherein the first flap is relatively shorter than the second flap, an article dispensing station dis-

posed forwardly of the means for folding spaced portions of the blanks, said article dispensing station including means for supporting a row of articles, means for successively positioning the carriers beneath the means for supporting a row of articles, means for lowering a predetermined number of said articles in said row into the corresponding carrier, means for maintaining the first and second flaps in substantially vertical position as the articles are lowered therebetween, means for advancing the successive carriers beyond the point at which the articles are lowered thereinto, means for forming a portion of the second flap across the upper surfaces of the articles previously lowered into the carrier to form a carrier in the shape of a substantially rectangular tube, means for stitching the last-named portion of the second flap to the upper portion of the first flap, said means for advancing the carriers also being operable to advance the carrier beyond the means of stitching said flaps together, means for stacking the successive filled carriers in superposed relation to each other, and means operable automatically upon a predetermined number of filled carriers being stacked for moving said stack of filled carriers to one side of the position in which they are stacked, whereby a box may be positioned to one side of a stack of filled carriers as they are stacked and the filled carriers may subsequently be moved into said box.

22. A machine for packaging individual rows of articles in carriers while forming said carriers from relatively thin flat substantially rectangular blanks and for stacking said carriers in superposed relation comprising a driven horizontally disposed conveyor, a magazine for containing a supply of said blanks, means for successively feeding the blanks from the magazine to the conveyor, one at a time, in timed relation to movement of the conveyor, means disposed forwardly of the magazine for forming each successive blank in the shape of a substantially channel-shaped carrier having spaced first and second side walls and wherein the second side wall is of substantially greater height than the first side wall, an article dispensing station disposed forwardly of the means for forming each successive blank in the shape of a substantially channel-shaped carrier, said article dispensing station comprising means for supporting a row of articles thereon at a point spaced above the conveyor, means operable automatically upon each successive carrier in channel-shaped form moving to a position beneath the means for supporting the row of articles for directing a predetermined number of articles in said row downwardly between the first and second side walls of the carrier, means for folding each successive carrier in the form of a substantially rectangular tube at a point forwardly of the article dispensing station upon forward movement of the conveyor comprising a horizontally disposed laterally movable folding plate normally disposed to one side of the conveyor and in a horizontal plane substantially above the conveyor, means operable automatically upon each successive carrier being advanced forwardly of the article dispensing station for moving the folding plate transversely of the conveyor over the articles in the corresponding carrier and in engagement with the second side wall to thereby fold the second side wall intermediate its upper and lower edges and thereby forming an upper wall on the carrier extending over the articles in the carrier, a carrier stacking station disposed forwardly of the

means for forming each successive carrier in the shape of a substantially rectangular tube and comprising a stacking plate disposed to one side of the conveyor and normally being disposed in substantially the same horizontal plane as the conveyor, means operable automatically upon each successive carrier being advanced to the carrier stacking station for moving the same off of the conveyor and onto the stacking plate, means operable automatically upon each carrier being positioned upon the stacking plate for moving the stacking plate upwardly and then returning the same to its normal position, means for retaining each successive carrier in the position to which it is raised by the carrier stacking plate to thereby form a stack of superposed carriers spaced above the normal position of the stacking plate, a vertically disposed stacking guide plate having an opening therein past which the carriers move as they are stacked by the stacking plate, means for supporting an open-ended container in alignment with the opening in said stacking guide plate and means operable automatically upon a predetermined number of carriers being stacked by the stacking guide plate for moving the stack of carriers through the opening in the stacking guide plate and thus into the container.

23. In a structure according to claim 22, means operable automatically for stopping the conveyor in the event of an obstruction being disposed in the path of the laterally movable folding plate as it moves transversely of the conveyor.

30 24. A machine for packaging individual rows of articles in carriers and arranging the carriers in a stack and packaging stacks of carriers in a container comprising a driven horizontal conveyor, means for feeding flat substantially rectangular carrier blanks to the conveyor, one at a time, in timed relation to movement of the conveyor, an article dispensing station disposed above the path of travel of the conveyor and comprising means for supporting a row of articles at a point spaced above the conveyor, a first folding means disposed in advance of the article dispensing station for folding each successive carrier blank to form a carrier having first and second spaced side walls extending upwardly from opposite edges of a bottom wall, said first folding means being so positioned relative to the means for feeding the carrier blanks as to form the first wall of substantially less height than the second wall, said first folding means also including means for forming a first handle flap projecting outwardly from the upper edge of the first wall, means operable automatically upon each successive carrier being advanced on the conveyor to a position beneath the means for supporting the row of articles for directing a predetermined number of articles in said row downwardly between the first and second walls and onto the bottom wall of said carrier, a second folding means disposed forwardly of the article dispensing station for folding the second wall intermediate its upper and lower edges to form an upper flap extending across the upper surfaces of the articles previously positioned in the carrier and also overlapping the first handle flap of the first wall as the conveyor advances the corresponding carrier forwardly beyond the article dispensing station, the portion of the upper flap which overlaps the first handle flap constituting a second handle flap, a stitching device disposed adjacent the conveyor forwardly of the second folding means and having electrically

40 45 50 55 60 65 70 75

operated stitching means thereon disposed in the path of travel of the handle flaps, means operable automatically in timed relation to movement of the conveyor for completing a circuit from a source of electrical energy to the electrically operated stitching means upon each successive filled carrier being positioned adjacent the stitching device by the conveyor to thereby stitch the handle flaps together, third folding means disposed forwardly of the stitching device for folding the handle flaps against the outer surface of the first wall, a stacking station disposed forwardly of the third folding means and comprising a vertically reciprocable stacking plate normally positioned in substantially the same horizontal plane as the upper surface of the conveyor, means operable automatically upon each successive carrier being advanced to a position in alignment with the stacking plate for moving each successive carrier off of the conveyor and onto the stacking plate, means operable in timed relation to the movement of each successive carrier onto the stacking plate for elevating and then lowering the stacking plate, means for retaining each successive carrier elevated by the stacking plate in a predetermined spaced relation to the normal lowered position of the stacking plate whereby each successive carrier elevated by the stacking plate will engage the carrier disposed thereabove to elevate the same, and stack transfer means operable automatically upon a predetermined number of carriers being stacked above the stacking plate for transferring the stack of carriers to one side of the vertical plane of the stacking plate, whereby a container may be positioned opposite the stack transfer means for receiving the stack of filled carriers transferred thereinto by the stack transfer means.

25. In a structure according to claim 24, means operable automatically to prevent operation of the stitching means upon the absence of a carrier being positioned adjacent the stitching device.

26. In a structure according to claim 24, means operable automatically to prevent operation of the stitching means in the event of a carrier being incorrectly positioned adjacent the stitching device.

27. A machine for successively forming carriers from flat substantially rectangular blanks and for placing articles in said carriers comprising means for successively conveying the blanks into the machine one at a time, means for folding spaced portions of each successive blank to form a carrier having a laterally extending wall and first and second substantially parallel flaps extending at substantially right angles to the laterally extending wall and wherein the first flap is relatively shorter than the second flap, an article dispensing station disposed forwardly of the means for folding spaced portions of the carriers, said article dispensing station including means for supporting a row of articles, means for directing the articles to the means for supporting a row of articles, means for successively positioning the carriers adjacent the means for supporting a row of articles, means for positioning a predetermined number of said articles in said row in the corresponding carrier, means for maintaining the first and second flaps in substantially parallel relation as the articles are positioned therebetween, means for advancing the successive carriers beyond the point at which the articles are positioned therein, means for forming a portion of the second flap across the surfaces of the articles remote from the surfaces thereof adjacent the laterally extending wall of each of the carriers to form each successive carrier in the shape of a substantially rec-

tangular tube with a row of articles therein, means for stitching the last-named portion of the second flap to the portion of the first flap remote from the laterally extending wall, said means for advancing the carriers also being operable to advance each successive carrier beyond the means for stitching said flaps together, means for stacking the successive filled carriers in superposed relation to each other, and transfer means operable automatically upon a predetermined number of filled carriers being stacked for transferring said stack of filled carriers to one side of their normal path of travel whereby a box may be positioned to one side of the normal path of travel of the filled carriers as they are stacked and the filled carriers may subsequently be transferred into said box by the transfer means.

28. A machine for packaging individual rows of articles in carriers and arranging the carriers in a stack and packaging a stack of carriers in a container comprising an elongated horizontally disposed trackway, means for feeding flat substantially rectangular carrier blanks onto the trackway, means for propelling the blanks forwardly along said trackway, an article dispensing station disposed above the trackway and comprising a pair of longitudinally extending transversely spaced article retaining tracks, means for guiding a row of articles onto the article retaining tracks, a first folding means disposed in advance of the article dispensing station for folding each successive carrier blank to form a carrier having first and second spaced walls extending upwardly from opposite edges of a bottom wall, said first folding means being so positioned relative to the means for feeding carrier blanks onto the trackway as to form the first wall of substantially less height than the second wall, said first folding means also including means for forming a first handle flap projecting outwardly from one edge of the first wall, means operable automatically upon each successive carrier being advanced on the trackway to a position below the article retaining tracks for imparting relative outward movement to the article retaining tracks to permit a predetermined number of articles to move downwardly by gravity between the first and second walls and onto the bottom of said carrier, a second folding means disposed forwardly of the article dispensing station for folding the second wall intermediate its upper and lower edges to form a flap extending across the upper surfaces of the articles previously positioned in the carrier and also overlapping the first handle flap of the first wall as the corresponding carrier is propelled forwardly beyond the article dispensing station, the portion of the last-named flap overlapping the first handle flap constituting a second handle flap, means for securing the first handle flap to the second handle flap upon each successive carrier being propelled beyond the second folding means, third folding means disposed forwardly of the means for securing the handle flaps together for folding the handle flaps against the outer surface of the first wall, a stacking station disposed forwardly of the third folding means and comprising a vertically reciprocable stacking plate normally positioned in substantially the same horizontal plane as the upper surface of the trackway, means operable automatically upon each successive carrier being propelled along the trackway to a position in alignment with the stacking plate for moving each successive carrier off of the trackway and onto

the stacking plate, means operable automatically in timed relation to the movement of each successive carrier onto the stacking plate for elevating and then lowering the stacking plate, means for retaining each successive carrier elevated by the stacking plate in a predetermined spaced relation above the normal lowered position of the stacking plate, whereby each successive carrier elevated by the stacking plate will engage the carrier disposed thereabove to elevate the same therewith, and stack transfer means operable automatically upon a predetermined number of carriers being stacked above the stacking plate for transferring at least some of the carriers in said stack to one side of the vertical plane of the stacking plate, whereby a container may be positioned opposite the stack transfer means for receiving the filled carriers transferred thereinto by the stack transfer means.

29. In a structure according to claim 28, said first folding means comprising a fixed folding die closely spaced above the trackway and having spaced parallel opposite side edges, a pair of vertically movable horizontally disposed external flap folding bars disposed below the horizontal plane of the upper surface of the trackway and adjacent opposite sides of the trackway, means operable automatically upon each successive blank being propelled to a position beneath the folding die for moving said folding bars upwardly adjacent opposite side edges of the folding die to fold the blank in the form of a substantially channel-shaped carrier having spaced side walls.

30. In a structure according to claim 29, said folding die having a lateral flap folding plate thereon projecting outwardly from one of its side edges and being spaced a predetermined distance above the lower surface of the corresponding side edge of the folding die, a laterally movable flap folding bar spaced immediately below the lateral flap folding plate, and means operable automatically upon said external flap folding bars moving upwardly and forming the side walls of the channel-shaped carrier for moving said flap folding bar inwardly beneath the lateral flap folding plate to thereby bend the corresponding side wall of the carrier intermediate its upper and lower edges to form the first handle flap projecting from the upper edge of the first side wall of the carrier.

31. A machine for packaging individual rows of articles in carriers while forming said carriers from relatively thin flat substantially rectangular blanks and for stacking said carriers in superposed relation comprising an elongated horizontal trackway, a magazine disposed rearwardly of the trackway and comprising a magazine base plate for supporting a stack of blanks, at least one set of driven upper and lower feed rolls disposed forwardly of the magazine, a carrier feed plate having its rear edge disposed adjacent the feed rolls and having its front edge disposed adjacent the rear end of the trackway, a carrier feed grasping device normally disposed in grasping engagement with the uppermost blank in said stack of blanks, means for successively elevating the grasping device and moving the same forwardly to a point adjacent the feed rolls to thereby move the corresponding uppermost blank in said stack into engagement with the feed rolls, means to release said uppermost blank from the grasping device as the blank engages the feed rolls whereby the feed rolls will direct the corresponding blank onto the carrier

feed plate and thus onto the trackway, said means for moving the grasping device also being operable to return the same to its normal position, means operable in timed relation to the grasping device for propelling each successive blank along the trackway as it is directed thereto, means disposed forwardly of the magazine for forming each successive blank in the shape of a substantially channel-shaped carrier having spaced first and second side walls and wherein the second side wall is of substantially greater height than the first side wall, an article dispensing station disposed forwardly of the means for forming each successive blank in the shape of a substantially channel-shaped carrier, said article dispensing station comprising means for supporting a row of articles thereon at a point spaced above the trackway, means operable automatically upon each successive carrier in channel-shaped form being propelled to a position beneath the means for supporting the row of articles for directing a predetermined number of articles in said row downwardly between the first and second side walls of the carrier, means for folding each successive carrier in the form of a substantially rectangular tube as it is propelled forwardly beyond the dispensing station, a filled carrier stacking plate disposed forwardly of the means for folding the carrier in the form of a tube and also being disposed to one side of the trackway and normally being disposed in substantially the same horizontal plane as the trackway, means operable automatically upon each successive carrier being propelled along the trackway to a point adjacent the carrier stacking plate for moving each successive carrier off of the trackway and onto the stacking plate, means operable automatically upon each carrier being positioned upon the stacking plate for moving the stacking plate upwardly and then returning the same to its normal position, means for retaining each successive carrier in the position to which it is raised by the stacking plate to thereby form a stack of superposed carriers spaced above the normal position of the stacking plate, means for supporting an open-ended container above and to one side of the vertical plane of the stacking plate, and means operable automatically upon a predetermined number of carriers being stacked by the stacking plate for moving the stack of carriers into the container.

32. In a structure according to claim 31, means operable automatically for raising the magazine base plate upon the uppermost blank thereon being disposed below a predetermined elevation relative to the carrier feed grasping device to thereby position each successive uppermost blank at substantially the same elevation at which the preceding uppermost blank was positioned.

33. Apparatus for forming carriers from flat substantially rectangular sheets of paper board and the like while filling each carrier with a row of articles comprising a magazine for supporting a stack of superposed rectangular sheets therein, a conveyor disposed forwardly of said magazine, means to drive said conveyor in a step-by-step manner, means for feeding the rectangular sheets, one at a time, onto the conveyor upon each successive step being imparted to the conveyor, a first folding means disposed adjacent the conveyor forwardly of the point at which the successive sheets are fed to the conveyor and being operable upon each successive step being imparted to the conveyor for folding opposite side portions of the corresponding sheet up-

wardly to form a substantially channel-shaped carrier, article retaining tracks disposed above the conveyor forwardly of said first folding means, means for directing a row of articles onto the article retaining tracks, means operable automatically upon each successive step being imparted to the conveyor for moving the article retaining tracks away from the articles disposed thereon to permit the same to fall into the corresponding substantially channel-shaped carrier, a second folding means disposed forwardly of the article retaining tracks, means operable automatically upon each successive step being imparted to the conveyor for folding at least one of said previously formed side portions of the corresponding carrier horizontally across the upper surfaces of the articles positioned therein to form a filled carrier in the shape of a substantially rectangular tube, stitching means operable automatically upon each successive step being imparted to the conveyor for stitching said horizontal portion of one of the side portions to the upper portion of the other of the side portions of the corresponding carrier, a horizontally disposed stacking plate disposed to one side of the conveyor forwardly of the stitching means and normally being disposed in substantially the same horizontal plane as the conveyor, means operable automatically upon each successive step being imparted to the conveyor for moving the corresponding filled carrier onto the stacking plate, means operable automatically in timed relation to the movement of each successive carrier onto the stacking plate for elevating the stacking plate, filled carrier retaining means disposed above the stacking plate for retaining each successive carrier elevated by the stacking plate as said stacking plate returns to its normal position in the horizontal plane of the conveyor, a stack transfer member normally disposed to one side of, and above the horizontal plane of, the filled carrier retaining means and means operable automatically in response to a predetermined number of filled carriers being stacked upon the filled carrier retaining means for moving at least some of the filled carriers off of the filled carrier retaining means simultaneously whereby an open-ended box may be positioned in alignment with the stack transfer member and the filled carriers may be ejected into the box.

34. Apparatus for forming carriers from flat substantially rectangular sheets of paper board and the like while filling each carrier with a row of articles comprising a magazine for supporting a stack of superposed rectangular sheets therein, a conveyor disposed forwardly of said magazine, means to drive said conveyor in a step-by-step manner, means for feeding the rectangular sheets, one at a time, onto the conveyor upon each successive step being imparted to the conveyor, a first folding means disposed adjacent the conveyor forwardly of the point at which the successive sheets are fed to the conveyor and being operable upon each successive step being imparted to the conveyor for folding opposite side portions of the corresponding sheet upwardly to form a substantially channel-shaped carrier, article retaining tracks disposed above the conveyor forwardly of said first folding means, means for directing a row of articles onto the article retaining tracks, means operable automatically upon each successive step being imparted to the conveyor for moving the article retaining tracks away from the articles disposed

50

thereon to permit the same to fall into the corresponding substantially channel-shaped carrier, a second folding means disposed forwardly of the article retaining tracks, means operable automatically upon each successive step being imparted to the conveyor for folding at least one of said previously formed side portions of the corresponding carrier horizontally across the upper surfaces of the articles positioned therein to form a filled carrier in the shape of a substantially rectangular tube, a horizontally disposed stacking plate disposed to one side of the conveyor forwardly of the last-named folding means and normally being disposed in substantially the same horizontal plane as the conveyor, means operable automatically upon each successive step being imparted to the conveyor for moving the corresponding filled carrier onto the stacking plate, means operable automatically in timed relation to the movement of each successive carrier onto the stacking plate for elevating the stacking plate, filled carrier retaining means disposed above the stacking plate for retaining each successive carrier elevated by the stacking plate as said stacking plate returns to its normal position in the horizontal plane of the conveyor, a stack transfer member normally disposed to one side of, and above the horizontal plane of, the filled carrier retaining means and means operable automatically in response to a predetermined number of filled carriers being stacked upon the filled carrier retaining means for moving at least some of the filled carriers off of the filled carrier retaining means simultaneously whereby an open-ended box may be positioned in alignment with the stack transfer member and the filled carriers may be ejected into the box.

35. A machine for packaging individual rows of articles in carriers while forming said carriers from relatively thin flat substantially rectangular blanks and for stacking said carriers in superposed relation comprising a driven horizontally disposed conveyor, a magazine for containing a supply of said blanks, means for successively feeding the blanks to the conveyor, one at a time, in timed relation to movement of the conveyor, means disposed forwardly of the magazine for forming each successive blank in the shape of substantially channel-shaped carrier having spaced first and second side walls and wherein the second side wall is of substantially greater height than the first side wall, an article dispensing station disposed forwardly of the means for forming the blank in the shape of a substantially channel-shaped carrier, said article dispensing station comprising means for supporting a row of articles thereon adjacent the conveyor, means operable automatically upon the carrier in channel-shaped form moving to a position adjacent the means for supporting the row of articles for directing at least some of the articles in said row of articles to a position between the first and second side walls of the carrier, means for folding each successive carrier in the form of a substantially rectangular tube at a point forwardly of the article dispensing station upon forward movement of the conveyor, a stacking plate disposed forwardly of the last-named folding means and to one side of the conveyor and normally being disposed at substantially the same level as the conveyor, means operable automatically upon each successive carrier being advanced to a point adjacent the stacking plate for moving each successive carrier off of the conveyor and onto the stacking plate, means operable au-

75

tomatically upon each carrier being positioned upon the stacking plate for moving the stacking plate upwardly and then returning the same to its normal position, means for supporting each successive carrier in the position to which it is raised by the stacking plate to thereby form a stack of superposed carriers spaced above the stacking plate, at least one vertically disposed stacking guide plate having an opening therein past which the carriers move as they are stacked by the stacking plate, means for supporting an open-ended container in alignment with the opening in said stacking guide plate, and means operable automatically upon a predetermined number of carriers being stacked by the stacking guide plate for moving at least some of the carriers in said stack through the opening in the stacking guide plate and into the container.

36. In a machine for packaging articles in carriers while forming said carriers from relatively thin flat substantially rectangular blanks and for stacking said carriers in superposed relation, an endless conveyor mounted in said machine, a plurality of spaced clamping devices mounted on the conveyor, each of said clamping devices comprising an inner jaw and an outer jaw, spring means normally holding the jaws of the clamping devices in closed position, a framework, a magazine spaced rearwardly of the conveyor, said magazine comprising a horizontally disposed magazine base plate carried by said framework for supporting a stack of blanks thereon, at least one carrier feed grasping device normally positioned above the uppermost blank on said magazine base plate, means carried by said framework for supporting the carrier feed grasping device for vertical movement and horizontal forward and rearward movement thereon, means operable automatically in timed relation to movement of the conveyor for actuating the carrier feed grasping device to move the same downwardly into engagement with the uppermost blank in said stack on the magazine base plate and to then elevate the carrier feed grasping device while moving the same forwardly toward the conveyor to thus direct said uppermost blank to a corresponding clamping device on the conveyor, means operable automatically for momentarily opening and then closing the jaws of each successive clamping device adjacent the magazine as each blank is directed thereto, means operable automatically for releasing the corresponding uppermost blank from the carrier feed grasping device at the termination of its forward stroke, said means for raising and moving the carrier feed grasping device forwardly also being operable to return the carrier feed grasping device to its original position, a first folding means disposed forwardly of said magazine for forming each successive blank into a carrier in substantially the shape of an open-ended channel having a bottom wall and spaced side walls as the conveyor advances the corresponding carrier thereby, means for positioning a row of articles including a predetermined number of articles on the bottom wall and between the spaced side walls of said carrier, a second folding means disposed forwardly of the means for positioning a row of articles in the carrier for forming the carrier substantially in the shape of an open-ended substantially rectangular tube with the row of articles therein as the corresponding carrier is advanced thereby by the conveyor, means operable automatically for securing opposite edges of the carrier together at a point forwardly

of the second folding means as the corresponding carrier is advanced thereby by the conveyor, stacking means disposed forwardly of the means for securing opposite edges of the carrier together and being operable automatically for stacking successive carriers in superposed relation as they are advanced thereto by the conveyor, and means operable automatically upon a predetermined number of carriers being stacked for transferring the stack of carriers to one side of the position in which they were originally stacked whereby an open-ended container may be positioned adjacent the point at which the carriers are stacked and the stack of carriers may be transferred into said container.

37. In a structure according to claim 36, said carrier feed grasping device comprising at least one vertically disposed tubular member, a suction device, pipe connections between the suction device and the vertically disposed tubular member, a normally closed valve interposed in the pipe connections between the suction device and the tubular member and normally creating suction in the tubular member when closed whereby, as the grasping device moves downwardly, the tubular member engages the uppermost carrier attracting the same thereto due to the suction therein and then moves the carrier upwardly and forwardly toward the conveyor, and means operable automatically upon the carrier feed grasping device reaching the end of its forward stroke for opening said valve to stop the suction in said tubular member thereby releasing the corresponding blank from the carrier feed grasping device.

38. In a structure according to claim 37, said tubular member having a resilient suction cup on the lower end thereof for resiliently engaging the upper surface of the uppermost blank supported by the magazine base plate in transferring the corresponding blank to the conveyor.

39. In a machine for packaging articles in carriers while forming said carriers from relatively thin flat substantially rectangular blanks and for stacking said carrier in superposed relation, an endless conveyor mounted in said machine, a plurality of spaced clamping devices mounted on the conveyor, each of said clamping devices comprising an inner jaw and an outer jaw, spring means normally holding the jaws of the clamping devices in closed position, a framework, a magazine spaced rearwardly of the conveyor, said magazine comprising a horizontally disposed magazine base plate for supporting a stack of blanks thereon, means supporting the magazine base plate for vertical movement in said framework, at least one carrier feed grasping device positioned above the uppermost blank on said magazine base plate, means carried by said framework for supporting the carrier feed grasping device for vertical movement and horizontal forward and rearward movement thereon, means operable automatically in timed relation to movement of the conveyor for actuating the carrier feed grasping device to move the same downwardly into engagement with the uppermost blank in said stack on the magazine base plate and to then elevate the carrier feed grasping device while moving the same forwardly toward the conveyor to thus direct said uppermost blank to a corresponding clamping device on the conveyor, means operable automatically for momentarily opening and then closing the jaws of each successive clamping device adjacent the magazine as each blank is directed thereto, means operable automatically for releasing the corresponding uppermost blank from the carrier feed grasping device at the termination of its forward stroke, said means for raising and moving the carrier feed grasping device forwardly also being operable to return the carrier feed grasping device to its original position, a first folding means disposed forwardly of said magazine for forming each successive blank into a carrier in substantially the shape of an open-ended channel having a bottom wall and spaced side walls as the conveyor advances the corresponding carrier thereby, means for positioning a row of articles including a predetermined number of articles on the bottom wall and between the spaced side walls of said carrier, a second folding means disposed forwardly of the means for positioning a row of articles in the carrier for forming the carrier substantially in the shape of an open-ended substantially rectangular tube with the row of articles therein as the corresponding carrier is advanced thereby by the conveyor, means operable automatically for securing opposite edges of the carrier together at a point forwardly

operable automatically for releasing the corresponding uppermost blank from the carrier feed grasping device at the termination of its forward stroke, said means for raising and moving the carrier feed grasping device forwardly also being operable to return the carrier feed grasping device to its original position, means operable automatically for raising the magazine base plate as successive blanks are fed therefrom to the conveyor to thereby insure that each successive uppermost blank in said stack supported by the magazine base plate is in proper position to be engaged by the carrier feed grasping device, a first folding means disposed forwardly of said magazine for forming each successive blank into a carrier in substantially the shape of an open-ended channel having a bottom wall and spaced side walls as the conveyor advances the corresponding carrier thereby, means for positioning a row of articles including a predetermined number of articles on the bottom wall and between the spaced side walls of said carrier, a second folding means disposed forwardly of the means for positioning a row of articles in the carrier for forming the carrier substantially in the shape of an open-ended substantially rectangular tube with the row of articles therein as the corresponding carrier is advanced thereby by the conveyor, means operable automatically for securing opposite edges of the carrier together at a point forwardly of the second folding means as the corresponding carrier is advanced thereby by the conveyor, stacking means disposed forwardly of the means for securing opposite edges of the carrier together and being operable automatically for stacking successive carriers in superposed relation as they are advanced thereto by the conveyor, and means operable automatically upon a predetermined number of carriers being stacked for transferring the stack of carriers to one side of the position in which they were originally stacked whereby an open-ended container may be positioned adjacent the point at which the carriers are stacked and the stack of carriers may be transferred into said container.

40. In a structure according to claim 39, said means for raising the magazine base plate comprising a shaft rotatably supported in said framework, a ratchet wheel fixed on said shaft, a pawl carrying arm pivotally mounted on said shaft and having a ratchet pawl pivotally mounted thereon and engaging the teeth in said ratchet wheel, at least one rack connected to said magazine base plate, a pinion fixed on said shaft and meshing with said rack, said pawl carrying arm normally being stationary and being operable automatically upon said carrier feed grasping device moving downwardly below a predetermined level relative to the magazine base plate for imparting oscillatory movement to the pawl carrying arm to, in turn, impart step-by-step rotary movement to said shaft to move said rack and the magazine base plate upwardly, and means operable automatically upon the uppermost blank in the stack of blanks on the magazine base plate engaging and moving the carrier feed grasping device upwardly above a predetermined level relative to the magazine base plate for stopping movement of the pawl carrying arm.

41. In a structure according to claim 39, said magazine also having a fixed front wall past which the front edges of the blanks in said stack and the magazine base plate move as the magazine base plate is raised, at least one resilient stripper element carried by said front wall and

extending rearwardly therefrom above the uppermost blank in said stack on the magazine base plate whereby, upon the leading edge of the uppermost blank being elevated by said carrier feed grasping device, the stripper element will be moved upwardly slightly by said uppermost blank and will immediately move downwardly as the blank moves past the same to engage the next succeeding blank for separating the next succeeding uppermost blank from the first-named uppermost blank as each succeeding uppermost blank is directed to the conveyor.

42. In a structure according to claim 41, said magazine also having a pair of side walls adjacent which the blanks move with movement of the magazine base plate as the uppermost blanks are successively fed to the conveyor, said side walls each having a vertically extending slot therein, a weight member resting upon the medial portion of the uppermost blank and being guided at opposite ends thereof in the slots in the side walls of the magazine, said weight member serving to hold down the stack of blanks on the magazine base plate as each successive uppermost blank is fed to the conveyor.

43. In a machine for packaging articles in carriers while forming said carriers from relatively thin flat substantially rectangular blanks and for stacking said carriers in superposed relation, an endless conveyor mounted in said machine, a plurality of spaced clamping devices mounted on the conveyor, each of said clamping devices comprising an inner jaw and an outer jaw, spring means normally urging the outer jaw into closed position relative to the inner jaw, a magazine spaced rearwardly of the conveyor, said magazine comprising a horizontally disposed magazine base plate for supporting a stack of blanks thereon, a framework, at least one carrier feed grasping device positioned above the magazine base plate, a pair of rocker arms pivotally mounted upon said framework at a point substantially below the level of the carrier feed grasping device and being disposed adjacent opposite sides of said framework, cam controlled means for imparting forward and rearward reciprocatory movement to said rocker arms in timed relation to movement of the conveyor, a substantially vertically disposed guide bar mounted for vertical sliding movement in each of said rocker arms, a transverse frame member bridging the upper ends of said vertically disposed guide bars and to which the carrier feed grasping device is secured, cam controlled means for effecting upward movement to the guide bars and the corresponding carrier feed grasping device as the rocker arms move forwardly and for lowering the guide bars as the rocker arms move rearwardly whereby the grasping device will engage and grasp the uppermost blank in the stack of blanks on the magazine base plate and move the same upwardly and forwardly onto the conveyor in timed relation to movement of said conveyor and will then return to its original position, means operable automatically upon the grasping device reaching the end of its forward stroke for releasing the corresponding blank therefrom as it is directed to the conveyor, means operable automatically for momentarily opening and then closing the jaws of the carrier clamping device adjacent the magazine as each blank is directed thereto, a first folding means disposed forwardly of said magazine for forming each blank into a carrier in substantially the shape of an open-ended channel having a

bottom wall and spaced side walls as the conveyor advances the corresponding carrier thereby, means for positioning a row of articles including a predetermined number of articles on the bottom wall and between the spaced side walls of said carrier, a second folding means disposed forwardly of the means for positioning a row of articles in the carrier for forming the carrier substantially in the shape of an open-ended substantially rectangular tube with the row of articles thereon as the corresponding carrier is advanced thereby by the conveyor, means operable automatically for securing opposite edges of the carrier together at a point forwardly of the second folding means as the corresponding carrier is advanced thereby by the conveyor, stacking means disposed forwardly of the means for securing opposite edges of the carrier together and being operable automatically for stacking successive carriers in superposed relation as they are advanced thereto by the conveyor, and means operable automatically upon a predetermined number of carriers being stacked for transferring the stack of carriers to one side of the position in which they were originally stacked whereby an open-ended container may be positioned adjacent the point at which the carriers are stacked and the stack of carriers may be transferred into said container.

44. In a machine for packaging articles in carriers while forming said carriers from relatively thin flat substantially rectangular blanks and for stacking said carriers in superposed relation, an endless conveyor mounted in said machine, a plurality of spaced clamping devices mounted on the conveyor, each of said clamping devices comprising an inner jaw and an outer jaw, spring means normally urging the outer jaw into closed position relative to the inner jaw, a magazine spaced rearwardly of the conveyor, said magazine comprising a horizontally disposed magazine base plate for supporting a stack of blanks thereon, a framework, means supporting the magazine base plate for vertical movement in said framework, at least one carrier feed grasping device positioned above the magazine base plate, a pair of rocker arms pivotally mounted upon said framework at a point substantially below the level of the carrier feed grasping device and being disposed adjacent opposite sides of said framework, cam controlled means for imparting forward and rearward reciprocatory movement to said rocker arms in timed relation to movement of the conveyor, a substantially vertically disposed guide bar mounted for vertical sliding movement in each of said rocker arms, a transverse frame member bridging the upper ends of said vertically disposed guide bars and to which the carrier feed grasping device is secured, cam controlled means for effecting upward movement to the guide bars and the corresponding carrier feed grasping device as the rocker arms move forwardly and for lowering the guide bars as the rocker arms move rearwardly whereby the grasping device will engage and grasp the uppermost blank in the stack of blanks on the magazine base plate and move the same upwardly and forwardly onto the conveyor in timed relation to movement of said conveyor and will then return to its original position, means operable automatically upon the grasping device reaching the end of its forward stroke for releasing the corresponding blank therefrom as it is directed to the conveyor, means operable automatically for raising the magazine base plate upon the upper-

most blank thereon being spaced below the carrier feed grasping device when the carrier feed grasping device is in its rearward position to thereby position the uppermost blank in the magazine at a level to be properly engaged by the carrier feed grasping device, means operable automatically for momentarily opening and then closing the jaws of the carrier clamping device adjacent the magazine as each blank is directed thereto, a first folding means disposed forwardly of said magazine for forming each blank into a carrier in substantially the shape of an open-ended channel having a bottom wall and spaced side walls as the conveyor advances the corresponding carrier thereby, means for positioning a row of articles including a predetermined number of articles on the bottom wall and between the spaced side walls of said carrier, a second folding means disposed forwardly of the means for positioning a row of articles in the carrier for forming the carrier substantially in the shape of an open-ended substantially rectangular tube with the row of articles thereon as the corresponding carrier is advanced thereby by the conveyor, means operable automatically for securing opposite edges of the carrier together at a point forwardly of the second folding means as the corresponding carrier is advanced thereby by the conveyor, stacking means disposed forwardly of the means for securing opposite edges of the carrier together and being operable automatically for stacking successive carriers in superposed relation as they are advanced thereto by the conveyor, and means operable automatically upon a predetermined number of carriers being stacked for transferring the stack of carriers to one side of the position in which they were originally stacked whereby an open-ended container may be positioned adjacent the point at which the carriers are stacked and the stack of carriers may be transferred into said container.

45. In a machine for packaging articles in carriers while forming said carriers from relatively thin flat substantially rectangular blanks and for stacking said carriers in superposed relation, an endless conveyor mounted in said machine, a plurality of spaced clamping devices mounted on the conveyor, each of said clamping devices comprising an inner jaw and an outer jaw, spring means normally urging the outer jaw into closed position relative to the inner jaw, a magazine spaced rearwardly of the conveyor, said magazine comprising a horizontally disposed magazine base plate for supporting a stack of blanks thereon, at least one set of driven upper and lower feed rolls disposed forwardly of, and above the level of, the magazine base plate, a horizontal carrier feed plate having its rear edge disposed adjacent the feed rolls and having its front edge disposed adjacent the conveyor, a framework, at least one carrier feed grasping device positioned above the magazine base plate, means carried by said framework for supporting the carrier feed grasping device for vertical and forward and rearward movement thereon, means operable automatically in timed relation to movement of the conveyor for actuating the carrier feed grasping device to move the same downwardly into grasping engagement with the uppermost blank in said stack on the magazine base plate and to then elevate the carrier feed grasping device while moving the same forwardly toward the conveyor to thus direct said uppermost blank to the corresponding clamping

device on the conveyor, means operable automatically for momentarily opening and then closing the jaws of each successive carrier clamping device adjacent the magazine as each blank is directed thereto, means operable automatically for releasing the corresponding uppermost blank from the carrier feed grasping device at the termination of its forward stroke, said means for raising and moving the carrier feed grasping device forwardly also being operable to return the carrier feed grasping device to its original position, a first folding means disposed forwardly of said magazine for forming each blank as a carrier in substantially the shape of an open-ended channel having a bottom wall and spaced side walls as the conveyor advances the corresponding carrier thereby, means for positioning a row of articles including a predetermined number of articles on the bottom wall and between the spaced side walls of said carrier, a second folding means disposed forwardly of the means for positioning a row of articles in the carrier for forming the carrier substantially in the shape of an open-ended substantially rectangular tube with the row of articles thereon as the corresponding carrier is advanced thereby by the conveyor, means operable automatically for securing opposite edges of the carrier together at a point forwardly of the second folding means as the corresponding carrier is advanced thereby by the conveyor, stacking means disposed forwardly of the means for securing opposite edges of the carrier together and being operable automatically for stacking successive carriers in superposed relation as they are advanced thereto by the conveyor, and means operable automatically upon a predetermined number of carriers being stacked for transferring the stack of carriers to one side of the position in which they were originally stacked whereby an open-ended container may be positioned adjacent the point in which the stack of carriers are stacked and the stack of carriers will be transferred into said container.

46. In a structure according to claim 45, a longitudinally extending guide rail secured to the upper surface of said carrier feed plate and being disposed to one side of the path of travel of each successive blank as it is directed onto the carrier feed plate by the feed rolls, a carrier blank locator bar normally disposed adjacent the path of travel of the side edge of each successive carrier directed onto the carrier feed plate remote from the edge adjacent the guide rail, spring means normally urging said carrier blank locator bar inwardly towards the guide rail and cam controlled means normally holding the carrier blank locator bar outwardly of the corresponding edge of each successive carrier as it is directed onto the carrier feed plate and being operable to permit the spring means to move the carrier blank locator bar inwardly against the corresponding edge of the corresponding blank as it is directed onto the carrier feed plate from the feed rolls to thereby position the opposite edge of the corresponding blank against the guide rail to properly align each successive blank with the conveyor.

47. In a structure according to claim 45, at least one throw arm normally disposed below the level of the bite of the set of driven upper and lower feed rolls and cam controlled means operable in timed relation to each forward stroke of the carrier feed grasping device for moving the throw arm forwardly and upwardly adjacent

the bite of the feed rolls for engaging the trailing edge of the corresponding blank to move the same forwardly to insure that the leading edge of the corresponding blank is properly positioned between the jaws of the corresponding clamping device on the conveyor.

48. In a structure according to claim 45, a blank hold-down plate normally resting upon the carrier feed plate and having an upwardly and rearwardly extending inclined portion thereon disposed forwardly of said upper and lower feed rolls and means pivotally supporting the blank hold-down plate at the upper edge of the inclined portion thereof whereby, upon each successive blank being directed forwardly between the feed rolls, the inclined portion on the hold-down plate will direct the corresponding blank downwardly as it moves forwardly, causing the blank to move beneath the same to be held down thereby to insure that the blank is in the proper horizontal attitude relative to the conveyor as it is directed thereto.

49. A machine for packaging individual rows of articles in carriers while forming said carriers from relatively thin flat substantially rectangular blanks and for stacking said carriers in superposed relation comprising a driven horizontally disposed endless conveyor, a magazine for containing a supply of said blanks, means for successively feeding the blanks from the magazine to the conveyor, one at a time, in timed relation to movement of the conveyor, a plurality of equally spaced carrier clamping devices mounted on said conveyor, said carrier clamping devices each comprising an inner jaw and an outer jaw, resilient means normally urging the jaws of each of the clamping devices to closed position with respect to each other, said jaws of each clamping device being pivotally interconnected, each outer jaw having a wing portion thereon disposed adjacent the opposite side of the pivot point of the jaw from that portion of the jaw which engages the inner jaw, a pressure applying element disposed above the path of travel of the upper reach of the conveyor and forwardly of said magazine, cam controlled means for moving said pressure applying element downwardly into engagement with said wing portion of the outer jaw for moving the outer jaw away from the inner jaw upon the corresponding blank being fed from the magazine to the conveyor and for returning the pressure applying element to its original position to thereby permit the jaws to clamp the leading edge of the corresponding blank therebetween,

means disposed forwardly of the magazine for forming each successive blank in the shape of a substantially channel-shaped carrier having spaced first and second side walls and wherein the second side wall is of substantially greater height than the first side wall, an article dispensing station disposed forwardly of the means for forming each successive blank in the shape of a substantially channel-shaped carrier, said article dispensing station comprising means for supporting a row of articles at a point spaced above the conveyor, means operable automatically upon each successive carrier in channel-shaped form moving to a position beneath the means for supporting the row of articles for directing a predetermined number of articles in said row downwardly between the first and second side walls of the carrier, means for folding each successive carrier in the form of a substantially rectangular tube at a point forwardly of the article dispensing station upon forward movement of the conveyor,

a carrier stacking station disposed forwardly of the means for forming each successive carrier in the shape of a substantially rectangular tube and comprising a stacking plate disposed to one side of the conveyor and normally being disposed in substantially the same horizontal plane as the conveyor, means operable automatically upon each successive carrier being advanced to the carrier stacking station for moving the same off of the conveyor and onto the stacking plate, means operable automatically upon each carrier being positioned upon the stacking plate for moving the stacking plate upwardly and then returning the same to its normal position, means for supporting each successive carrier in the position to which it is raised by the stacking plate to thereby form a stack of superposed carriers spaced above the normal position of the stacking plate, a vertically disposed stacking guide plate having an opening therein past which the carriers move as they are stacked by the stacking plate, means for supporting an open ended container in alignment with the opening in said stacking guide plate, and means operable automatically upon a predetermined number of carriers being stacked by the stacking plate for moving the stack of carriers through the opening in the stacking guide plate and thus into the container.

50. A machine for packaging individual rows of articles in carriers while forming said carriers from relatively thin flat substantially rectangular blanks and for stacking said carriers in superposed relation comprising a driven horizontally disposed conveyor, a magazine for containing a supply of said blanks, means for successively feeding the blanks from the magazine to the conveyor, one at a time, in timed relation to movement of the conveyor, means disposed forwardly of the magazine for forming each successive blank in the shape of a substantially channel-shaped carrier having spaced first and second side walls and wherein the second side wall is of substantially greater height than the first side wall, an article dispensing station disposed forwardly of the means for forming each successive blank in the shape of a substantially channel-shaped carrier, said article dispensing station comprising a pair of longitudinally extending transversely spaced article retaining tracks spaced above the path of travel of the conveyor, means for guiding a row of articles onto the article retaining tracks, cam controlled means for imparting relative inward and outward movement to the article retaining tracks to permit the articles thereon to move downwardly by gravity between the first and second side walls of a corresponding carrier in timed relation to movement of the conveyor, means for folding each successive carrier in the form of a substantially rectangular tube at a point forwardly of the article dispensing station upon forward movement of the conveyor, a carrier stacking station disposed forwardly of the means for forming each successive carrier in the shape of a substantially rectangular tube and comprising a stacking plate disposed to one side of the conveyor and normally being disposed in substantially the same horizontal plane as the conveyor, means operable automatically upon each successive carrier being advanced to the carrier stacking station for moving the same off of the conveyor and onto the stacking plate, means operable automatically upon each carrier being positioned upon the stacking plate for moving the stacking plate upwardly and then returning the same to its normal position, means for supporting each suc-

sive carrier in the position to which it is raised by the stacking plate to thereby form a stack of superposed carriers spaced above the normal position of the stacking plate, means for supporting an open-ended contained adjacent one side of the stack of carriers formed by the stacking plate, and means operable automatically upon a predetermined number of carriers being stacked by the stacking plate for moving the stack of carriers into the open-ended container.

51. In a structure according to claim 50, means preventing the articles from being directed to a position above the horizontal plane of the article retaining tracks before the article retaining tracks have returned to their inward position.

52. A machine for packaging individual rows of articles in carriers while forming said carriers from relatively thin flat substantially rectangular blanks and for stacking said carriers in superposed relation comprising an intermittently driven horizontally disposed conveyor, a magazine for containing a supply of said blanks, means for successively feeding the blanks from the magazine to the conveyor, one at a time, in timed relation to movement of the conveyor, means disposed forwardly of the magazine for forming each successive blank in the shape of a substantially channel-shaped carrier having spaced first and second side walls and wherein the second side wall is of substantially greater height than the first side wall, an article dispensing station disposed forwardly of the means for forming each successive blank in the shape of a substantially channel-shaped carrier, said article dispensing station comprising a pair of longitudinally extending transversely spaced article retaining tracks, means for guiding a row of articles onto the article retaining tracks, a driven cam, a resilient mechanical connection between said cam and the article retaining tracks, said driven cam being operable upon the resilient connection to the article retaining tracks for normally moving said article tracks outwardly with respect to each other upon each step in movement of the conveyor, locking means locking said article retaining tracks in their inward position beneath the articles, means controlled by the corresponding carrier positioned on the conveyor as it moves into position beneath the article retaining tracks for releasing the article retaining tracks from the locking means to permit the articles previously supported on the article retaining tracks to move downwardly by gravity to a position between the first and second side walls of the carrier, said resilient connection serving to permit the cam to operate upon the resilient connection without moving the article retaining tracks outwardly relative to each other in the event the article retaining tracks are not released from the locking means due to the absence of a carrier on the conveyor beneath the article retaining tracks, means for folding each successive carrier in the form of a substantially rectangular tube at a point forwardly of the article dispensing station upon forward movement of the conveyor, a carrier stacking station disposed forwardly of the means for forming each successive carrier in the shape of a substantially rectangular tube and comprising a stacking plate disposed to one side of the conveyor and normally disposed in substantially the same horizontal plane as the conveyor, means operable automatically upon each successive carrier being advanced to the carrier stacking station for moving the same off of the con-

veyor and onto the stacking plate, means operable automatically upon each carrier being positioned upon the stacking plate for moving the stacking plate upwardly and then returning the same to its normal position, means for supporting each successive carrier in the position to which it is raised by the stacking plate to thereby form a stack of superposed carriers spaced above the normal position of the stacking plate, means for supporting an open-ended container adjacent one side of the stack of carriers formed by the stacking plate, and means operable automatically upon a predetermined number of carriers being stacked by the stacking plate for moving the stack of carriers into the open-ended carrier.

53. In a structure according to claim 52, means preventing the articles from being directed to a position above the level of the article retaining tracks before the article retaining tracks have returned to their inward position.

54. A machine for packaging individual rows of articles in carriers while forming said carriers from relatively thin flat substantially rectangular blanks and for stacking said carriers in superposed relation comprising an intermittently disposed horizontally disposed conveyor, a magazine for containing a supply of said blanks, means for successively feeding the blanks from the magazine to the conveyor, one at a time, in timed relation to movement of the conveyor, means disposed forwardly of the magazine for forming each successive blank in the shape of a substantially channel-shaped carrier having spaced first and second side walls and wherein the second side wall is of substantially greater height than the first side wall, an article dispensing station disposed forwardly of the means for forming each successive blank in the shape of a substantially channel-shaped carrier, said article dispensing station comprising a framework, a pair of longitudinally extending transversely spaced article guide plates supported in the framework and disposed adjacent opposite sides of the conveyor, an inclined chute comprising a bottom wall and spaced chute side walls, the open lower end of said chute being aligned with the article guide plates, the article guide plates each having a longitudinally extending slot therein, a pair of parallel longitudinally extending shafts oscillatably supported by said framework above the article guide plates, a pair of article retaining track supports pivotally mounted one on each of the corresponding shafts above the article guide plates, said article retaining track supports each having an article retaining track thereon normally projecting through the slot in the corresponding article guide plate and inwardly of the vertical plane of the corresponding article guide plate, spring means urging said article retaining tracks to their normal position inwardly of the vertical planes of the article guide plates, the bottom wall of said chute being disposed at substantially the same level as the article retaining tracks for guiding a row of articles onto the article retaining tracks, inwardly projecting arms carried by the article retaining track supports and said arms overlapping one another in side-by-side relation at their inner proximate ends, a third shaft spaced above and to one side of the first-named shafts and being oscillatably mounted in the framework, a lever arm fixed intermediate its ends on said shaft and extending above the proximate ends of said arms projecting inwardly from the article retaining track sup-

ports, means on one end of said lever arm engaging the upper surfaces of the proximate ends of said arms projecting inwardly from the article retaining track supports, a connecting rod resiliently connected to the other end of said lever arm, cam controlled means operable upon each step of the conveyor being completed to move said connecting rod to thereby move the lever arm on said third shaft to cause the proximate ends of said arms projecting inwardly from the article retaining track supports to move downwardly to thus move the article retaining tracks outwardly relative to each other for releasing the row of articles therefrom to permit the same to move downwardly between first and second side walls of the corresponding carrier, means for folding each successive carrier in the form of a substantially rectangular tube at a point forwardly of the article dispensing station upon forward movement of the conveyor, a carrier stacking station disposed forwardly of the means for forming each successive carrier in the shape of a substantially rectangular tube and comprising a stacking plate disposed to one side of the conveyor and normally being disposed in substantially the same horizontal plane as the conveyor, means operable automatically upon each successive carrier being advanced to the carrier stacking station for moving the same off of the conveyor and onto the stacking plate, means operable automatically upon each carrier being positioned upon the stacking plate for moving the stacking plate upwardly and then returning the same to its normal position, means for supporting each successive carrier in the position to which it is raised by the stacking plate to thereby form a stack of superposed carriers spaced above the normal position of the stacking plate, means for supporting the open end of an open-ended container adjacent one side of the stack of carriers formed by the stacking plate, and means operable automatically upon a predetermined number of carriers being stacked by the stacking plate for moving the stack of carriers into the open-ended container.

55. In a structure according to claim 54, a locking means for maintaining said article retaining tracks in their normal position in the absence of a carrier being positioned beneath the article retaining tracks, the resilient connection between the connecting rod and the lever arm serving to permit the cam controlled means to move the connecting rod without moving the corresponding lever arm, and means operable automatically upon a carrier on the conveyor being positioned beneath the article retaining tracks for releasing the article retaining tracks from said locking means to thus permit the article retaining tracks to move outwardly in response to movement of the connecting rod.

56. In a structure according to claim 54, a gate normally positioned adjacent and above the level of the open lower end of said chute, and means operable automatically upon said retaining tracks being moved outwardly to move said gate into the path of the articles in said chute to prevent said articles from moving between the article guide plates while the retaining tracks are in their outward position and for moving said gate out of the path of the articles in said chute upon the article retaining tracks returning to their inward position to permit succeeding articles to move onto the article retaining tracks preparatory to a repeat operation.

57. In a structure according to claim 54, means

controlled by the leading article directed to the article retaining tracks and upon the leading article being properly positioned on the article retaining tracks for effecting each successive step in movement to the conveyor whereby, upon the absence of a row of articles on the article retaining tracks, the conveyor will remain stationary.

58. A machine for packaging individual rows of articles in carriers and arranging the carriers in a stack and packaging a stack of carriers in a container comprising an elongated horizontally disposed trackway, means for feeding flat substantially rectangular carrier blanks onto the trackway, means for propelling the blanks forwardly along said trackway, an article dispensing station disposed above the trackway and comprising a pair of longitudinally extending transversely spaced article retaining tracks, means for guiding a row of articles onto the article retaining tracks, a first folding means disposed in advance of the article dispensing station for folding each successive carrier blank comprising a fixed folding die closely spaced above the trackway and having spaced parallel opposite side edges, a pair of vertically movable horizontally disposed external flap folding bars normally disposed below the level of the upper surface of the trackway and adjacent opposite sides of the trackway, cam controlled means operable in timed relation to the means for propelling the blanks along said trackway for moving said folding bars upwardly adjacent opposite side edges of the folding die as each successive blank is positioned beneath the folding die to fold the blank in the form of a carrier having first and second spaced side walls extending upwardly from opposite side edges of a bottom wall, said first folding means being so positioned relative to the means for feeding carrier blanks onto the trackway as to form the first wall of substantially less height than the second wall, means operable automatically upon each successive carrier being advanced on the trackway to a position below the article retaining tracks for imparting relative outward movement to the article retaining tracks to permit a predetermined number of articles to move downwardly by gravity between the first and second side walls and onto the bottom wall of said carrier, a second folding means disposed forwardly of the article dispensing station for folding the second wall intermediate its upper and lower edges to form a flap extending across the upper surfaces of the articles previously positioned in the carrier as the corresponding carrier is propelled forwardly beyond the article dispensing station, means for securing the upper edge of the first wall to the corresponding edge of the flap formed by the second folding means upon each successive carrier being propelled beyond the second folding means, a stacking station disposed forwardly of the means for securing the upper edge of the first wall to the flap formed by the second folding means, said stacking station comprising a vertically reciprocable stacking plate positioned to one side of said trackway and normally being disposed at substantially the same level as the upper surface of the trackway, means operable automatically upon each successive carrier being propelled along the trackway to a position adjacent the stacking plate for moving each successive carrier off of the trackway and onto the stacking plate, means operable automatically in timed relation to the movement of each successive carrier onto the stacking plate for ele-

vating and then lowering the stacking plate, means to support each successive carrier elevated by the stacking plate in a predetermined spaced relation above the normal lowered position of the stacking plate, whereby each successive carrier elevated by the stacking plate will engage a carrier which may be disposed thereabove to elevate the same therewith and stack transfer means operable automatically upon a predetermined number of carriers being stacked above the stacking plate for transferring at least some of the carriers in said stack to one side of the vertical plane of the stacking plate whereby a container may be positioned opposite the stack transfer means for receiving the filled carriers transferred thereinto by the stack transfer means.

59. In a structure according to claim 58, said folding die of the first folding means having a lateral flap folding plate thereon projecting outwardly from the side edge thereof at which the first side walls of the carrier is formed and being spaced a predetermined distance above the lower surface of the corresponding side edge of the folding guide, a laterally movable flap folding bar normally spaced adjacent the outer edge of the lateral flap folding plate and being movable to a position spaced below the lateral flap folding plate, and cam controlled means operable in timed relation to the upward movement of the external flap folding bars for moving said movable flap folding bar inwardly beneath the lateral flap folding plate to thereby bend the corresponding side wall of the carrier intermediate its upper and lower edges to form a first handle flap projecting outwardly from the upper edge of the first side wall of the carrier.

60. A machine for packaging individual rows of articles in carriers while forming said carriers from relatively thin flat substantially rectangular blanks and for stacking said carriers in superposed relation comprising a driven horizontally disposed conveyor, a magazine for containing a supply of said blanks, means for successively feeding the blanks from the magazine to the conveyor, one at a time, in timed relation to movement of the conveyor, first folding means disposed forwardly of the magazine for forming each successive blank in the shape of a substantially channel-shaped carrier having spaced first and second side walls and wherein the second side wall is of substantially greater height than the first side wall, an article dispensing station disposed forwardly of the first folding means, said article dispensing station comprising means for supporting a row of articles therein at a point spaced above the conveyor, means operable automatically upon each successive carrier in channel-shaped form moving to a position beneath the means for supporting the row of articles for directing a predetermined number of articles in said row downwardly between the first and second side walls of the carrier, a second folding means to fold each successive carrier in the form of a substantially rectangular tube at a point forwardly of the article dispensing station upon forward movement of the conveyor comprising a horizontally disposed laterally movable folding plate normally disposed to one side of the conveyor and in a horizontal plane substantially above the conveyor, cam controlled means operable upon each successive carrier being advanced forwardly of the article dispensing station for moving the laterally movable folding plate transversely of the conveyor over the articles in the corresponding carrier and in engagement with

the second side wall of the carrier to thereby fold the second side wall intermediate its upper and lower edges to form an upper wall on the carrier extending over the articles in the carrier, a carrier stacking station disposed forwardly of the second folding means and comprising a stacking plate disposed to one side of the conveyor and normally being disposed in substantially the same horizontal plane as the conveyor, means operable automatically upon each successive carrier being advanced to the carrier stacking station for moving the same off of the conveyor and onto the stacking plate, means operable automatically upon each carrier being positioned upon the stacking plate for moving the stacking plate upwardly and then returning the same to its normal position, means to support each successive carrier in the position to which it is raised by the carrier stacking plate to thereby form a stack of superposed carriers spaced above the normal position of the stacking plate, means for supporting an open-ended container to one side of the stack of carriers as the stack is formed by the stacking plate, and means operable automatically upon a predetermined number of carriers being stacked by the stacking plate for moving at least some of the carriers in said stack to one side of the position in which they were stacked by the stacking plate to thus move the carriers into the container.

61. In a structure according to claim 60, means operable automatically for stopping the conveyor in the event of an obstruction being disposed in the path of the laterally movable folding plate as it moves transversely of the conveyor.

62. A machine for packaging individual rows of articles in carriers while forming said carriers from relatively thin flat substantially rectangular blanks and for stacking said carriers in superposed relation comprising a driven horizontally disposed conveyor, a magazine for containing a supply of said blanks, means for successively feeding the blanks from the magazine to the conveyor, one at a time, in timed relation to movement of the conveyor, first folding means disposed forwardly of the magazine for forming each successive blank in the shape of a substantially channel-shaped carrier having spaced first and second side walls and wherein the second side wall is of substantially greater height than the first side wall, an article dispensing station disposed forwardly of the first folding means, said article dispensing station comprising means for supporting a row of articles at a point spaced above the conveyor, means operable automatically upon each successive carrier in channel-shaped form moving to a position beneath the means for supporting the row of articles for directing a predetermined number of articles in said row downwardly between the first and second side walls of the carrier, a second folding means to fold each successive carrier in the form of a substantially rectangular tube at a point forwardly of the article dispensing station upon forward movement of the conveyor, a carrier stacking station disposed forwardly of the second folding means, comprising a stacking plate disposed to one side of the conveyor and normally being disposed in substantially the same horizontal plane as the conveyor, a transfer plate normally disposed adjacent the opposite side of the conveyor from that adjacent which the stacking plate is disposed and being disposed in substantially lateral alinement with said stacking plate relative to the conveyor, cam controlled

means for moving the transfer plate transversely of and across the upper surface of the conveyor for engaging each successive carrier as it is advanced thereto by the conveyor and moving the same off of the conveyor and onto the stacking plate, means operable automatically upon each carrier being positioned upon the stacking plate for moving the stacking plate upwardly and then returning the same to its normal position, means to support each successive carrier in the position to which it is raised by the carrier stacking plate to thereby form a stack of superposed carriers spaced above the normal position of the stacking plate, means for supporting an open-ended container to one side of the stack of carriers as the stack is formed by the stacking plate, and means operable automatically upon a predetermined number of carriers being stacked by the stacking plate for moving at least some of the carriers in said stack to one side of the position in which they were stacked by the stacking plate to thus move the carriers into the container.

63. In a structure according to claim 62, means operable automatically for stopping the conveyor in the event of an obstruction being disposed in the path of the transfer plate as the transfer plate moves transversely of the conveyor.

64. In a structure according to claim 62, means operable automatically for stopping the conveyor in the event of an obstruction being disposed in the path of the carrier being transferred by the transfer plate as it moves transversely of the conveyor.

65. A machine for packaging individual rows of articles in the carriers while forming said carriers from relatively thin flat substantially rectangular blanks and for stacking said carriers in superposed relation comprising a driven horizontally disposed conveyor, a magazine for containing a supply of said blanks, means for successively feeding the blanks from the magazine to the conveyor, one at a time, in timed relation to movement of the conveyor, first folding means disposed forwardly of the magazine for forming each successive blank in the shape of a substantially channel-shaped carrier having spaced first and second side walls and wherein the second side wall is of substantially greater height than the first side wall, an article dispensing station disposed forwardly of the first folding means, said article dispensing station comprising means for supporting a row of articles at a point spaced above the conveyor, means operable automatically upon each successive carrier in channel-shaped form moving to position beneath the means for supporting the row of articles for directing a predetermined number of articles in said row downwardly between the first and second side walls of the carrier, a second folding means for folding each successive carrier in the form of a substantially rectangular tube at a point forwardly of the article dispensing station upon forward movement of the conveyor comprising a horizontally disposed laterally movable folding plate normally disposed to one side of the conveyor and in a horizontal plane substantially above the conveyor, cam controlled means operable upon each successive carrier being advanced forwardly of the article dispensing station for moving the laterally movable folding plate transversely of the conveyor over the articles in the corresponding carrier and in engagement with the second side wall to thereby fold the second side wall intermediate its upper and lower edges to form an upper wall on the

carrier extending over the articles in the carrier, a carrier stacking station disposed forwardly of the means for forming each successive carrier in the shape of a substantially rectangular tube and comprising a stacking plate disposed to one side of the conveyor and normally being disposed in substantially the same horizontal plane as a conveyor, means operable automatically upon each successive carrier being advanced to the carrier stacking station for moving the same off of the conveyor and onto the stacking plate, cam controlled means operable in timed relation to the movement of the means for moving each successive carrier off of the conveyor and onto the stacking plate for moving the stacking plate upwardly and then returning the same to its normal position, means to support each successive carrier in the position to which it is raised by the carrier stacking plate to thereby form a stack of superposed carriers spaced above the normal position of the stacking plate, means for supporting an open-ended container to one side of the stack of carriers as it is formed by the stacking plate and means operable automatically upon a predetermined number of carriers being stacked by the stacking plate for moving at least some of the carriers in said stack to one side of the position in which they were stacked by the stacking plate to thus move the carriers into the container.

66. In a structure according to claim 65, means operable automatically for stopping the machine in the event of an obstruction being disposed in the path of the stacking plate in the course of its upward movement in forming a stack of carriers.

67. In a structure according to claim 65, means operable automatically for stopping the machine in the event of an obstruction being disposed in the path of a carrier above the stacking plate in the course of its upward movement as the stack of carriers is formed.

68. A machine for packaging individual rows of articles in carriers while forming said carriers from relatively thin flat substantially rectangular blanks and for stacking said carriers in superposed relation comprising a horizontally disposed conveyor, means for driving the conveyor in a step-by-step manner, a magazine for containing a supply of said blanks, means for successively feeding the blanks from the magazine to the conveyor, one at a time, in timed relation to movement of the conveyor, first folding means disposed forwardly of the magazine for forming each successive blank in the shape of a substantially channel-shaped carrier having spaced first and second side walls and wherein the second side wall is of substantially greater height than the first side wall, an article dispensing station disposed forwardly of the first folding means, said article dispensing station comprising means for supporting a row of articles thereon at a point spaced above the conveyor, means operable automatically upon each successive carrier in channel-shaped form moving to a position beneath the means for supporting the row of articles for directing a predetermined number of articles in said row downwardly between the first and second side walls of the carrier, second folding means for folding each successive carrier in the form of a substantially rectangular tube at a point forwardly of the article dispensing station upon forward movement of the conveyor, a carrier stacking station disposed forwardly of the second folding means and comprising a stacking

70
75

plate disposed to one side of the conveyor and normally being disposed in substantially the same horizontal plane as the conveyor, means operable automatically upon each successive carrier being advanced to the carrier stacking station for moving the same off of the conveyor and onto the stacking plate, means operable automatically upon each carrier being positioned upon the stacking plate for moving the stacking plate upwardly and then returning the same to its normal position, means for supporting each successive carrier in the position to which it is raised by the carrier stacking plate to thereby form a stack of superposed carriers spaced above the normal position of the stacking plate, a stacker housing spaced above the normal position of the stacking plate and comprising a first stacking guide plate and a second stacking guide plate spaced from the first stacking guide plate and upwardly between which the successive carriers are moved upon each carrier being raised by the stacking plate, the lower edges of the stacking guide plates being positioned immediately above the means for supporting each successive carrier in the position to which it is raised by the carrier stacking plate, said first and second stacking guide plates having coinciding openings therein, means on the first stacking guide plate for supporting an open-ended container with its open end in alignment with the opening in the first stacking guide plate, a stack transfer plate registering with the opening in the second stacking guide plate, a driven cam movable in timed relation to each step in movement of the conveyor, a resilient mechanical connection between the cam and the stack transfer plate normally tending to urge the stack transfer plate through the opening in the second stacking guide plate to move the corresponding carriers disposed between the stacking guide plates through the opening in the first stacking guide plate and into the container, locking means to prevent movement of the stack transfer plate through the opening in the second stacking guide plate during certain cycles in movement of said cam, and means operable automatically upon a predetermined number of carriers being positioned between the stacking guide plates for releasing the stack transfer plate from the locking means to thereby permit the stack transfer plate to move through said openings for transferring a predetermined number of said carriers into the container.

69. In a structure according to claim 68, said means for supporting each successive carrier in the position to which it is raised by the carrier stacking plate comprising a pair of horizontally disposed filled carrier retaining bars, one each positioned beneath the lower edge of each of the stacking guide plates, spring means normally urging said filled carrier retaining bars inwardly of the vertical planes of the stacking guide plates, the proximate edges of the filled carrier retaining bars being beveled from their lowermost and innermost edges upwardly and inwardly to provide upwardly converging proximate edges thereon whereby, upon each successive carrier being raised by the stacking plate, the upper outside edges of the carrier will engage the upwardly converging proximate edges of the filled carrier retaining bars to urge the same outwardly and, upon the stacking plate moving the corresponding carrier above the carrier retaining bars, the carrier retaining bars will move inwardly beneath the corresponding carrier and will support the

corresponding carrier as the stacking plate returns to its normal position.

70. In a structure according to claim 68, said locking means to prevent movement of the stack transfer plate during certain cycles of the cam comprising a locking pin, said resilient mechanical connection having at least one hole therein registering with the locking pin, a solenoid connected to the locking pin, means for supporting the solenoid in fixed relation to the stacker housing, a normally open switch spaced substantially above the lower edges of the stacking guide plates and having actuating means thereon positioned in the path of the uppermost carrier upon a predetermined number of carriers being raised by the stacking plate to thus cause the switch to be closed by the uppermost of a predetermined number of carriers positioned between the stacking guide plates, electrical connections between opposite sides of the switch and the solenoid and a source of electrical energy and an electrical connection between the proximate sides of the switch and the solenoid whereby, upon said switch being closed, the solenoid will be energized to withdraw the locking pin from the hole in said resilient mechanical connection and whereby, upon the next movement by the cam, the stack transfer plate will be caused to move through the opening in the second stacking guide plate for transferring at least some of the carriers in said stack into the container supported by the first stacking guide plate.

71. A machine for forming a carrier from a substantially rectangular blank and for placing articles in said carrier comprising means for directing articles into the machine to a predetermined position, means for successively conveying the carriers in blank form into the machine one at a time, means for folding portions of each successive carrier to form first and second flaps on the carrier wherein the first flap is relatively shorter than the second flap, an article dispensing station disposed forwardly of the means for folding portions of the carriers, means for positioning the carriers at said article dispensing station, means for directing a predetermined number of said articles into the corresponding carrier, means for maintaining the first and second flaps in substantially perpendicular relation to the body of the carton as the articles are directed therebetween, means for advancing the successive carriers beyond the point at which the articles are directed thereinto, means for folding a portion of the second flap across the articles previously directed into the carrier to form the carrier in the shape of a substantially rectangular tube, means for fastening the last-named portion of the second flap to the first flap, said means for advancing the carrier also being operable to advance the carrier beyond the means for fastening said flaps together, means for stacking the successive filled carriers in superposed relation to each other, means operable automatically upon a predetermined number of filled carriers being stacked for moving said predetermined number of filled carriers away from said stacking point.

72. Apparatus for forming carriers from carrier blanks in sheet form and packaging articles therein comprising a magazine for containing a supply of carriers in blank form, an intermittently driven conveyor positioned adjacent the magazine, means operable automatically in timed relation to movement of said conveyor for successively feeding the carriers in blank form to

the conveyor as the conveyor is advanced, means operable automatically for folding opposite side portions of the carrier into substantially perpendicular relation to the body of the carrier to

5 form a flat-bottomed channel, means containing a supply of articles, means operable automatically for positioning a predetermined number of articles in the carrier in its channel-shaped form, means for folding a portion of the carrier about

10 the articles in said carrier, means operable automatically for fastening the ends of the carrier together to form a substantially rectangular tube having the articles disposed therein, means for moving the corresponding carrier with articles

15 therein off of the conveyor, means for stacking successive carriers in superposed position as they are moved away from said conveyor successively, and means for moving a predetermined number of stacked carriers away from said stacking

20 means.

73. A machine for forming carriers from flat substantially rectangular blanks and placing articles in the carriers as they are formed comprising means for conveying the carriers in blank

25 form into the machine, an article dispensing station, means for feeding the articles to the article dispensing station in the form of a row of articles, means in advance of the article dispensing station for folding each successive carrier in blank

30 form into the form of a channel, means for positioning the carrier in channel-shaped form adjacent the article dispensing station, means for dispensing a predetermined number of articles at the end of said row of articles into said carrier

35 in channel-shaped form, means for folding said carrier about said articles previously positioned in said carrier to form a substantially tubular carrier being substantially rectangular in cross-section, means operable automatically to

40 secure the proximate edges of the carrier blank together, means for elevating each successive filled carrier beneath each preceding filled carrier to form a stack of filled carriers, and means operable automatically on a predetermined number of the filled carriers being stacked for moving

45 a predetermined number of the filled carriers away from said stacking means.

74. Apparatus for forming carriers from flat substantially rectangular sheets of paper board and the like while filling each carrier with a row

50 of cylindrical articles comprising a magazine for supporting a stack of superposed substantially rectangular sheets therein, an intermittently driven conveyor disposed forwardly of said magazine, means for successively feeding the rectangular

55 sheets, one at a time, onto the conveyor upon a first step being imparted to the conveyor, a first folding means disposed adjacent the conveyor forwardly of the point at which the successive sheets are fed to the conveyor and being

60 operable upon a second step being imparted to the conveyor for folding opposite side portions of the corresponding sheet to form a substantially channel-shaped carrier, article dispensing means disposed adjacent said conveyor, means for directing a row of articles into said article dispensing means, means operable automatically upon a third step being imparted to the conveyor for

65 actuating the article dispensing means to permit the articles to be directed into the substantially channel-shaped carrier, a second folding means disposed forwardly of the article dispensing means, means automatically operable upon a fourth step being imparted to the conveyor for

70 folding at least one of said previously formed side

75 folding at least one of said previously formed side

101

portions of the carrier across the articles positioned therein to form a substantially rectangular tube, securing means operable automatically upon a fifth step being imparted to the conveyor for securing the end portion of the last-named portion of the carrier to the end portion of the other side portion of the carrier, a stacking plate disposed to one side of the conveyor, means operable automatically upon a subsequent step being imparted to the conveyor for moving each successive filled carrier onto the stacking plate, means operable automatically in timed relation to the movement of each successive filled carrier onto the stacking plate for elevating and lowering the stacking plate, filled carrier retaining means disposed above the stacking plate for retaining each successive carrier elevated by the stacking plate as said stacking plate returns to its normal position, a stack transfer member normally disposed to one side of and above the horizontal plane of the filled carrier retaining means, and means operable automatically in response to a predetermined number of filled carriers being stacked upon the filled carrier retaining means for moving at least some of the filled carriers off of the filled carrier retaining means simultaneously.

75. A machine for packaging individual rows of articles in carriers and arranging the carriers in a stack and packaging stacks of carriers in a container comprising a driven horizontal conveyor, means for feeding flat substantially rectangular carrier blanks to the conveyor in timed relation to the movement of the conveyor, an article dispensing station disposed above the path of travel of the conveyor, means for guiding a row of articles to the article dispensing station, a first folding means disposed in advance of the article dispensing station for folding each successive carrier blank to form a carrier having first and second spaced side walls extending perpendicularly from opposite edges of a bottom wall, said first folding means being so positioned relative to the feeding means as to form the first wall of substantially less height than the second wall, said first folding means also including means for forming a handle flap projecting from the upper edge of the first wall, means operable automatically upon each successive carrier being advanced on the conveyor to a position below the article dispensing station for directing a predetermined number of articles between the first and second walls and onto the bottom of said carrier, a second folding means disposed forwardly of the article dispensing station for folding the second wall intermediate its upper and lower edges to form an upper flap extending across the upper surfaces of the articles previously positioned in the carrier and also overlapping the projecting handle flap of the first wall as the conveyor advances the corresponding carrier forwardly beyond the article dispensing station, means for securing the overlapping portion of the second wall to the handle flap on the first wall upon the conveyor advancing each successive carrier beyond the second folding means, third folding means disposed forwardly of said means for securing the overlapping portion of the second wall to the handle flap of the first wall for folding the handle flap of the first wall and the corresponding overlapping portion of the second wall against the outer surface of the first wall to form a handle flap from the portion of the second wall which overlaps the handle flap of the first wall, a stacking station disposed forwardly

102

of the third folding means and comprising a vertically reciprocable stacking plate normally positioned in substantially the same horizontal plane as the upper surface of the conveyor, means operable automatically upon each successive carrier being advanced to a position in alignment with the stacking plate for moving each successive carrier off of the conveyor and onto the stacking plate, means operable in timed relation to the movement of each successive conveyor onto the stacking plate for elevating and then lowering the stacking plate, means for retaining each successive carrier elevated by the stacking plate in a predetermined position spaced above the normal lowered position of the stacking plate whereby each successive carrier elevated by the stacking plate will engage the carrier disposed thereabove to elevate the same, and stack transfer means operable automatically upon a predetermined number of articles being stacked above the stacking plate for transferring the stack of carriers to one side of the vertical plane of the stacking plate.

76. In a structure according to claim 75, said first folding means comprising a stationary folding die closely spaced above the path of travel of the conveyor and having spaced parallel opposite side edges, a pair of vertically movable horizontally disposed flap folding bars normally disposed below the horizontal plane of the upper surface of the conveyor and adjacent opposite sides of the conveyor, means operable automatically upon each successive blank being advanced to a position beneath the folding die for moving said folding bars upwardly at least partially past and adjacent opposite sides of the folding die to fold the blank in the form of the substantially channel-shaped carrier having first and second spaced side walls.

77. In a structure according to claim 76, said folding die having an outwardly extending lateral flap folding plate thereon projecting outwardly beyond one of its side edges, a laterally movable flap folding bar spaced immediately below the lateral flap folding plate, and means operable automatically upon said external flap folding bars moving upwardly and forming the side walls of the channel-shaped carrier for moving said flap folding bar inwardly beneath the lateral flap folding plate to thereby fold the corresponding side wall of the carrier intermediate its upper and lower edges to form the handle flap projecting from the upper edge of the first side wall of the carrier.

78. A machine for packaging cylindrical articles in carriers while forming said carriers from flat substantially rectangular blanks comprising an intermittently driven horizontal conveyor, a magazine disposed rearwardly of said conveyor for containing a supply of blanks, means operable automatically in timed relation to the intermittent movement of said conveyor for successively feeding blanks from the magazine, one at a time, to the conveyor, an article dispensing station spaced forwardly from the magazine, means between the article dispensing station and the magazine for forming each successive blank as a carrier substantially in the shape of an open-ended channel having a bottom wall and spaced side walls, said article dispensing station comprising means for positioning a row of articles, including a predetermined number of said articles, in each successive carrier in timed relation to the movement of said conveyor, means for forming each successive carrier substantially in

103

the shape of an open-ended substantially rectangular tube with a row of articles therein, means operable automatically for securing opposite edges of the carrier together to maintain them in said tubular shape, means operable automatically for stacking the carriers in superposed relation, and means operable automatically upon a predetermined number of carriers being stacked for moving said stack of carriers away from said stacking means.

79. In a structure according to claim 78, said conveyor comprising an endless belt having a plurality of equally spaced carrier clamping devices thereon, each comprising an inner jaw and an outer jaw, spring means normally urging the jaws to closed position with respect to each other, means operable automatically in timed relation to movement of said conveyor for momentarily opening the jaws upon each blank being fed to the conveyor and then closing the same so the leading edge of each successive blank is clamped between said jaws, the outer jaw associated with each of said clamping devices having at least one retaining projection thereon for limiting movement of the articles positioned upon the bottom wall of the corresponding carrier at the article dispensing station, and said conveyor also having a plurality of equally spaced article retaining members thereon each being spaced a predetermined distance from a corresponding clamping device for also retaining the articles on the bottom wall of the carrier as the articles are deposited between the article retaining member and the article retaining projection on the corresponding clamping device to thereby insure that the articles and the corresponding carrier are advanced in unison by the conveyor.

80. In a structure according to claim 78, means preventing operation of said article dispensing means in the event of there being less than the predetermined number of articles positioned at the article dispensing station.

81. In a structure according to claim 78, means preventing operation of the article dispensing means in the event the foremost article in a row directed to the carrier is disposed in a skewed position relative to the direction of travel of the conveyor.

82. A machine for packaging cylindrical articles in carriers while forming said carriers from flat substantially rectangular blanks comprising an intermittently driven horizontal conveyor, a magazine disposed rearwardly of said conveyor for containing a supply of blanks, means operable automatically in timed relation to the intermittent movement of said conveyor for successively feeding blanks from the magazine, one at a time, onto the conveyor, an article dispensing station spaced forwardly from the magazine, means between the article dispensing station and the magazine for forming each successive blank as a carrier substantially in the shape of an open-ended channel having a bottom wall and spaced side walls as each blank is advanced by the conveyor, said article dispensing station including a pair of vertically disposed transversely spaced article guide plates astride which the side walls of the carrier are positioned upon each successive carrier being advanced to the article dispensing station by the conveyor, an inclined chute having top and bottom walls and spaced side walls, the lower ends of the top and bottom walls terminating adjacent the rear portions of the article guide plates at the conveyor, a gate normally positioned adjacent the open lower

104

end of the inclined chute, means operable automatically upon a predetermined number of articles being positioned on a carrier for moving the gate into the path of the articles in the chute to thereby prevent additional articles from moving between the article guide plates and onto the carrier, means operable automatically upon said filled carrier being moved from said article dispensing station and another carrier being positioned at said article dispensing station for moving said gate away from the open lower end of the chute to permit articles in the chute to move between said article guide plates and onto said carrier for a repeat operation, means for forming each successive carrier substantially in the form of an open-ended substantially rectangular tube with a row of articles therein, means operable automatically for securing opposite edges of the carrier together to maintain said tubular shape, means operable automatically for stacking the carriers in superposed relation, and means operable automatically upon a predetermined number of carriers being stacked for transferring the stack of carriers away from said stacking means.

83. In a structure according to claim 82, means operable automatically upon the absence of a carrier on that portion of the conveyor disposed beneath the article dispensing means upon cessation of a step in movement by the conveyor to prevent the article dispensing means from directing articles to the conveyor.

84. A machine for packaging cylindrical articles in carriers while forming said carriers from flat substantially rectangular blanks comprising an intermittently driven horizontal conveyor, a magazine disposed rearwardly of said conveyor for containing a supply of blanks, means operable automatically in timed relation to the intermittent movement of said conveyor for successively feeding blanks from the magazine, one at a time, to the conveyor, an article dispensing station spaced forwardly from the magazine, means between the article dispensing station and the magazine for forming each successive blank as a carrier substantially in the shape of an open-ended channel having a bottom wall and spaced side walls as each blank is advanced by the conveyor, said article dispensing station comprising a pair of vertically disposed transversely spaced article guide plates astride which the side walls of the conveyor are positioned upon each successive carrier being advanced to the article dispensing station by the conveyor, an inclined chute having a bottom wall and spaced side walls, the lower end of the bottom wall terminating adjacent the vertical guide plate, whereby the articles may move downwardly along the chute to a position between the article guide plates, means operable automatically upon each successive carrier being properly positioned in the article dispensing station for simultaneously directing a row of articles from said chute between said article guide plates and onto the bottom of said carrier, a gate normally positioned adjacent the open lower end of the inclined chute and means operable automatically in timed relation to the movement of said conveyor for operating said gate for limiting movement of the articles in said chute, means for forming each successive carrier substantially in the shape of an open-ended substantially rectangular tube with a row of articles therein upon the conveyor moving the articles forwardly beyond the article dispensing station, means operable automatically for securing

opposite edges of the successive carriers together upon the conveyor moving the carriers forwardly beyond the last-named means to maintain the carriers in said tubular shape, automatically operable means disposed forwardly of the securing means for stacking the carriers in superposed relation, means for supporting a box having one end open adjacent the point at which the carriers are stacked, and means automatically operable upon a predetermined number of carriers being stacked for transporting said stack of carriers into said box.

85. A machine for packaging individual rows of articles in carriers and arranging the carriers in a stack and packaging a stack of carriers in a container comprising an elongated horizontally disposed trackway, means for feeding flat substantially rectangular carrier blanks onto the trackway, means for propelling the blanks forwardly along said trackway, an article dispensing station disposed above the trackway, a first folding means disposed in advance of the article dispensing station for folding each successive blank to form a carrier having first and second spaced walls extending upwardly from opposed edges of a bottom wall, said first folding means being so positioned relative to the means for feeding carrier blanks onto the trackway as to form the first wall of substantially less height than the second wall, said first folding means also including means for forming a first handle flap projecting outwardly from one edge of the first wall, means operable automatically upon each successive carrier being advanced on the trackway to a position below the article dispensing means for dispensing a predetermined number of articles from said article dispensing means and positioning the same between the first and second walls and onto the bottom of said carrier, a second folding means disposed forwardly of the article dispensing station for folding the second wall intermediate its upper and lower edges to form a flap extending across the upper surfaces of the articles previously positioned in the carrier and also overlapping the first handle flap of the first wall as the corresponding carrier is propelled forwardly beyond the article dispensing station, the first of the last-named flaps overlapping the first handle flap constituting a second handle flap, means for securing the first handle flap to the second handle flap upon each successive carrier being propelled beyond the second folding means, third folding means disposed forwardly of the means for securing the handle flaps together for folding the handle flaps against the outer surface of the first wall, a stacking station disposed forwardly of the third folding means and comprising a vertically reciprocable stacking plate normally positioned at substantially the same horizontal plane as the upper surface of the trackway, means operable automatically upon each successive carrier being propelled along the trackway to a position in alignment with the stacking plate for moving each successive carrier off of the trackway and onto the stacking plate, means operable in timed relation to the movement of each successive carrier onto the stacking plate for elevating and lowering the stacking plate, means for retaining each successive carrier elevated by the stacking plate in a predetermined spaced relation above the normal lowered position of the stacking plate, whereby each successive carrier elevated by the stacking plate will engage the carrier disposed thereabove to elevate the same therewith, and

stack transfer means operable automatically upon a predetermined number of carriers being stacked above the stacking plate for transferring at least some of the carriers in said stack to one side of the vertical plane of the stacking plate, whereby a container may be positioned opposite the stack transfer means for receiving the filled carriers transferred thereinto by the stack transfer means.

86. Apparatus for forming carriers from flat substantially rectangular sheets of paper board and the like while filling each carrier with a row of articles comprising a magazine for supporting a stack of superposed rectangular sheets therein, a conveyor disposed forwardly of said magazine, means to drive said conveyor in a step-by-step manner, means for feeding the rectangular sheets, one at a time, onto the conveyor upon each successive step being imparted to the conveyor, a first folding means disposed adjacent the conveyor forwardly of the point at which the successive sheets are fed to the conveyor and being operable upon each successive step being imparted to the conveyor for folding opposite side portions of the corresponding sheet upwardly to form a substantially channel-shaped carrier, article dispensing means disposed above the conveyor forwardly of said first folding means, means for directing a row of articles from said article dispensing means upon each successive step being imparted to the conveyor for depositing said articles into the corresponding substantially channel-shaped carrier, a second folding means disposed forwardly of the article dispensing means, means operable automatically upon each successive step being imparted to the conveyor for folding at least one of said previously formed side portions of the corresponding carrier horizontally across the upper surfaces of the articles positioned therein to form a filled carrier substantially in the shape of a rectangular tube, fastening means operable automatically upon each successive step being imparted to the conveyor for securing said horizontal portions of one of the side portions to the upper portion of the other of the side portions of the corresponding carrier, a horizontally disposed stacking plate disposed to one side of the conveyor forwardly of the fastening means and normally being disposed in substantially the same horizontal plane as the conveyor, means operable automatically upon each successive step being imparted to the conveyor for moving the corresponding filled carrier onto the stacking plate, means operable automatically in timed relation to the movement of each successive carrier onto the stacking plate for elevating the stacking plate, filled carrier retaining means disposed above the stacking plate for retaining each successive carrier elevated by the stacking plate as said stacking plate returns to its normal position in the horizontal plane of the conveyor, a stack transfer member normally disposed to one side of, and above the horizontal plane of, the filled carrier retaining means, and means operable automatically in response to a predetermined number of filled carriers being stacked upon the filled carrier retaining means for moving at least some of the filled carriers off of the filled carrier retaining means simultaneously whereby an open-ended box may be positioned in alignment with the stack transfer member and the filled carriers may be ejected into the box.

87. A machine for packaging individual rows of articles in carriers while forming said carriers from relatively thin flat substantially rectangular

blanks and for stacking said carriers in superposed relation comprising a driven horizontally disposed conveyor, a magazine for containing a supply of blanks, means for successively feeding the blanks from the magazine to the conveyor, one at a time, in timed relation to the movement of the conveyor, means disposed forwardly of the magazine for forming each successive blank in the shape of a substantially channel-shaped carrier having spaced first and second side walls wherein the second side wall is of substantially greater height than the first side wall, an article dispensing station disposed forwardly of the means for forming each successive blank in the shape of a substantially channel-shaped carrier, means automatically operable for actuating said article dispensing station to permit a row of articles to move downwardly by gravity between the first and second side walls of a corresponding carrier in timed relation to the movement of the conveyor, means for folding each successive carrier in the form of a substantially rectangular tube at a point forwardly of the article dispensing station upon forward movement of the conveyor, a carrier stacking station disposed forwardly of the means for forming each successive carrier in the shape of a substantially rectangular tube and comprising a stacking plate disposed at one side of the tube and normally being disposed in substantially the same horizontal plane as the conveyor, means operable automatically upon each successive carrier being advanced to the carrier stacking station for moving the same off of the conveyor and onto the stacking plate, means operable automatically upon each carrier being positioned upon the stacking plate for moving the stacking plate upwardly and then returning the same to its normal position, means for supporting each successive carrier in the position to which it is raised by the stacking plate to thereby form a stack of superposed carriers spaced above the normal position of the stacking plate, means for supporting an open-ended container adjacent one side of the stack of carriers formed by the stacking plate, and means operable automatically upon a predetermined number of carriers being stacked upon the stacking plate for moving the stack of carriers into the open-ended container.

88. A machine for packaging individual rows of articles in carriers while forming said carriers from relatively thin flat substantially rectangular blanks and for stacking said carriers in superposed relation comprising an intermittently driven horizontally disposed conveyor, a magazine for containing a supply of blanks, means for successively feeding the blanks from the magazine to the conveyor, one at a time, in timed relation to the movement of the conveyor, means disposed forwardly of the conveyor for forming each successive blank in the shape of a substantially channel-shaped carrier having spaced first and second side walls and wherein the second side wall is of substantially greater height than the first side wall, an article dispensing station disposed forwardly of the means for forming each successive blank in the shape of a substantially channel-shaped carrier, said article dispensing station comprising a framework, a pair of longitudinally extending transversely spaced article guide plates supported in the framework and disposed adjacent opposite sides of the conveyor, an inclined chute comprising a bottom wall and spaced side walls, the open lower end of said chute being aligned with the article guide plates, means operable automatically in timed

relation to the movement of said conveyor for permitting a plurality of articles to move, by gravity, from said chute onto a channel-shaped carrier on said conveyor, means for folding each successive carrier in the form of a substantially rectangular tube at a point forwardly of the article dispensing station upon forward movement of the conveyor, a carrier stacking station disposed forwardly of the means for forming each successive carrier in the shape of a substantially rectangular tube and comprising a stacking plate disposed to one side of the conveyor and normally being disposed in substantially the same horizontal plane as the conveyor, means operable automatically upon each successive carrier being advanced to the stacking station for moving the same off of the conveyor and onto the stacking plate, means operable automatically upon each carrier being positioned upon the stacking plate for moving the stacking plate upwardly and then returning the same to its normal position, means for supporting each successive carrier in the position to which it is raised by the stacking plate to thereby form a stack of superposed carriers spaced above the normal position of the stacking plate, means for supporting the open end of an open-ended container adjacent one side of the stack of carriers formed by the stacking plate, and means operable automatically upon a predetermined number of carriers being stacked by the stacking plate for moving the stack of carriers into the open-ended container.

89. In a structure according to claim 88, retaining means associated with said article dispensing means, and means operable automatically upon a carrier on the conveyor being positioned beneath the article dispensing means for releasing the retaining means to permit the articles to move by gravity from the article dispensing means to the carrier.

90. In a structure according to claim 88, means controlled by the leading article directed from the article dispensing means upon the leading article being properly positioned by the article dispensing means for effecting each successive step in movement to the conveyor whereby, upon the absence of a row of articles at the article dispensing station, the conveyor will remain stationary.

91. A machine for packaging individual rows of articles in carriers and arranging the carriers in a stack and packaging a stack of carriers in a container comprising an elongated horizontally disposed trackway, means for feeding flat substantially rectangular carrier blanks onto the trackway, means for propelling the blanks forwardly along said trackway, an article dispensing station disposed above the trackway and including means for guiding a row of articles onto the trackway, a first folding means disposed in advance of the article dispensing station for folding each successive carrier blank comprising a fixed folding die closely spaced above the trackway and having spaced parallel opposite side edges, a pair of vertically movable horizontally disposed external flap folding bars normally disposed below the level of the upper surface of the trackway and adjacent opposite sides of the trackway, cam control means operable in timed relation to the means for propelling said blanks along said trackway for moving said folding bars upwardly adjacent opposite side edges of the folding die as each successive blank is positioned beneath the folding die to form the blank in the form of a carrier

having first and second spaced side walls extending upwardly from opposite side edges of a bottom wall, said first folding means being so positioned relative to the means for feeding carrier blanks onto the trackway as to form the first wall of substantially less height than the second wall, means operable automatically upon each successive carrier being advanced on the trackway to a position below the article dispensing means for operating said article dispensing means to permit a predetermined number of articles to move downwardly by gravity between the first and second side walls and onto the bottom wall of said carrier, a second folding means disposed forwardly of the article dispensing station for folding the second wall intermediate its upper and lower edges to form a flap extending across the upper surfaces of the articles previously positioned in the carrier as the corresponding carrier is propelled forwardly beyond the article dispensing station, means for securing the upper edge of the first wall to the corresponding edge of the flap formed by the second folding means upon each successive carrier being propelled beyond the second folding means, a stacking station disposed forwardly of the means for securing the upper edge of the first wall to the flap formed by the second folding means, said stacking station comprising a vertically reciprocable stacking plate positioned to one side of said trackway and normally being disposed at substantially the same level as the upper surface of the trackway, means operable automatically upon each successive carrier being propelled along the trackway to a position adjacent the stacking plate for moving each successive carrier off of the trackway and onto the stacking plate, means operable automatically in timed relation to the movement of each successive carrier onto the stacking plate for elevating and then lowering the stacking plate, means to support each successive carrier elevated by the stacking plate in a predetermined spaced relation above the normal lowered position of the stacking plate, whereby each successive carrier elevated by the stacking plate will engage a carrier which may be disposed therabove to elevate the same therewith, and stack transfer means operable automatically upon a predetermined number of carriers being stacked above the stacking plate for transferring at least some of the carriers in said stack to one side of the vertical plane of the stacking plate, whereby a container may be positioned opposite the stack transfer means for receiving the filled carried transferred thereto by the stack transfer means.

92. In a structure according to claim 91, said folding die of the first folding means having a lateral flap folding plate thereon projecting outwardly from the side edge thereof at which the first side wall of the carrier is formed and being spaced a predetermined distance above the lower surface of the corresponding side edge of the folding guide, a laterally movable flap folding bar normally spaced adjacent the outer edge of the lateral flap folding plate and being movable to a position spaced below the lateral flap folding plate, and cam controlled means operable in timed relation to the upward movement of the external flap folding bars for moving said movable flap folding bar inwardly beneath the lateral flap folding plate to thereby bend the corresponding side wall of the carrier intermediate its upper and lower edges to form a first handle flap projecting outwardly from the upper edge of the first side wall of the container.

93. A machine for packaging individual rows of articles in carriers while forming said carriers from relatively thin flat substantially rectangular blanks and for stacking said carriers in superposed relation comprising a horizontally disposed conveyor, means for driving the conveyor in a step-by-step manner, a magazine for containing a supply of said blanks, means for successively feeding the blanks from the magazine to the conveyor, one at a time, in timed relation to the movement of the conveyor, first folding means disposed forwardly of the magazine for forming each successive blank in the shape of a substantially channel-shaped carrier having spaced first and second side walls and wherein the second side wall is of substantially greater height than the first side wall, an article dispensing station disposed forwardly of the first folding means, said article dispensing means comprising means for supporting a row of articles thereon at a point spaced above the conveyor, means operable automatically upon each successive carrier in channel-shaped form moving to a position beneath the means for supporting the row of articles for directing a predetermined number of articles in said row downwardly between the first and second side rows of the carrier, second folding means for folding each successive carrier in the form of a substantially rectangular tube at a point forwardly of the article dispensing station upon forward movement of the conveyor, a carrier stacking station disposed forwardly of the second folding means and comprising a stacking plate disposed to one side of the conveyor and normally being disposed in substantially the same horizontal plane as the conveyor, means operable automatically upon each successive carrier being advanced to the carrier stacking station for moving the same off of the conveyor and onto the stacking plate, means operable automatically upon each carrier being positioned upon the stacking plate for moving the stacking plate upwardly and then returning the same to its normal position, means for supporting each successive carrier in the position to which it is raised by the carrier stacking plate to thereby form a stack of superposed carriers spaced above the normal position of the stacking plate, a stacker housing spaced above the normal position of the stacking plate and comprising a first stacking guide plate and a second stacking guide plate spaced from the first stacking guide plate and upwardly between which the successive carriers are moved upon each carrier being raised by the stacking plate, the lower edges of the stacking guide plate being positioned immediately above the means for supporting each successive carrier in the position to which it is raised by the carrier stacking plate, said first and second stacking guide plates having coinciding openings therein, means on the first stacking guide plate for supporting an open-ended container with its open end in alignment with the opening in the first stacking guide plate, a stack transfer plate registering with the opening in the second stacking guide plate, means for moving the stack transfer plate through the opening in the second stacking guide plate to move the corresponding carriers disposed between the stacking guide plates through the opening in the first stacking guide plate and into the container, said means being operable automatically upon a predetermined number of carriers being positioned between the stacking guide

111

plates for transferring a predetermined number of said carriers into the container.

94. In a structure according to claim 93, said means for supporting each successive carrier in the position to which it is raised by the carrier stacking plate comprising a pair of horizontally disposed filled carrier retaining bars, one each positioned beneath the lower edge of each of the stacking guide plates, spring means normally urging said filled carrier retaining bars inwardly of the vertical planes of the stacking guide plates, the proximate edges of the filled carrier retaining bars being beveled from their lowermost and innermost edges upwardly and inwardly to provide upwardly converging proximate edges thereon whereby, upon each successive carrier being raised by the stacking plate, the upper outside edges of the carrier will engage the upwardly converging proximate edges of the filled carrier retaining bars to urge the same outwardly and, upon the stacking plate moving the corresponding carrier above the carrier retaining bars, the carrier retaining bars will move inwardly beneath the corresponding carrier and will support the corresponding carrier as the stacking plate 25 returns to its normal position.

95. In a structure according to claim 93, said means for actuating said transfer plate comprising a switch positioned above said stacking plate and engageable by the uppermost carrier upon a predetermined number of carriers being raised by said stacking plate, a solenoid connected to said switch for operating said carrier transfer plate, whereby upon a predetermined number of carriers being positioned between the stacking guide plates, the switch will be engaged by the uppermost carrier for actuating said solenoid for in turn actuating the stack transfer plate to cause the same to move through the opening in the second stacking guide plate for transferring at least some of the carriers in said stack into the container supported by the first stacking guide plate.
